UNITED STATES PATENT OFFICE

2,200,856

TELEPHONE SYSTEM

John H. Voss, Downers Grove, Ill., assignor to
 Associated Electric Laboratories, Inc., Chicago,
 Ill., a corporation of Delaware

Application June 15, 1938, Serial No. 213,747

21 Claims. (Cl. 179—26)

The present invention relates to telephone systems in general, but is concerned more particularly with semi-automatic telephone systems, although certain of its features are not confined specifically thereto.

The main object of the invention is the production of new and improved circuit arrangements whereby connections between manual lines entering an exchange may be set up by automatic switches under the control of an operator at a switchboard in a remote exchange (hereinafter termed the control center). The invention is especially suitable for application to a cluster of small villages and rural population centers, in which case a plurality of semi-automatic exchanges (hereinafter termed sub-exchanges) may be individually trunked to a switching point (hereinafter termed a tandem exchange) and thence over a common group of trunks to a control center.

A further object of the invention is to provide means whereby a semi-automatic exchange (hereinafter termed a satellite exchange) may be trunked to a sub-tandem exchange and terminated therein on line equipment, thus the trunks from the sub-tandem exchange are made available to the satellite exchange.

A still further object of the invention is to provide means whereby an automatic exchange may trunk into the aforementioned control center and thus secure connection with the various exchanges in the semi-automatic network.

These and other objects and features, not specifically pointed out, will be apparent by referring to the accompanying drawings which, together with the detailed description, constitute the preferred embodiment of the invention.

The drawings, Figs. 1 to 38, inclusive, show by means of the usual circuit diagrams, a sufficient amount of apparatus to enable the invention to be discussed and understood.

Fig. 1 shows a trunking diagram of a telephone network employing the principles of this invention. The network consists, in part, of the automatic exchange "A", hereinafter termed the tandem exchange, which is a small exchange employing finder-connector links substantially as shown in Saunders Patent No. 1,999,788. This portion of the tandem exchange consists of line circuits LC—1 and LC—2, distributor DIS—1 and the finder-connector link FC—1. Further equipment at the tandem exchange comprises the incoming connector IC—1, the control group CG—1, the control center trunk switch TS—1, and the control group trunk switch TS—2.

The manual exchange "B" is hereinafter referred to as the control center, while the manual exchange "C" will be termed the magneto manual exchange.

The semi-automatic exchange D comprises line 5 circuits LC—3 and LC—5, distributor DIS—2, finder connector link FC—2, and tandem exchange trunk switch TS—3.

The semi-automatic exchange "E" comprises the line circuit LC—4 and the single finder-con- 10 nector link FC—3.

Fig. 2 shows line circuit LC—1 and finder F—1 of finder connector link FC—1, at the tandem exchange.

Figs. 3 and 4 show connector C—1 of the finder- 15 connector link FC—1.

Fig. 5 shows the distributor DIS—1.

Figs. 6, 7 and 8 show miscellaneous equipment at the tandem exchange. Fig. 6 shows conversa- 20 tion timing equipment CTE; operator's test circuit OTC; and tone relay circuits TRC—1. Fig. 7 shows ringing interrupter RI; permanent timing equipment PTE; and ringing connector RC—1. Fig. 8 shows supervisory alarm circuits SAC.

Fig. 9 shows trunk terminal equipment at ex- 25 change "C".

Fig. 10 shows line circuit LC—2 at the tandem exchange.

Fig. 11 is a chart explanatory of permanent 30 timing equipment PTE.

Fig. 12 is a chart explanatory of ringing inter- 35 rupter RI.

Fig. 13 shows trunk alternating relays TAR—1 associated with the trunks to the sub-tandem exchange, and trunk alternating relays TAR—2 35 associated with the trunks to the control group.

Fig. 14 shows the sub-tandem exchange trunk group STG, and trunk alternating relays TAR—3 associated with the control group trunk switches.

Fig. 15 shows the control group trunk switch 40 TS—2, and a portion of control group CG—1.

Figs. 16, 17, 18, 19, and 20 show control group CG—1, at the tandem exchange.

Fig. 21 shows control center trunk switch TS—1, and trunk alternating relays TAR—4 associated 45 with the control center trunk switches.

Fig. 22 shows the alarm forwarding equipment AFE located at the tandem exchange.

Fig. 23 shows trunk terminal equipment TTE at control center "B", and alarm receiving equip- 50 ment ARE.

Fig. 24 shows line circuits LC—3 and LC—5 at the sub-tandem exchange, and trunk alternating relays TAR—5 associated with the finder- connector links.

Fig. 25 shows distributor DIS-2 and finder F-2 of finder-connector link FC-2.

Figs. 26, 27, 28, and 29 show connector C-2 of finder-connector link FC-2.

5 Fig. 30 shows tandem exchange trunk switch TS-2, and trunk alternating relays TAR-6 associated with the tandem exchange trunk switches.

10 Fig. 31 shows miscellaneous equipment at the sub-tandem exchange, timing equipment TE (both permanent and conversation); ringing converter RC-2; and tone relay circuit TRC-2.

Fig. 32 shows line circuit LC-4 at the satellite exchange.

15 Figs. 33 and 34 show finder-connector link FC-3.

Figs. 35, 36, and 37 show incoming connector IC-1 at the tandem exchange.

20 Fig. 38 shows the significance of the reference characters used throughout the drawings. It will be noted that while both four and five digit numbers are used, it is always the hundreds digit that distinguishes between the reference to "conductors," "relays," or "miscellaneous equipment." The first digit or a four-digit number is the "figure" reference, as is also the first two digits of a five-digit number.

25 For convenience in locating the references, relay numbers have been assigned as 500, 510, 520, etc., across the figure from left to right. Odd-numbered spring combinations appear above the relay, numbering up; while even-numbered spring combinations appear below the relay, numbering down.

30 35 In order to obviate unnecessary repetition of description, the specification proper has been divided into three parts, first, a consideration of the trunking of each exchange, discussed under items A, B, C, and D; second a consideration of the operation at each exchange, discussed under items E, F, and G; and third, a description of the circuits in use at each exchange, discussed under items H, I, J, K, L, M, N, and O.

40 45 In order that an understanding may be had of a particular feature, without the necessity of following the operation from its inception, each subdivision of circuit operation is prefaced by a statement of the relays operated at that time.

50 55 A cross reference chart appears in Fig. 38, from which the item covering a desired explanation can be readily ascertained. For further convenience, the items are listed below in alphabetical order.

- Item A—Trunking—Tandem Exchange
- 55   B—Trunking—Magneto Manual Exchange
- C—Trunking—Sub-tandem Exchange
- D—Trunking—Satellite Exchange
- E—Operation—Tandem-exchange
- 60   E1—Local calls
- E2—Trunk calls
- E3—Incoming trunk calls
- E4—Paystation calls
- E5—Registration of calls
- 65   E6—Permanent line lockout
- E7—Trunk alternating relays
- E8—Alarm sender
- E9—Test facilities
- E10—Trunk busying
- Item F—Operation—Sub-tandem exchange
- 70   F1—Local Calls
- F2—Trunk calls
- F3—Incoming calls
- F4—Paystation
- Item G—Operation—Satellite exchange
- 75   G1—Local calls

- Item H—Circuit description—Tandem exchange
- H1—Station-to-station calls
- H1a—Making calling line busy
- H1b—Seizing the preselected link
- H1c—Distributor preselects next 5 idle trunk
- H1d—Calling subscriber does not dial
- H1e—Dialling the called subscriber
- H1f—Called line busy
- H1g—Seizing dialled line when idle
- H1h—Called party answers
- H1i—Release of the connection
- H2—Tandem station calls control center
- H2a—Dialling the digit "0"
- H2b—Seizing an idle control group
- H2c—Idle control center trunk switch finds calling control group
- H2d—Signalling the control center operator
- H2e—Control center operator answers
- H2f—Forwarding paystation tone
- H2g—Release of the connection
- H2h—Release, prior to answer by control operator
- H2i—All trunks to control center busy
- H2j—Meter circuit, tandem station calling control center
- H2k—Busying of control center trunk
- H3—Tandem station call magneto exchange
- H3a—Seizing the dialled line when it is idle
- H3b—Release of the connection
- H3c—Prevention of meter registration
- H4—Miscellaneous operations, tandem exchange
- H4a—Ringing interrupter RI
- H4b—Ringing converter RC-1
- H4c—Tone relay circuit TRC-1
- H4d—Permanent timing equipment PTE
- H4e—Control group trunk alternating relays TAR-2
- H4f—Outgoing sub-tandem exchange trunk alternating relays TAR-1
- H4g—Control group trunk switch alternating relays TAR-3
- H4h—Control center trunk alternating relays TAR-4
- H5—Power supervisory equipment, tandem office
- H5a—No danger fuse alarm
- H5b—Switch release alarm
- H5c—Distributor alarm
- H5d—Emergency fuse alarm
- H6—Test facilities
- H6a—Alarm forwarding circuit
- H6b—Operator dials test number
- Item I—Circuit description—Magneto manual exchange
- I1—Magneto manual exchange calls tandem exchange station
- I1a—making the called line busy
- I1b—called party answers
- I1c—Release of the connection
- I2—Magneto manual exchange calls control center

20	J1b—Idle finder-connector link finds calling line	L2c—Operator dials called number
25	J1c—Idle tandem exchange trunk switch finds calling link	L2d—Repeating impulses to the associated connector
30	J1d—Idle control group trunk switch finds calling sub-tandem exchange trunk	L2e—Dialling the associated connector
35	J1e—Idle control center trunk switch finds calling control group	L2f—Selecting idle trunk to sub-tandem exchange
40	J1f—Signalling the control center operator	L2g—Selecting idle finder connector link
45	J1g—Control center operator answers	L2h—Dialling connector at sub-tandem exchange
50	J1h—Forwarding paystation tone	L2i—Dialed line busy
55	J1i—Release of the connection	L2j—Seizure of idle line
60	Item K—Circuit description—Satellite exchange	L2k—Operator rings called line
65	K1—Local subscriber initiates call	L2l—Ringing off connection
70	K1a—Marking the calling line	L2m—Operator releases the connection
75	K1b—Link (if available) finds calling line	L3—Control center calls station in satellite exchange
80	K1c—Extending the call to the sub-tandem exchange	L3a—Seizure of line to satellite
85	K1d—Idle finder-connector link finds calling line	L3b—Dialling connector at satellite exchange
90	K1e—Idle tandem exchange trunk switch finds calling link	L3c—Dialed line busy
95	K1f—Idle remote control group trunk switch finds calling sub-tandem exchange trunk	L3d—Seizure of the called line
100	K1g—Idle control center trunk switch finds calling remote control group	L3e—Operator rings called line
105	K1h—Signalling the control center operator	L3f—Ringing off connection
110	K1i—Control center operator answers	L3g—Operator releases the connection
115	K1j—Forwarding paystation tone	L3h—Line to satellite busy
120	K1k—Release of the connection	L4—Miscellaneous operations—control center
125	Item L—Circuit description—Control center	L4a—Busying control center trunk
130	L1—Control center calls tandem exchange station	L4b—Stored call
135	L1a—Selecting idle trunk to tandem exchange	Item M—Circuit description—control center reverts call from tandem office
140	L1b—Seizing an idle control relay group	M1—Tandem subscriber calls sub-tandem subscriber
145	L1c—Operator dials called number	M1a—Operator retires from the connection
150	L1d—Repeating impulses to the associated connector	M1b—Calling subscriber releases connection
155	L1e—Dialling the associated connector	M1c—Busy condition encountered
160	L1f—Dialed line busy	M1d—Paystation calls
165	L1g—Seizure of idle line	Item N—Circuit description—Control center reverts call from sub-tandem exchange
170	L1h—Operator starts automatic ringing on called line	N1—Sub-tandem subscriber calls tandem subscriber
175	L1i—Called party answers	N1a—Operator retires from the connection
180	L1j—Release of the connection	N1b—Called subscriber releases the connection

- N3—Sub-tandem subscriber calls sub-tandem subscriber in another exchange area
 5 N3a—Operator retires from the connection
 N3b—Ringing off connection
 N3c—Connection released by timing equipment
 Item O—Circuit description—Control center reverts call from satellite exchange
 10 O1—Satellite subscriber calls satellite subscriber in same area

The finder switch F—1, the connectors C—1 and IC—1 are all of the well known type of Stromger vertical and rotary step-by-step switch.

The trunk switches TS—1, TS—2, TS—3; the distributor DIS—1; the conversation timing equipment CTE; the ring-interrupter RI; the finder switches F—2 and F—3; the connector switches C2 and C3; and the timing equipment TE are all of the well known single motion pawl and ratchet type arranged to advance their wipers upon each deenergization of their motor magnet.

The register switch, shown in Fig. 18 as comprising operating magnet 18510, release magnet 18520 and wipers 18901 and 18902, is also of the well known single motion pawl and ratchet type which advances its wipers upon the energization of the operating magnet, and is provided with a release magnet which functions to permit the wipers to restore to a normal position under restoring spring tension.

The various relays diagrammatically shown in the drawings are of the general type ordinarily employed in automatic telephone systems.

ITEM A

40 TRUNKING—TANDEM EXCHANGE

A plurality of automatic telephones, such as T—1, are each connected to a line circuit, such as LC—1, and thus are accessible from the finder and connector banks. A plurality of finder-connector links, such as FC—1, are provided, and the next link to be used is preselected by the distributor DIS—1.

The tenth level in the banks of the local connectors are trunked to control groups, such as CG—1.

Exchange "A" is connected with the control center "B" by a plurality of two-way trunks, such as TWT—1, which terminate in the latter exchange upon line and jack equipment. The operator at exchange "B" has dial equipment available for use when extending calls to exchange "A." The trunk TWT—1 terminates in exchange "A" upon the control center trunk switch TS—1, which has access to the remote control group.

On calls from exchange "A" to exchange "B" the next available control center trunk switch acts as a finder to extend the calling control group to exchange "B."

The control operator, when calling exchange "A," will select an idle two-way trunk, whereupon the associated trunk switch, such as TS—1, will select an idle control group. Each control group has in association therewith an incoming connector, such as IC—1, which is utilized when extending calls. Each control group has also in association therewith a control group trunk switch, such as TS—2, which is utilized to find calling sub-tandem exchange trunks.

ITEM B

TRUNKING—MAGNETO MANUAL EXCHANGE

Magneto manual exchange "C" is connected with exchange "A" by means of the two-way trunk TWT—2, which terminates in the latter exchange upon line circuit LC—2. Two-way trunk TWT—2 terminates in exchange "C" upon line and jack equipment. The operator has dial equipment available for use when extending calls to exchange "A".

ITEM C

TRUNKING—SUB-TANDEM EXCHANGE

Sub-tandem exchange "D" serves a plurality of magneto manual telephones, such as T—2, which are each connected to a line circuit, such as LC—3, and thus are accessible from the finder and connector links. A plurality of finder-connector links, such as FC—2, are provided and the next link to be used is preselected by the relay type distributor DIS—2.

Exchange "D" is connected with exchange "A" by a plurality of two-way trunks, such as TWT—3, which terminate in the latter exchange in the banks of control group trunk switches, such as TS—2, and in the banks of incoming connectors, such as IC—1. The trunk TWT—3 terminates in exchange "D" upon tandem exchange trunk switch TS—3, which has access to the finder connector links.

On calls from exchange "D" the next available tandem exchange trunk switch, such as TS—3, acts as a finder to extend the connection from the calling link. The next available incoming control group trunk switch, such as TS—2, now acts as a finder to extend the calling trunk to the control group associated therewith. The next available control center trunk switch, such as TS—1, now acts as a finder to extend the calling group to the control center.

The control operator, when calling exchange "D", will select an idle two-way trunk to the tandem exchange, whereupon the associated trunk line, such as TS—1, will select an idle control group, the connection being extended to the incoming connector associated therewith. The control operator next dials two digits representative of the desired sub-tandem exchange (digits 91 in case of exchange "D"), and as a result the incoming connector will select the first idle trunk such as TWT—3, leading to that exchange. The tandem exchange trunk switch associated with the trunk in question will next select an idle finder-connector link, such as FC—2, and the connection may be completed thereover.

ITEM D

TRUNKING—SATELLITE EXCHANGE

Satellite exchange "E" serves a plurality of magneto manual telephones, such as T—3, which are each connected to a line circuit, such as LC—4, and thus are accessible from the banks of the single finder-connector link FC—3. Exchange "E" is connected with exchange "D" by two-way trunks, such as TWT—4, which terminate in the latter exchange upon line circuits, such as LC—5, thus calls from exchange "E" are routed over the two-way trunks connecting exchange "D" and "A".

ITEM E

OPERATION—TANDEM EXCHANGE

The trunking plan having been briefly described, the operation of the network will now be considered more in detail.

E1—Local calls

The removal of the receiver from the switchhook of a calling telephone will cause the operation of the associated line equipment, and this in turn will cause the seizure of the preselected finder-connector link. The finder switch of this link will hunt for and connect the link to the calling line. At this point the subscriber will hear dial tone.

All stations in the tandem exchange will be assigned two-digit numbers. After dialling the desired number, the called subscriber's bell will ring, and the calling subscriber will receive ringing tone. If the called line is engaged, the calling subscriber will receive the busy tone.

The connection at all times remains under the control of the calling subscriber.

E2—Trunk calls

A local subscriber in the tandem exchange desiring a connection with a subscriber in a sub-tandem or satellite exchange, or with a toll operator, will dial "O" after receiving the dial tone. The connector of the link used will then select an idle control group, after which an idle trunk will be secured to the control center.

The control operator ascertains the desired connection and, in the case of a toll call, will extend the connection manually.

In the case of a call for a sub-tandem exchange, the control operator will dial the first two digits of the called number back over the trunk on which the call was received, thus actuating the incoming connector associated with the control group in use. If no trunks are available between exchange "A" and the desired sub-tandem exchange, the operator will hear the busy signal (see item L2f). If both a trunk and a link are available, the operator will hear dial tone, thus indicating that the desired sub-tandem exchange has been reached (see item L2g). The control operator now dials the remaining digits of the called subscriber's number. If the called line is engaged, busy tone will be returned to the operator (see item M1c). In this case the "ring and offer" key is operated once, which will disconnect the control operator from the called line and reconnect her with the calling subscriber, in order that she may advise same that the connection cannot be completed.

If the called line is available, the operator, after listening, operates the "ring and offer" key twice (see item L2k). The first operation is without effect, but succeeding operations will ring the bell at the called station. When the called subscriber answers, the control operator may retire from the connection (see item M1a). The trunk between exchanges "A" and "B" is now released, and the connection is under control of the calling subscriber. If the operator desires to regain control of the connection she may secure same by momentarily operating the "split and incomplete call" key (see item M1d).

On calls to magneto-manual exchange "C", the tandem subscriber will dial the two-digit number assigned to that exchange, whereupon the manual operator at exchange "C" will answer and complete the call. The tandem subscriber can release from this connection and in so doing will give the operator disconnect supervision.

E3—Incoming trunk calls

All incoming trunk calls for tandem local subscribers will be handled by the control operator

by way of a control group and the incoming connector associated therewith.

When the control operator takes up a trunk to the tandem exchange, dial tone will be heard as soon as an idle control group is found. The control operator now dials the required two-digit number, thus extending the connection to the called subscriber's line.

If the called subscriber's line is free, the control operator starts the ringing of the called station by operating the "ring and offer" key twice, which will start the automatic ringing from the connector (see item L1h).

If the called subscriber's line is engaged, the operator receives the busy signal. She may then offer the call by operating the "ring and offer" key once (see item L1f). This places a "tick-tone" on the local connection to indicate to the subscriber that a trunk call is offered to one of them. Both subscribers will now restore their receivers, and the "tick-tone" will stop when the local connection is released. The operator now proceeds in the same manner as when a free line has been called.

The release of a trunk call is under the control of the control operator.

E4—Paystation calls

Provision is made in the tandem exchange for paystations of the "prepay" type on regular subscribers' terminals. These subscribers can call the control operator without depositing a coin. The control operator is able to identify tandem paystations by the fact that when the call is answered, a momentary tone signal will be heard (see item H2f). In case of doubt, the control operator may operate the "ring and offer" key once, thereby causing a repetition of the momentary tone signal.

Tandem paystations making local calls will have to deposit the necessary coin before the calling subscriber can start a conversation.

Paystations are instructed not to call magneto-manual exchange "C" directly, but to dial the control operator for calls to this exchange, it being contemplated that such calls will be completed over toll trunks not shown on the network disclosed in Fig. 1.

E5—Registration of calls

Local calls between subscribers will be automatically registered on the calling subscriber's message register as soon as the called subscriber answers (see item H1h). Trunk calls will not be registered on the calling subscriber's message register.

E6—Permanent line lockout

The line circuits are arranged in such a manner that if a link is seized and held, and dialling does not start within a certain predetermined interval, the line lockout relay of the associated line will operate (see item H1d). This will release the link and make it available for other calls. The locked out line will test engaged at the connection terminal.

The locked out line will be automatically restored to service as soon as the cause of the permanent condition has been removed.

E7—Trunk alternating relays

Relay equipment is provided to alternate calls between the first two trunks of any group, thus preventing the tying up of all traffic because of a faulty trunk (see items H4e, f, g, and h).

E8—Alarm sender

An alarm, caused by a faulty condition in the tandem exchange, is automatically extended to the control center over the first trunk, and received thereat on equipment individual to this trunk (see item H6a).

E9—Test facilities

10 A connector terminal is set aside at the tandem office for test purposes (see item H6b). When this number is dialled by the control operator, tone signals will indicate the relative importance of the faulty condition which initiated the alarm.

E10—Trunk busying

15 The trunks between the tandem office and the control center are arranged so that they may be made busy at the control center, thus preventing seizure at the tandem office (see item L4a).

ITEM F**OPERATION—SUB-TANDEM EXCHANGE**

Subscribers in this exchange originate calls by operating the hand generator at their telephones. 25 The line equipment associated with the calling subscriber's line operates and locks, thus causing an idle finder switch (if available) to search for and connect with the calling line. An idle tandem exchange trunk switch (if available) will 30 now find the calling finder-connector link, whereupon an idle control group trunk switch (if available) will find the calling trunk and extend the connection to the associated control group. An idle control center trunk switch (if available) will 35 now find the calling group and extend the connection to the control center.

If the connection between the calling subscriber and the control center is established, the calling subscriber will hear a tone indicating that fact. 40 The control operator answers the call, and completes the desired connection either by dialling the called subscriber's number back over the control trunk, or by extending the call manually from the control center.

45 If all of the local links, or all of the trunks in any required trunk group, are engaged when a subscriber originates a call, no tone will be heard, and the subscriber, presumably, will restore his receiver. The call is stored, however, and when 50 a link or a trunk becomes available, the call is extended to the control center. The control operator, upon answering a stored call, receives no response to her challenge, she will then operate said "ring and offer" key to signal the calling subscriber, after which the connection will be completed as described hereinafter (see item L4b).

F1—Local calls

For a local call within this exchange, the subscriber will signal the control operator as described above. After receiving the number of the desired subscriber, the control operator dials this number back over the trunk on which the call was received. If the called line is free, the operator then rings the called station by the operation of the "ring and offer" key.

The "sub-tandem-to-tandem trunks" and the "tandem-to-control center trunks" will be released when the control operator retires from the connection. The local link in the sub-tandem exchange will be held during the entire length of the call.

70 The call may be released by the "ring-off" of either subscriber, or by the operation of the timing equipment in the sub-tandem exchange,

which is arranged to release the call at the end of a predetermined interval (see item N2f).

F2—Trunk calls

Trunk calls originating within the sub-tandem 5 exchange are initiated in the same manner as explained above.

If the call is for a subscriber in the tandem exchange the control operator will extend the same by dialling the required number back over 10 the trunk on which the call was received. If the called line is available, the "ring and offer" key is operated twice, thus starting the automatic ringing of the connector switch. When the called subscriber answers, the control operator retires 15 from the connection, thus freeing the trunk between the tandem office and the control center. The connection is now under the control of the called subscriber in the tandem exchange.

If the called subscriber's line is engaged, the 20 control operator receives the busy signal. The "ring and offer key" is then operated momentarily. This disconnects the operator from the tandem exchange talking circuit and connects her to the calling subscriber who is now informed 25 that the called subscriber's line is engaged. The operator then releases the connection by withdrawing her answering plug from the trunk jack.

F3—Incoming calls

All incoming calls are handled by the control operator. The operator selects a free trunk to the tandem exchange, dial tone being received as soon as the connection is extended to an idle 30 control group. The operator first dials the two-digit number assigned to the sub-tandem exchange, after which dial tone is again heard as an indication that the equipment at the sub-tandem office is available. The operator now dials the remaining digits necessary to connect with 35 the called subscriber.

If the called line is busy the operator will receive the busy tone. If the called line is available, the operator rings the called station by operating the "ring and offer" key twice, the 40 second operation being the actual ringing operation.

All of the equipment involved in a connection of this type is under the control of the control operator when the call originated at the control center (see item L2m). When the call originates at the tandem exchange, the release of the connection is under control of the calling subscriber (see item M1b). When the call originates at another sub-tandem exchange, the connection 45 may be released by either subscriber ringing off (see item N3b), or by the timing equipment (see item N3c).

F4—Paystations

Paystations of the local battery magneto post-payment type may be connected to subscriber line equipments in the semi-automatic exchanges. On calls originating from a paystation, the control operator will momentarily receive a paystation tone signal of short duration (see item J1h). 60 The operator cannot cause this tone to be repeated, as may be done in the case of paystation calls from the tandem exchange.

ITEM G**OPERATION—SATELLITE EXCHANGE**

70 Subscribers in this exchange originate calls by operating the hand generator at their telephones. The line equipment associated with the calling subscriber's line operates and locks, and this 75

causes the single finder switch (if available) to search for and connect itself with the line. The associated line equipment at the sub-tandem exchange now operates and locks, and from this point on the sequence of operation is as described above in connection with a call originating at the sub-tandem exchange.

G1—Local calls

18 On local calls, the trunk between the satellite and the sub-tandem exchange will be left in on the connection, in order that the timing equipment at the sub-tandem exchange may be utilized to release the connection after the allotted talking period has expired (see item O1).

ITEM H

CIRCUIT DESCRIPTION—TANDEM EXCHANGE

H1—Station to station calls

H1a—Making the calling line busy (no relays operated)

With reference to Fig. 2, when the receiver is removed from the switchhook of telephone T1, assumed to have the number 11, the circuit of relay 2510 is closed through both windings in series by way of 2521, 2523, and conductors 2001 and 2002.

30 Relay 2510 operates; closes start relay 5510 by way of 5001, 2534, and 2518; and places ground on test conductor 2005 at 2514 to make the calling line busy in the banks of the associated connectors.

H1b—Seizing the preselected link (relay 2510 operated)

Relay 5510 operates; grounds the distributor alarm conductor 8005 at 5512; and closes relay 5520 in series with motor magnet 5500 by way of 40 5501, relay 5520, 5514, 5532, 5566, 5574, 5008, 2911, and 2588, and similar circuits in other links. Motor magnet 5500 does not operate in series with relay 5520.

45 Relay 5520 operates; locks itself at 5522; connects motor magnet 5500 to wiper 5908 through 5527; and closes relay 5570 by way of 5562 and 5521.

Relay 5570 operates; closes relay 5550 by way of 5572, 5564, and 5521; closes relay 2590 by way 50 of 5002, 5901, 5900, 5511, 5529, and 5573; and closes vertical magnet 2550 by way of 2592, 5004, 5903, 5902, 5533, 5541, 5575, and 5529—1.

55 Relay 2590 operates; prepares the circuit to vertical magnet 2550 at 2592; prepares the circuit to rotary magnet 2560 at 2596; and opens the circuit to release magnet 2570 at 2598.

Relay 5550 operates; closes relay 5560 by way of 5561, 5551, 5523, and 5571; and closes a holding circuit for relay 5570 by way of 5551, 5523, 60 and 5571.

Relay 5560 operates; locks itself by way of 5561 and 5521; opens relay 5550 at 5564; and opens the operating circuit of relay 5570 at 5562.

65 Relay 5550 restores; but due to the momentum of weighted spring 5551, slow to release relay 5570 will remain operated until spring 5551 ceases to vibrate.

Vertical magnet 2550 operates; raises wipers 2904 to 2908, inclusive, one step; and closes relay 70 5540 by way of 5908, 5907, 5006, and 2551.

75 Relay 5540 operates and opens vertical magnet 2550 at 5541. This cycle of operations continues, and the wipers are raised step by step, until test wiper 2908 finds ground on an associated bank contact.

In the case under discussion, the vertical movement will cease when test wiper 2908 reaches the first contact in its bank, for relay 5530 is then closed in series with relay 5540 by way of 5524, relay 5530, 5534, 5904, 5915, 5005, 2908, 2909, 2534, and 2518.

Relay 5530 operates; locks its second winding by way of 5531 and 5571; and opens its operating circuit, and the circuit of relay 5540, at 5534.

Relay 5540 restores and closes rotary magnet 10 2560 by way of 2584, 2588, 5003, 5533, 5541, 5575 and 5529—1.

Rotary magnet 2560 operates; rotates wipers 2904 to 2908, inclusive, one step; and closes relay 5540 by way of 5906, 5907, 5006 and 2561.

Relay 5540 operates and opens rotary magnet 2560 at 5541. This cycle of operations continues, and the wipers are rotated step by step, until test wiper 2908 finds battery potential on an associated bank contact. In the case under discussion, the rotary movement will cease when test wiper 2908 reaches the first contact in its bank, for relay 2580 is then closed in series with 2914 by way of 2516, 2532, 2902, 2908, relay 2580, 5005, 5915, 5904, 5535, and 5529—2.

Relay 2580 operates quickly because of the non-inductive resistance 2914 around relay 2520, opens rotary magnet 2560 at 2584; locks its lower winding by way of 2582 and 2591; extends ground by 30 way of 2581, 2581, 2906, 2902, 2532, and 2516 to relay 2520; extends the calling line to relay 3530 by way of 2521 and 2523, 3515 and 3517, 3001 and 3000, 2583 and 2585, 2905 and 2904, 2901 and 2900, and 2002 and 2001; and causes the distributor to 35 select the next idle link, as will be explained later.

Relay 2520 operates from direct ground at 2591; locks to its energizing circuit at 2522; opens relay 2510 at 2521 and 2523; and closes relay 2530 at 2524.

Relay 2510 restores; removes starting ground from start conductor 5001 at 2518; and removes the non-inductive shunt 2914 from around relay 2520 at 2512.

Relay 2530 operates and prepares a locking circuit for itself at 2534.

Relay 3530 operates; closes relay 3540 by way of 3532 and 3511; and closes relay 3560 by way of 3904, 3532, and 3511.

Relay 3540 operates; extends ground by way of 50 3512, 3544, 4016, 4524 and conductor 7006, to start the ringing and timing equipment; and replaces ground at 2591 by way of 3002, 3543 and 3583.

Relay 3560 operates; connects relay 3580 by way of 3561 and 3581 to "time in" conductor 55 7009; and connects dial tone conductor 6005 to the calling line in multiple with the lower winding of relay 3530, by way of 3563, 4003, 4900, 4004, and 3901.

60 H1c—Distributor preselects next idle trunk (Relays operated 2520, 2530, 2580, 2590, 3530, 3540, 3560, 5510, 5520, 5530, 5560, and 5570)

Distributor DIS—I will preselect the next idle trunk as soon as relay 2580 operates as the result of finder F—I finding the calling line. For the purpose of explanation it will be assumed that other lines are calling, and that relay 5510 remains operated.

The energization of relay 2580 closed a circuit 70 to motor magnet 5500 by way of 5527, 5908, 5909, 5007, 2594, 2584, 2596, 5003, 5533, 5541, 5575, and 5529—1.

Motor magnet 5500 operates and opens relay 5520 at 5581.

- Relay 5520 restores; opens its locking circuit at 5522, prepares the circuit of motor magnet 5500 at 5527; opens relay 5560 at 5521; and opens relay 5570 at 5523.
- 5 Motor magnet 5500 restores and advances wipers 5900, 5902, 5904, 5906, and 5908, one step. If the next link is busy, wiper 5908 will find ground on the associated bank contact, and motor magnet 5500 will operate as a buzzer to advance the associated wipers until wiper 5908 engages an ungrounded bank contact. All unused contacts accessible to wiper 5908 are permanently grounded, except the last contact, which is multiplied to all distributor banks, and to the off 10 normal springs of each finder, as indicated in Fig. 2. It follows then, that the last contact will be ungrounded when all of the finder links are busy, and that distributor DIS—I will then rest thereon until some link becomes idle.
- 15 Relay 2590 restores when its circuit is opened by the deenergization of relay 5520.

- H1d—Calling subscriber does not dial* (Relays operated 2520, 2530, 2580, 3530, 3540, 3560)
- 25 Relay 3560 closes a circuit from ground at 7604 by way of 7009, 3581, and 3561 to relay 3580. Assuming that permanent timing equipment PTE, Fig. 7, is standing in a position when ground is placed on "time in" conductor 7009 at 7604. (See item H4d for explanation of permanent timing equipment.)

- 30 Relay 3580 operates to "time in" the connection; locks itself at 3581; and replaces ground at 3583 by time cut-off conductor 7010, which is grounded at 7584. After an interval of time, assuming that the subscriber does not dial, ground is removed from conductor 7010, thus opening relay 2520 and 2580.

- 35 Relay 2520 restores and again bridges relay 2510 across the calling subscriber's loop. Relay 2510 operates; and ground test conductor 2005 at 2514; and locks slow-to-release relay 2530 by way of 2534 and 2518.

- 40 Relay 2580 restores and opens relay 3530.
- 45 Relay 3530 restores and opens relays 3540 and 3560, thereby bringing about the release of the link as will be explained below. The link is now free, and the subscriber's line is in the locked out position.

H1e—Dialling the called line (Relays operated 2520, 2530, 2580, 3530, 3540, 3560 and 3580)

When the subscriber dials, relay 3530 will follow the dial impulses, alternately opening and closing the holding winding of relay 3560, and the circuit is vertical magnet 3570 by way of 3511, 3532, 3542, and 3562. The vertical magnet 3570 will raise wipers 4906, 4907 and 4908 to the level 60 which was dialled. Vertical off normal springs 3904 are operated as a result of the first energization of the vertical magnet 3570, and open the operating circuit of relay 3560. Relay 3560, being slow to release, will remain operated throughout the pulsing period, and will restore shortly thereafter.

When relay 3560 restores, the connection may or may not have been "timed in" (see item H4d for explanation of the permanent timing equipment). If the connection was not "timed in", the restoration of relay 3560 is without effect as regards relay 3580; but if the connection had "timed in", the restoration of relay 3560 opens relay 2580 at 3561. Relay 3580 restores; opens 75 its locking circuit at 3581; and replaces the

grounded time cut-off conductor 7010 by direct ground at 3583, thus rendering the connection independent of the permanent timing equipment.

On the second digit dialled, relay 3530 will alternately open and close relays 4530, 4540, and 5 rotary magnet 4570, by way of 3511, 3532, 3542, 3562, 4010, 4552, and 4562.

Relay 4540 operates; closes the holding circuit of relay 4530 at 4541, and, since it is slow to release, will remain energized throughout the 10 pulsing period. Rotary magnet 4570 will rotate wipers 4906, 4907 and 4908 into engagement with the bank contacts of the called line.

Relay 4530 operates and prepares the busy test circuit at 4534.

H1f—Called line busy (Relays operated 2520, 2530, 2580, 3530, 3540, 4530, and 4540)

If the called line is busy; ground on test contact 4911 closes relay 4550 before relay 4530 restores, by way of 4911, wiper 4908, 4563, 4534, and 4571.

Relay 4550 operates; locks itself (after relay 4530 restores) by way of 3583, 3543, 4007, 4554, 4534, and 4571, and places busy tone on the 25 calling line in multiple with relay 3530 by way of conductor 6004, 4903, 4551, 4900, 4004, 3901, and 3521.

The calling subscriber now restores his receiver, and effects the release of the connection 30 as described under item H1i.

H1g—Seizing the dialled line when it is idle (Relays operated 2520, 2530, 2580, 3530, 3540)

If the called line is not busy, a circuit is closed (after relay 4530 restores) from 3583, 3543, 4007, 4554, relay 4560, 4534, 4563, wiper 4908, and 4911 to the cut-off relay of the called line.

Relay 4560 operates; closes its holding winding by way of 3583, 3543, 4007, and 4561; opens rotary magnet 4570 at 4562; places interrupted generator on the called line by way of conductor 4007, 4523, 4565, 4005, 3515, 4006, wiper 4907, 4910, the called line 4909, wiper 4906, 4002, 3517, 4004, 4569, 4525 and relay 4520 (which does not operate on ringing current); and places ring-back tone on the calling line in parallel with relay 3530 by way of conductor 7007, 4523, 4565, 4567, 4900, 4004, 3901 and 3521.

H1h—Called party answers (Relays operated 2520, 2530, 2580, 3530, 3540, and 4560)

When the called subscriber removes his receiver, a direct current circuit is closed through 55 the upper winding of relay 4520.

Relay 4520 operates; completes a circuit through its two windings in series by way of 3541, 4009 and 4522, thereby becoming fully operated; removes ringing current from the called line at 4523; opens the ringing machine start circuit at 4524; closes the circuit of message register 2540 by way of cam springs 4901, 4521, 4008, 3003, 2907, and wiper 2903; connects batteryfeed relay 4510 to the called line at 4523 and 65 4525.

Relay 4510 operates and closes relay 3520 by way of 4012, 4512, 4522, 4009, and 3541.

Relay 3520 operates and reverses the polarity 70 of the calling line at 3521 and 3523. The transmission circuit is now complete and the two subscribers may talk.

Message register 2540 operates to register the call. For other meter circuit functions see items H2j and H3c.

H1a—Release of the connection (Relays operated 2520, 2530, 2580, 3520, 3530, 3540, 4510, 4520, and 4560)

Assume that the called subscriber hangs up his receiver first, thereby opening relay 4510, which restores and opens relay 3520, the latter relay restores normal polarity to the calling line when it deenergizes. The calling subscriber now hangs up and opens relay 3530, which restores and opens relay 3540.

Relay 3540 restores; opens relays 2520, 2580, 4520, and 4560; and closes release magnet 3550 by way of 3511, 3532, 3542, off normal springs 3905, release magnet 3550 and release battery conductor 8004.

Relay 2580 restores and closes release magnet 2570 by way of 2588, off normal springs 2911, 2986, release magnet 2570 and release battery conductor 8004.

We will next assume that the calling subscriber hangs up first, thus causing the release of the equipment as just described, whereupon the called subscriber's line circuit (not shown) will be seized by an idle finder, and will eventually go into the lockout position, as described under item H1d. When the called subscriber replaces his receiver, the associated line circuit will return to normal.

Failure to release is described under item H5b.

H2—Tandem station calls control center

We will next assume that the subscriber at station T1, Fig. 2, desires to call the control center, he will therefore remove his receiver and dial the digit 0.

Operations under items H1a, b, c, d, e, f, and g are applicable here, and will not be described again.

H2a—Dialling the digit "0" (Relays operated 2520, 2530, 2580, 3530, 3540 and 3560)

When the subscriber dials the digit 0, relay 3530 will follow the dial impulses, alternately opening and closing the holding winding of relay 3560, and the circuit of vertical magnet 3570, by way of 3511, 3532, 3542, and 3562. The vertical magnet 3570 will raise wipers 4906, 4907 and 4908 to the tenth level of bank contacts. Vertical off normal springs 3904 are operated as a result of the first energization of the vertical magnet 3570, and open the operating circuit of relay 3560. Relay 3560, being slow to release, will remain operated throughout the pulsing period, and will restore shortly thereafter.

When the shaft is raised to the 0 level, springs 4902 engage and close relay 4510 by way of 4902, 4912, 4553, 4007, 3543, and 3553.

Relay 4510 operates and closes relay 4550 by way of 3566 (relay 3560 has not yet released) 60 4013, 4518, and 4571.

Relay 4550 operates; locks itself by way of 3563, 3543, 4007, 4554, 4518, and 4571; places busy tone on the calling line at 4551, as previously described; and closes rotary magnet 4570 65 in parallel with relays 4530 and 4540 by way of 3564 (relay 3560 has now restored), 4011, 4514, 4904, 4552, and 4562.

Rotary magnet 4570 operates; advances wipers 4906, 4907, and 4908 into engagement with the first contact in the tenth level; and opens relay 4550 at 4571.

Relay 4550 restores and opens rotary magnet 4570 at 4552.

Rotary magnet 4570 restores; and extends relay 4550 to test wiper 4908 by way of 4571, 4534

(relay 4530 has not yet restored) and 4563. If the contact now engaged by wiper 4908 is grounded, relay 4550 will again operate, and the foregoing cycle will repeat until wiper 4908 engages an ungrounded bank contact.

In case all of the trunks are busy, the shaft will rotate eleven steps and operate springs 4909, thereby opening the circuit to rotary magnet 4570, and closing relay 4550 by way of 4571. Thus the rotation ceases, and the calling subscriber must hang up his receiver to clear the calling line from busy tone.

H2b—Seizing an idle control group (Relays operated 2520, 2530, 2580, 3530, 3540, and 4510)

It will be assumed that the first idle trunk in the tenth level is that represented by conductors 13000, 13010, and 13011 of Fig. 13, and, when test wiper 4908 engages the bank contact (not shown) to which conductor 13011 is connected, a circuit is closed from battery by way of resistance 16900, 16533, 13019, 13547, conductor 13011 and the bank contact (not shown) associated therewith, test wiper 4908, 4563, 4534, lower winding of relay 4560, 4554, 4007, 3543, to ground at 3583.

Relay 4560 operates; locks its upper winding at 4561, opens relay 4510 at 4563; opens rotary magnet 4570 and relay 4550 at 4562; and closes relay 3510 by way of 4561, 4905, and 4014.

Relay 4510 restores, but without effect at this time.

Relay 3510 operates; extends the calling line conductors 3000 and 3001 to wipers 4906 and 4907, respectively, at 3515 and 3517; opens relay 3530 at 3515 and 3517; and opens the circuit of release magnet 3550 and relay 3540 at 3511.

Relay 3540 restores and removes ground from conductor 4007 at 3543 but, as will be explained presently, relays 3510 and 4560 are held by ground returned for the remote control group RCG—1.

Relay 3530 restores; but without effect at this time.

The calling line is now extended to line relay 16520 for the reason that wipers 4906 and 4907 are now standing on bank contacts (not shown) 45 associated with conductors 13009 and 13010, respectively.

Relay 16520 operates and closes release relay 16530 at 16522.

Relay 16530 operates; returns holding ground 50 to connector C—1 by way of 18583, conductor 15020, 16533, conductor 13019, 13547, conductor 13011 and the bank contact associated therewith (not shown), and test wiper 4908; closes relay 15590 by way of 16531 and 15023; closes 55 relay 20540 by way of 16531, 15023, 17555, 17030, 19582, 19011; and closes relay 16540 at 16532.

Relay 15590 operates; removes ground from ATB—2 conductor 15031 at 15594; and switches chain conductor 14008 to the next available control relay group at 15592, thereby making RCG—1 60 busy to calls from the sub-tandem exchange.

Relay 16540 operates; closes relay 18560 by way of 16544, 15029, 15562, and 15028; and closes relay 19570 by way of 16544 and 15029.

H2c—Idle Control center trunk switch finds calling control group (Relays operated 2520, 2530, 2580, 3510, 4560, 15590, 16520, 16530, and 16540)

Relay 19570 operates; removes ground from 70 conductor 19008 at 19577, thus making CG—1 busy to calls from the control center trunk switches; and reverses battery on trunk conductors 20000 and 20001 by way of 19573 and 19575, conductors 19007 and 19009, and 20563 and 75

20565, in order that "answering supervision" may later be given to the control operator.

Relay 18560 operates; locks its upper winding by way of 18561, 15023, and 16531; and at 18563 5 prevents dial tone from being connected to the trunk when the operator answers.

Relay 20540 operates; grounds motor start conductor 7006 at 20545 to start the ringing equipment; grounds conductor 20002 by way of 10 20583, 20543, 15017 and 15527 to provide the control circuit by which a control center trunk switch may associate itself with CG-1; closes relay 20560 at 20542; closes the lower windings of relays 21600 and 21590 by way of 21591, 20003, 15 20541, 20581, 25030 and 21571; closes the upper winding of relay 21600 by way of 21601, 20003, 20541, 20581, 15030, and 21571; and closes relay 21530 by way of 21524, 21552, 21603, 20003, 20541, 25081, 15030 and 21571.

20 Relay 21590 operates and locks locally at 21591. Relay 21600 does not operate at this time because its windings are in opposition.

Relay 21530 operates; closes the circuit of motor magnet 21500 by way of 21512, 21522 and 25 21532; and prepares a stopping circuit at 21531.

Motor magnet 21500 operates and closes relay 21510 at 21501.

Relay 21510 operates and opens motor magnet 21500 at 21512.

30 Motor magnet 21500 restores; advances wipers 21900 to 21904, inclusive, one step, and opens relay 21510 at 21501. Relay 21510 and motor magnet 21500 continue to operate as above described, and advance the associated wipers step by step until test wiper 21903 engages the marked bank contact.

When wiper 21903 engages the bank contact associated with conductor 20002 a circuit is closed from ground at 15527, 15017, 20543, 20563, 20002, 21903, 21531, 21905, and relays 21520 and 21510.

40 Relay 21510 will remain operated and thus prevent further operation of motor magnet 21500.

Relay 21520 operates; locks its upper winding by way of 21521, 21904 and the contact upon which it is standing, 17013, 17523, 16008, 16577, 45 16563, 16009, and relay 19580; connects TCG-1 through to control center trunk conductors 21000 and 21001 by way of 21525 and 21527; switches start conductor 20003 through to the next available control center trunk switch at 21524; removes ground from ATB-1 conductor 21006 at 50 21526; and opens relay 21530 at 21524.

Relay 21530 restores; and opens relays 21520 and 21510 at 21531.

55 Relay 21510 restores, but without effect at this time.

Relay 21520 remains operated because of its locked second winding.

Relay 20560 operates; locks at 20561 to ground on delay ground conductor 20004 at 20571; closes relay 20560 by way of 20562 and delay conductor 20005; and prepares to send generator over the control trunk by way of 20563 and 20565.

Relay 20560 operates when generator becomes 60 available, and opens relay 20570 and 20552.

Relay 20570 restores and removes ground from delay ground conductor 20004 at 20571, thus opening the locking circuit of relay 20560.

70 H2d—Signalling the control center operator (Relays operated 2520, 2530, 2580, 3510, 4560, 15590, 16520, 16530, 16540, 18560, 19570, 20540, 20550, 20560 and 21520)

For the purposes of the present discussion it 75 will be assumed that trunk switch TS-1 found

CG-1, whereupon the control center is signalled from generator on conductor 7008 by way of 20565, 20008, 21900, 21527, 21000, 23513, 23554, 23612, 23571, relay 23560, 23906, 23515, 21001, 21525, 21904, 20001, 20563 and 20902.

5 Relay 19580 operates; opens relay 20540 at 19582; provides a multiple holding circuit for relay 15590 by way of 15023 and 19584; closes relay 20580 by way of 19012, 19586, and 19584; and provides ring-back tone by connecting interrupted generator conductor 7007 to the calling line by way of 16579-2, 15004, 18579-1, 18005, 19900 and 19585.

10 Relay 20504 restores, removes ground from conductor 20002 at 20543; removes ground from start conductor 20003 at 20541; and opens relay 20560 at 20542.

15 Relay 20560 restores (assuming that relay 20570 has already restored); removes generator from the control trunk at 20563 and 20565; and opens relay 20550 at 20582. Under the assumed condition, the duration of the splash ring on the control trunk is determined only by the fall-away time of slow-to-release relay 20560.

20 Relay 20550 restores and closes relay 20570 at 20552.

Relay 20570 operates and again places ground on ground delay conductor 20004.

25 Relay 20580 operates; locks at 20582 to conductor 15023; opens conductor 20003 at 20581; and opens conductor 20002 at 20583.

30 Relay 21600 operates when ground is removed from start conductor 20003, because its lower winding only is now effective, and switches the chain circuit through to the next available control center trunk switch.

H2e—Control center operator answers (Relays operated 2520, 2530, 2580, 3510, 4560, 15590, 16520, 16530, 16540, 18560, 19750, 19580, 20580, and 21520) 40

45 Relay 23560 operates; in response to the splash of ringing current impressed upon the control trunk and mechanically locks armature springs 23561 and 23562 under control of cut-off relay 23570; closes a multiple circuit to relay 23610 at 23562; and closes the circuit of answering lamp L-23-1 at 23561.

The operator answers the call by inserting the 50 answering plug of an idle cord circuit (not shown) into the combined answering and calling jack J-23, thus closing the circuit of cut-off relay 23570 by way of the sleeve of the jack.

55 Relay 23570 operates; releases the springs of relay 23560 mechanically; removes relay 23560 from across the trunk at 23571; closes a multiple circuit to relay 23610 at 23570; removes high resistance relay 23600 from across the trunk at 23574; connects relay 23540, in series with windings 1 and 3 of repeating coil R-23, across the 60 trunk at 23574; and closes relay 23550 at 23576.

Relay 23560 restores and extinguishes answering lamp L-23-1 at 23561.

65 Relay 23560 operates; but without effect at this time.

The bridging of relay 23540 across the trunk completes a circuit from ground at relay 19580; differential relay 19560, 19575, winding 4 of repeating coil R-19, 19009, 20563, 20001, 21901, 21525, 21001, 23515, winding 1 of repeating coil 70 R-23, polar relay 23540, 23531, winding 3 of repeating coil R-23, 23574, 23513, 21000, 21527, 21900, 20008, 20565, 19001, winding 2 of repeating coil R-19, 170573, differential relay 19568, relay 19540 and marginal relay 19530. 75

- Relay 19560 does not operate at this time because its windings are opposed.
- Relay 19530 operates and prevents the operation of relay 18540 at 19532.
- 5 Relay 19540 operates and closes relay 18580 by way of 18008, 19542 and 19552.
- Relay 18580 operates; removes a short circuit from the lower winding of relay 20510 at 18583, thereby supplying holding ground through this winding to connector C-1 by way of 16020, 16533, 13019, 13547, and 13011; shunts contact 16533 at 18583, thus placing the release of the preceding switch train under control of the operator; and closes relay 18570 at 18582.
- 10 18 Relay 18570 operates; removes ring-back tone from the calling line at 18579-1; closes a multiple circuit to relay 19580 at 18578, placing the release of TS-1 under control of the operator; and closes the circuit of relay 20530 by way of 18011, 18574, 17029, and 19512.
- Relay 23540 operates since the polarity of the trunk is reversed due to the energization of relay 19570, and closes relay 23580 at 23541.
- 15 25 Relay 23580 operates and at 23583 and 23585 removes battery and ground from the tip and ring of the jack J-23 in order to give answering supervision in the cord circuit (not shown).
- 30 H2f—Forwarding paystation tone (Relays operated 2520, 2530, 2580, 3510, 4560, 15590, 16520, 16530, 16540, 18560, 18570, 18580, 19530, 19540, 19570, 19580, 20580, 21520, 23540, 23550, 23570, and 23580)
- 35 40 In the event that the calling line is a paystation, paystation tone conductor 6007 is connected by way of 2912, 2913, 2902, 2906, 2581, 3002, 4007, 4563, 4908, bank contact and conductor 13011, 13547, 13019, 18583, and 16020 to the lower winding of transformer 20510. Current flowing therein will induce a corresponding tone in upper winding, which becomes audible to the control operator by way of 20525 and 20523, 20553 and 20900.
- 45 Relay 20530 operates and sets its weighted spring 20531 into vibration, thereby intermittently closing the circuit of slow-to-operate relay 20520.
- Relay 20520 operates after a time, and removes paystation tone from the trunk at 20523 and 50 20525.
- The single splash of paystation tone will ordinarily be sufficient identification, but in case of doubt the operator may momentarily operate ring and offer key K-23-2, thereby unbalancing the trunk by placing ground on the mid-point of repeating coil R-23 by way of 23551.
- 55 Relay 19560 operates momentarily as a result of the unbalanced trunk, and closes relay 19510 by way of 19562, 19542 and 19552.
- Relay 19510 operates and opens relay 20530 at 19512.
- Relay 20530 restores and opens relay 20520 at 20531.
- 65 70 Relay 20520 restores and replaces paystation tone on the trunk at 20523 and 20525.
- The transmission circuit between the calling party and the operator's cord circuit is now complete through repeating coils R-19 and R-23. Relay 16520 supplies transmission battery and the calling party. For the purpose of the present explanation it will be assumed that the operator completes the call to the desired party via the control center exchange equipment.
- H2g—Release of the connection (Relays operated 2520, 2530, 2580, 3510, 4560, 15590, 16520, 16530, 16540, 18560, 18570, 18580, 19530, 19540, 19570, 19580, 20530, 20580 and 21520)
- When the calling party hangs up his receiver, the circuit of line relay 16520 is opened.
- Relay 16520 restores; opens relay 16530 at 16522; and closes relay 16560 by way of 16542 and 16522.
- 10 15 Relay 16530 restores; opens relays 15590 and 20580 at 16531; opens relay 16540 at 16532; opens part of the multiple ground circuit to holding conductor 13011 at 16533 (ground is now maintained on conductor 13011 by contact 18583 of relay 18580, which is under control of the operator); and opens the locking circuit to relay 18560 at 16531.
- Relay 16540 restores; opens relay 18560 and relay 19570 at 16544; and opens relay 16560 at 16542.
- 20 25 Relay 18560 restores, but without effect at this time.
- Relay 19570 restores and extends normal polarity to the control center to give the operator disconnect supervision.
- Relay 16560 restores, but without effect at this time.
- 30 35 Relay 15590 restores, but without effect at this time.
- Relay 20580 restores, but without effect at this time.
- Relay 23540 restores as a result of normal polarity on the trunk; and opens relay 23580 at 23541.
- 40 45 Relay 23580 restores and removes battery from the cord circuit at 23583 and 23585 to give the operator disconnect supervision. The operator, in response thereto, will remove the answering plug (not shown) from the jack J-23, thereby opening the circuit of cut-off relay 23570.
- Relay 23570 restores; removes relay 23540 from across the trunk at 23574, reconnects relay 23560 across the trunk at 23571; and reconnects high resistance relay 23600 across the trunk at 23574. The resulting decrease in current flow over the trunk will cause the deenergization of relays 19530, 19540, and 19560.
- 50 55 Relay 19540 restores; opens relay 18580 at 19542; and closes relay 18550 by way of 17027, 17514, 17026, 18572, 18010, 19542 and 19552.
- Relay 18550 operates and closes relay 16570 by way of 16016 and 18564.
- Relay 16570 operates and at 16577 opens the operating circuit of relays 19580 and 21520, but without effect because of the shunt at contact 18575.
- 60 65 Relay 18580 restores; removes ground from conductor 13011 at 18583, thus allowing the preceding switch train to restore; and opens relay 18570 at 18582.
- Relay 18570 restores; opens relays 19580 and 21521 at 18575; and opens relay 18550 at 18572.
- Relay 19580 restores, but without effect at this time.
- 70 75 Relay 21520 restores, thus making TS-1 available for other calls.
- Relay 18550 restores, and opens relay 16570 at 18554.
- Relay 16570 restores and the release of the connection is complete. The equipment is now in position to receive other calls.
- If the operator should disconnect before the calling subscriber restores his receiver, the release of the connection will take place as just de- 75

scribed, and the calling subscriber's line will go into the "lock-out" position as described under item H1d.

- 5 **H2h—Release prior to answer by control operator**
(Relays operated 2520, 2530, 2580, 3510, 4560, 15580, 16520, 16530, 16540, 18560, 19570, 19580, 20580, and 21520)

10 Returning now to a consideration of the conditions existing as discussed under item H2d, it will be evident that the connection is at this time under the control of the calling subscriber, and that the circuit of line relay 16520 will be opened upon the restoration of his receiver.

- 15 **16 Relay 16520 restores; opens relay 16530 at 16522; and closes relay 16580 by way of 16542 and 16522.**

20 **Relay 16530 restores; opens relays 15580 and 20580 at 16531; removes ground from hold conductor 18011 at 16533, thus effecting the release of the preceding switches; and opens relay 16540 at 16532.**

25 **Relay 15580 restores, but without effect at this time.**

- 30 **26 Relay 20580 restores, but without effect at this time.**

35 **Relay 16540 restores and opens relays 18560 and 19570 at 16544.**

- 40 **Relay 18560 restores, but without effect at this time.**

45 **Relay 19570 restores, but without effect at this time.**

- 50 **Relay 16560 operates momentarily, following the deenergization of relay 16520 (and prior to the deenergization of relay 16540), and opens the locking circuit of relays 19580 and 21520 at 16563.**

55 **Relay 19580 restores, but without effect at this time.**

- 60 **Relay 21520 restores thus making TS-1 available for other calls.**

The release of the connection is now complete, and the equipment is in position to receive other calls.

65 **H2i—All trunks to control center busy**

In the event that all the trunks to the control center become busy, the circuit of common relay 21580 will be opened when ground is removed from the last branch of ATB-1 conductor 21000.

- 70 **50 Relay 21580 restores, and opens relay 21570 at 21582.**

75 **Relay 21570 restores and removes ground from the equivalent of conductor 15030 in each control group accessible to the control center trunk switches.**

- 80 **If CG-1 is seized by a subscriber in the tandem office at this time, relay 20540 on operating will close the circuit of the upper winding of relay 20580 in series with relay 21590 (or relay 21600) over conductor 20003.**

85 **Relay 20580 operates; locks under control of relay 16530; removes ground from the "in" conductor 20002 at 20583, to remove the marking circuit from the banks of the control center trunk switches; and connects busy tone conductor 6684 to the calling line at 20585, thus indicating to the calling party that he must hang up his receiver and call again.**

90 **H2j—Meter circuit, tandem station calling control center**

Under item H1h it was shown that message register 2540 operates on station-to-station calls for the reason that message register 2540 is connected to ground and that when the called party

answers relay 4520 functions to impress negative battery on metering conductor 3003.

In the case of trunk calls, it is not desired that the message register should operate, and, when a tandem station calls the control center, such 5 operation is impossible for the reason that relay 3510, (which operates as the result of connector C1 selecting an idle remote control group) impresses the same polarity on metering conductor 3003 at 3513 as is connected to the message 10 register.

15 **H2k—Busying of control center trunk**

Associated with each trunk between the tandem exchange and the control center is a trunk-busy- 15 ing key, such as K-23-5. The operation of this key closes relay 21580 by way of 21525, 21001, and 23901.

Relay 21580 operates and at 21552 extends the chain start circuit to the next control center 20 trunk switch, thus busying TS-1 to incoming calls from the remote relay group.

25 **H3—Tandem station calls magneto exchange**

We will next assume that the subscriber at 25 station T1, Fig. 2, desires to call magneto manual exchange "C", he will therefore remove his receiver and dial the number 40. The call number of magneto manual exchange "C", and other similar exchanges, must terminate in the digit 0, 30 as will be apparent later, see item H3c.

Operation under items H1a, b, c, d, e and f are applicable here, and will not be described again.

35 **H3a—Seizing the dialled line when it is idle—(Relays operated 2520, 2530, 2580, 3530, 3540, 4530, and 4540)**

Referring now to Fig. 10, we will assume that wipers 4906, 4907, and 4908 of connector C1, Fig. 4, has been brought into engagement with 40 back contacts 10905, 10906 and 10907, respectively. If the called line is not busy, a circuit is closed (after relay 4530 restores) from 3583, 3543, 4907, 4554, relay 4560, 4534, 4563, wiper 4908, 10907, 10514 to cut-off relay 10520. 45

Relay 10520 operates and clears the called line of attachments at 10521 and 10523.

Relay 4560 operates; closes its holding winding by way of 3583, 3543, 4907, and 4561; opens rotary magnet 4570 at 4562; places interrupted generator 50 on the called line by way of conductor 7007, 4523, 4565, 4005, 3515, 4906, wiper 4907, 10906, 10503, conductor 9002, 9000, 9500, 9521, 9535, conductor 9001, 10505, wiper 4906, 4902, 3517, 4901, 4569, 4525 and relay 4520 (which does not operate 55 on ringing current); and places ring-back tone on the calling line in parallel with relay 3530 by way of conductor 7007, 4523, 4565, 4567, 4908, 4904, 3901, and 3521.

Relay 9500 operates and closes relay 9520 at 60 9582.

Relay 9520 operates; locks itself by way of 9522 and 9532; removes relay 9500 from across the trunk at 9521; prepares the circuit of relay 9530 at 9524; and lights lamp 9909 at 9526 to inform 65 the operator that a call is waiting to be answered.

The operator answers by plugging a cord circuit (not shown) into the "talk" jack J2, whereupon the circuit of relay 9530 is closed by way of 9524 and make contacts of jack J2. 70

Relay 9530 operates; locks to its operating circuit at 9534; opens relay 9520 at 9532; closes the polarizing winding of relay 9540 at 9531; closes relay 9510 at 9531; and connects the operating winding of relay 9540 across the trunk by way 75

of 9001, 9538, break contact J1, 9907, relay 9540, 9503, break contact J1, 9533 and 9002, thus causing connector C1 to cut off the ring and prepare itself for talking, as described under item H1h.

5 Relay 9510 operates and shunts relay 9500 or 9511, but without effect at this time.

Relay 9540 operates at this time because the polarity of the line is reversed, by virtue of the "reversed normals" associated with line 40 in the 10 bank of connector C1; and opens lamp 9908 at 9542.

15 Ordinary lines have "straight normals" as may be seen by reference to Figs. 2 and 4, where it may be noted that line conductor 2001 is normally connected to negative battery through the upper winding of line relay 10510, and is connected by conductor 2003 by bank contact 4913. This latter contact being accessible to wiper 4908, which, when the calling party answers, is connected to negative battery through the upper winding of called party battery feed relay 4810.

20 It follows then that the polarity of an ordinary line is the same when receiving a call as it is when extending a call, i. e., before the called party answers. In the case of a line or trunk to a manual exchange it is desirable that supervision be afforded the attendant operator and, to afford the required supervision under certain conditions, the normals of such lines are reversed as shown in Fig. 10. It will be noted that line conductor 9002 is normally connected to negative battery through the upper winding of line relay 10510, but that the associated bank contact 10008 has been made available to wiper 35 4907.

40 It follows then that the polarity of a line to a magneto manual exchange is the reverse of normal when receiving a call and under this condition of reversed polarity, the direction of current flow is such that relay 9540 will operate.

The circuit for talking is now complete through the winding of repeating coil R-8.

45 *H3b—Release of the connection (Relays operated 2520, 2530, 2580, 3530, 3540, 4530, 4540, 4800, 9500, 9510, 9520, 9530, 9540, 10520)*

50 The release of the connection is under control of the calling party and, when he hangs up his receiver, the connector will restore as described under item H1h. When ground is removed from wiper 4908, relay 10520 will restore and reconnect line relay 10510 across the line.

55 Relay 10510 operates for the reason that the operating winding of relay 9540 is bridged across conductors 9001 and 9002. The connection would now be extended as explained under items H1a, b, and d, were it not for the fact that the normal polarity of the line causes relay 9540 to restore and give the operator disconnect supervision by lighting lamp 9908 by way of 9538 and 9542. When the operator removes the answering plug (not shown) from jack J2, the circuit of relay 9530 is opened.

60 Relay 9530 restores; opens relay 9510 at 9531; and disconnects relay 9540 from across the trunk at 9533 and 9535, thus causing the release of the equipment at the tandem office.

65 Relay 9510 is slow to release and maintains the shunt on relay 9500 for an appreciable length of time after the answering plug (not shown) is withdrawn from jack J2, thus insuring that relay 9500 will not energize during the release of the equipment at the tandem office.

H3c—Prevention of meter registration

An explanation was given under item H1h, of the circuit of message register 2540, and the closure thereof when the called party answered. In the case of a call from a tandem station to a magneto manual exchange it is not desired that the meter should register when the operator answers the call and, for this reason, all such exchanges are assigned numbers terminating in the digit 0. Referring to Figs. 2, 3 and 4, the aforementioned metering circuit extends from ground at meter 2540 by way of 2903, 2907, 3003, 4008, 4521, 4801, through resistance 4916 to negative battery. Attention is directed to the fact that springs 4801 open on the tenth rotary step 16 on all levels, it follows then that meter registration will not occur when calls are made to a magneto manual exchange having a number which terminates in the digit 0.

H4—Miscellaneous operations, tandem exchange

H4a—Ringing interrupter R1

When ground is placed on the ringing machine start conductor 1008, the circuit of relay 7500, Fig. 7, is closed.

25 Relay 7500 operates; prepares a locking circuit for the permanent timer relays at 1504; closes relays 7550 and 7560 of the ringing converter RC-1 at 7508; closes relay 7510 in series with resistance 7800, at 7802, and at the same contact 30 closes circuits to resistance 7801 and resistance 7802 by way of 7812 and 7822, respectively.

35 Relay 7510 operates and removes the short circuit from relay 7520 at 7512, said relay then energizes in series with resistance 7801.

Relay 7520 operates and removes the short circuit from relay 7530 at 7522, said relay then energizes in series with resistance 7802.

40 Relay 7530 operates; short circuits relay 7510 at 7522, closes motor magnet 7540 at 7534; removes ground from conductor 7011 and places generator thereon by way of transformer winding 7822.

Relay 7510 restores and short circuits relay 7520 at 7512.

45 Relay 7520 restores and short circuits relay 7530 at 7522.

Relay 7530 restores; removes the short circuit from relay 7510; opens motor magnet 7540; and replaces ground on conductor 7011. The foregoing cycle repeats, so long as relay 7500 remains 50 operated.

Motor magnet 7540 operates when its circuit is closed and, upon deenergization, advances wipers 7804 to 7807, inclusive, one step.

55 Wiper 7805 is connected to conductor 7003 (generator #1), and it will be noted that conductor 7011 is multiplied to the even-numbered contacts of the bank accessible thereto. It follows then that generator will be impressed upon conductor 7003 only on alternate energizations 60 of relay 7530.

65 Wiper 7806 is connected to conductor 7007 (generator #2) and it will be noted that conductor 7011 is multiplied to contacts 2 and 3, 6 and 7, 10 and 11, 14 and 15, 18 and 19, and 22 and 23 of the bank accessible thereto. It follows then that generator will be impressed upon conductor 7007 in the manner of a code, comprising the repetition of two short rings.

70 The inter-relation of the foregoing may be best understood by reference to the ringing interrupter chart shown in Fig. 12, where the operation has been laid out on the assumption that the operate and release time of relays 7510 and 7520 and 7530 are of equal length. It will be 75

noted that the operation of the three-relay interrupter is symmetrical; that the motor magnet 7540 follows relay 7530; that the advance from bank contact to bank contact occurs upon the deenergization of the motor magnet; that generator is placed on conductor 7003 (generator #1) on each even-numbered bank contact, for the duration of the energization of relay 7530; and that generator is placed on conductor 7007 (generator #2) for the duration of the energization of relay 7530 on two consecutive bank contacts, followed by a pause space represented by two bank contacts.

The locking winding of relay 7500 is multiplied to contacts 2, 3, and 4, 6, 7, and 8, 10, 11, and 12, 14, 15, and 16, 18, 19, and 20, and 22, 23, and 24 of the bank accessible to wiper 7904 and, since said wiper is grounded, it follows that relay 7500 can only restore when the wipers of the 20 ringing interrupter are standing on contact 1, 5, 9, 13, 17, or 21. This arrangement permits the advantages of several stopping or home points. The twenty-fifth contact in the bank accessible to wiper 7904 is carried through self-interrupting springs 7541 to motor magnet 7540, it follows then that the ring interrupter will pass rapidly over the said twenty-fifth bank contact.

Wiper 7907 is connected to ground, contact 18 in the bank associated therewith is connected to 30 "time 2" conductor 7005, and contact 19 to "time 1" conductor 7004. Contacts 22, 23, and 24 are associated with the permanent timer equipment.

H4b—Ringing converter RC—1

35 The ringing converter RC—1, Fig. 7, is started when relay 7500 of ringing interrupter RI closes the relay 7550 by way of 7506, and closes vibrator relay 7560 by way of 7506 and 7551.

40 Relay 7560 operates with an initial amplitude greater than that obtained under normal operating conditions, and prepares to short circuit its winding. This occurs before the energization of relay 7550, since the latter relay is slow to operate.

45 Relay 7550 operates; closes relay 7570 by way of 7560 and 7552; and completes the short circuit of relay 7560 by way of 7561 and 7551, the battery is not short circuited because of resistance 7908.

50 Relay 7570 operates; removes the short circuit from its upper winding at 7571; and connects primary windings 7921 and 7923 to interrupter springs 7561 by way of 7571 and 7572, respectively.

Relay 7560 restores because of its short circuit, removes said short circuit at 7561, and the momentum of its weighted spring causes it to close winding 7921 by way of 7561, radio suppressor winding 7910, 7572, 7921, and 7920.

Relay 7560 operates in series with resistance 60 7908 with normal amplitude; short circuits its own winding at 7561, and closes winding 7923 by way of 7561, 7913, 7571, 7923 and 7920.

Relay 7560 restores and the cycle continues so long as relay 7500 remains energized. Since 65 the magnetic fields produced by windings 7921 and 7923 are in opposite directions, an alternating current is induced in the secondary winding 7922, which is termed "generator."

H4c—Tone relays TRC—1

70 Various tones, heretofore mentioned, are produced by the tone relay group TRC—1 of Fig. 6. Ground placed on the motor start lead 7006 closes relay 6550 in series with resistance 6907, relay 7580 in series with resistance 6910, relay 6590 in

series with resistance 6911 and relays 6560 and 6570.

Relay 6560 operates; closes an opposing winding at 6562; and grounds choke coil 6913 at the same contact. Relay 6560 releases as a result of the energizing of the opposing winding, but again operates, and the high speed buzzing action continues so long as ground remains on conductor 7006.

Relay 6550 operates; connects choke coil 6913 10 to busy tone conductor 6004 at 6552; and short circuits itself at 6551. Relay 6550 restores, but again operates, and the relatively slow speed buzzing action continues as long as ground remains on conductor 7006. Thus the characteristic busy tone is produced, relay 6550 serves to periodically impress upon conductor 6004 the high pitch tone produced by relay 6560.

Relay 6570 operates and functions to intermittently connect ground to choke 6908 at 6572 in 20 a manner similar to that explained in connection with relay 6560. The characteristics of the relay used is such that a distinctive dial tone results on conductor 6005.

Relay 6580 operates; and functions to intermittently connect ground to conductor 6006 at 6582, in a manner similar to that explained in connection with relay 6550. The characteristics of the relay used is such that a distinctive tick tone results on conductor 6006. 30

Relay 6590 operates and functions to intermittently connect ground to conductor 6007 at 6592, in a manner similar to that explained in connection with relay 6550. The characteristics of the relay used is such that a distinctive paystation 35 tone results on conductor 6007.

H4d—Permanent timing equipment PTE

Permanent timing equipment PTE, Fig. 7, is provided in order that permanent lines (line 40 equipment operated, but subscriber fails to dial) may be locked out after a predetermined time interval, thus freeing the link as described under item H1d.

Wiper 7907, upon next engaging the twenty-fourth contact in its bank, will close the circuit of relay 7600 by way of 7593.

Relay 7600 operates; locks itself by way of 7601, 7581, and 7504; prepares the circuit of relay 7590 at 7602; and removes ground from "time in" 50 conductor 7009 at 7604. The removal of ground from conductor 7009 precludes the operation of relay 3580, Fig. 3, and of similar relays in other links.

Wiper 7907, upon next engaging the twenty-third contact in its bank, will close the circuit of relay 7590 by way of 7602.

Relay 7590 operates; locks itself by way of 7591, 7581, and 7504; and prepares the circuit of relay 7580 at 7592.

Wiper 7909, upon next engaging the twenty-second contact in its bank, will close the circuit of relay 7580 by way of 7592.

Relay 7580 operates; locks to its energizing circuit at 7582; and opens relays 7590 and 7600 65 at 7581.

Relay 7590 restores but without effect at this time.

Relay 7600 restores and replaces ground on "time in" conductor 7009.

Relay 7580 restores when wiper 7607 passes beyond the twenty-second bank contact.

The inter-relation of the foregoing may be best understood by reference to the permanent timing chart shown in Fig. 11 where the opera- 75

tion has been laid out on the assumption that ringing interrupter R1 is resting on the first associated bank contact.

We will now assume that motor start conductor 7006 becomes grounded as the result of the seizure of a finder connector link, thereby causing the operation of ring interrupter R1 as described under item H4a. Six complete cycles of ringing interrupter R1 are shown from left to right, and the operating and release points of relays 1580, 1580 and 1600 are indicated in relation thereto.

It will be seen that "time in" conductor 7000 is normally grounded, and remains so until the wipers of ringing machine R1 first reach contact 24. Not only does the link in question "time in" by the operation of relay 1580 as explained under item H1d, but all other links as well, seized before ring interrupter R1 reaches its twenty-fourth bank contact, will "time in" in the same manner. Ground is removed from conductor 7000 on the twenty-fourth step of the first cycle, and is replaced on the twenty-second step of the third cycle of ring interrupter R1, it follows then that no link can "time in" during this period.

To summarize, it may be said that the interval within which a connection may "time in" (assuming the continuous operation of the ring interrupter) is that represented by twenty-seven steps, while the interval within which no connection may "time in" is that represented by forty-eight steps of the ring interrupter.

It will be noted that time cut-off conductor 7010 is normally grounded, and remains so except for the duration of the twenty-first step in each third cycle. All connections which were "timed in", and on which the calling subscriber has failed to dial, will be released during this interval as explained under item H1d.

40 H4e—Control group trunk alternating relays TAR—2

Trunk alternating relays 13540, 14680 and 13560 are associated with the first two trunks from the tenth level in the banks of the incoming connectors so that the first trunk will continue busy after it has been used for a call, until the second trunk is seized. This insures maintenance of service to the control center even though the first trunk is defective.

When the first trunk is seized relay 13550 operates from ground on conductor 13011 by way of 13545, and prepares the circuit of relay 13540 at 13551.

When the first trunk is freed, the circuit of relay 13540 is closed in series with relay 13550 by way of 13551, 13543, relay 13540 and 13562.

Relay 13540 operates; locks at 13541 by way of 13902; and opens relay 13550 at 13543.

Relay 13550 restores and regrounds conductor 13011 by way of 13545 and 13553.

When the second trunk is seized, the circuit of relay 13560 is closed from ground on conductor 13014 by way of 13542 and 13552.

Relay 13560 operates and opens relay 13540 at 13562.

Relay 13540 restores and removes ground from conductor 13011 at 13545, thus making the first trunk again available for calls.

70 H4f—Outgoing sub-tandem exchange trunk alternating relays TAR—1

Trunk alternating relays 13510, 13520 and 13530 are associated with the first two trunks from the ninth level in the banks of the incom-

ing connectors so that the first trunk will continue busy after it has been used for a call, until the second trunk is seized.

The operation of these relays is the same as just described for relays 13540, 13550 and 13560.

H4g—Control group trunk switch alternating relays TAR—3

Control group trunk switch alternating relays 14580 and 14590 are provided so that, assuming the sub-tandem exchange only is calling and that only one call is made at a time, the first and second control groups will be used alternately.

When ground is placed on start conductor 14003, the circuit of the lower winding of differential relay 14580 is closed by way of 14581, as is the lower winding of differential relay 14590, and the upper winding of the latter relay is also closed by way of 14581.

Relay 14580 operates and locks at 14581.

When ground is removed from start conductor 14003, the circuit of the upper winding of relay 14580 is opened.

Relay 14590 operates; directs start conductor 14003 to the second control group trunk switch at 14593; and prepares the circuit of relay 14580 at 14581.

The next time ground is placed on start conductor 14003, the second control group trunk switch will be actuated (as was TS—2, see item J1d), and the upper winding of differential relay 14580 will energize to neutralize the lower winding of that relay, whereupon relay 14580 restores. Relay 14580 remains operated from the ground on start conductor 14003.

When ground is next removed from start conductor 14003, relay 14590 will restore and redirect start conductor 14003 to the first control group trunk switch.

The next time ground is placed on start conductor 14003, the circuit of relay 14580 will again be closed, and the above cycle of operations will be repeated.

45 H4h—Control center trunk alternating relays TAR—4

Control center trunk alternating relays 21580 and 21600 are provided so that, assuming only one call is made at a time from the tandem exchange to the control center, the first and second trunks will be used alternately.

When ground is placed on start conductor 20003, the circuit of the lower winding of differential relay 21580 is closed by way of 21581, as is the lower winding of differential relay 21600, and the upper winding of the latter relay is also closed by way of 21601.

Relay 21580 operates and locks at 21581.

When ground is removed from start conductor 20003, the circuit of the upper winding of relay 21600 is opened.

Relay 21600 operates; directs start conductor 20003 to the second control center trunk switch at 21603; and prepares the circuit of relay 21580 at 21601.

The next time ground is placed on start conductor 20003, the second control center trunk switch will be actuated (as was TS-1, see item H2c), and the upper winding of differential relay 21580 will energize to neutralize the lower winding of that relay, whereupon relay 21580 restores. Relay 21600 remains operated from the ground on start conductor 20003.

When ground is next removed from start conductor 20003, relay 21600 will restore and redirect

start conductor 20003 to the first control center trunk switch.

The next time ground is placed on start conductor 20003, the circuit of relay 21590 will again be closed, and the above cycle of operations will be repeated.

H5—Power supervisory equipment, tandem office

10 The power supervisory equipment distinguishes between alarms of an emergency nature and those that do not require immediate attention.

H5a—No danger fuse alarm

15 Ground placed on conductor 8003, as the result of the blowing of a secondary fuse (not shown), passes by way of lamp 8901 to relay 8500. Lamp 8901 does not light at this time because of the high resistance of relay 8500.

20 Relay 8500 operates; places ground on motor start conductor 7006 by way of 8503 and 8514; and prepares the circuit for relay 8520 at 8502. The ringing interrupter R1 will start as described under item H4a, and, eventually, ground 25 will be returned on "time in" conductor 7004 to operate relay 8520 by way of 8502 and 8522.

25 Relay 8520 operates; locks at 8522; and prepares the circuit of relay 8510 at 8524. Ground will eventually be returned on "time 2" conductor 30 7005 to operate relay 8510 by way of 8524 and 8512.

30 Relay 8510 operates; locks at 8512; removes ground from motor start conductor 7006 at 8514; closes buzzer 8906 by way of 8513 and 8900; 35 shunts the high resistance lower winding of relay 8500 by the low resistance winding of the same relay at 8511, thereby causing lamp 8901 to light; connects conductor 7003 (generator #1) to test tone conductor 8008 by way of 8556 and 40 8516; and opens relay 22580 at 8513.

H5b—Switch release alarm

Ground placed on release battery conductor 8004 by the normal release of a switch, will cause 45 relay 8570 to operate and close relay 8500 by way of 8902 and 8571.

50 Relay 8500 operates and prepares the circuit of relay 8520 at 8502. In the event that the release is abnormal relays 8570 and 8500 will still be energized when ground is returned on conductor 7004, and the operation of relays 8520 and 8510 will follow as described above.

H5c—Distributor alarm

55 Ground placed on the distributor alarm conductor 8005 by start relay 5510 closes relay 8540 by way of lamp 8903. Lamp 8903 will not light at this time because of the high resistance of relay 8540.

60 Relay 8540 operates; grounds motor start conductor 7006 by way of 8544 and 8554; and prepares the circuit of relay 8560 at 8542. The ringing interrupter R1 will start as described under item H4a and in the event that start relay 5510 65 remains operated indefinitely, will return ground in "time 1" conductor 7004 to operate relay 8560 by way of 8542 and 8562.

65 Relay 8560 operates; locks at 8562; and prepares the circuit of relay 8550 at 8560. Ground 70 will eventually be returned on "time 2" conductor 7005 to operate relay 8550 by way of 8564 and 8552.

70 Relay 8550 operates; locks at 8552; removes ground from motor start conductor 7006 at 8554; 75 closes buzzer 8906 by way of 8553 and 8900;

shunts the high resistance lower winding of relay 8540 by the low resistance winding of the same relay at 8551, thereby causing lamp 8903 to light; opens test tone conductor 8008 at 8556; and opens relay 22550 at 8553. 5

Ground placed on conductor 8006 by the failure of the battery charging equipment (not shown) will cause the same relay operation as was last described above.

H5d—Emergency fuse alarm

Ground placed on conductor 8007, as the result of the blowing of primary fuse (not shown) passes to relay 8560 by way of lamp 8905. Lamp 8905 lights and relay 8530 operates to close relay 8550 at 8532. 15

Relay 8550 operates (without waiting for ring interrupter R1 to function) and closes various circuits as described above.

H6—Test Facilities

20

H6a—Alarm forwarding circuit

The alarm sender equipment is connected to one of the trunks to the control center, as shown in Figs. 21 and 22. The alarm receiving equipment is connected to the control center and of the same trunk as shown in Fig. 23. High resistance relay 23600 is normally bridged across the trunk in question; but its resistance is such that relays 21550 and 21560 are not operated thereby. 25

The alarm equipment functions to extend an alarm to the control center operator in the event of the failure of certain switching equipment at the tandem exchange. After receiving such an alarm the operator dials a certain test number in the tandem exchange to determine the nature of the particular alarm involved, and thereby resets the alarm forwarding equipment. 35

The alarm sender occupies the associated control trunk only momentarily, and can extend an alarm only when the associated trunk is idle. 40

When an alarm is initiated by the power supervisory equipment (see item H5a and H5d), the circuit of relay 22550 or the circuit of relay 22580 45 will be opened, depending on whether the alarm is of an "emergency" or "no danger" condition.

The deenergization of relay 22550 (or relay 22580) maintains the circuit of buzzer 8906 by way of 8002, 22581 (or 22551) and 22900; and 50 extends the circuit of the relay associated therewith to test contact 6010 by way of 6011, 22552 (or 22582) and 22560 (or 22570); and opens the circuit of relay 22530 at 22553 (or 22583).

Relay 22530 restores; shunts trunk conductors 21000 and 21001 by way of 21003, 22533, 22511, and 21002, thereby causing the deenergization of relay 23600; and closes relay 22520 at 22532. 55

Relay 22520 operates and closes slow-to-operate relay 22510 at vibrating contact 22522.

Relay 22510 operates, after a time, and opens the shunt across the trunk at 22512.

It will be noted that the foregoing operations cannot take place should the trunk be in use for, 65 at that time, relay 22540 will be operated to maintain relay 22530 energized, because of ground on conductor 21004 at either 21523, 21533, or 21551.

The momentary short circuit on the trunk 70 conductors will cause relay 23600 to fall away and open relay 23610 at 23602.

Relay 23610 restores and closes relay 23620 at 75 23614.

Relay 23620 operates; locks by way of 23622 75

and the alarm release key K-23-4, closes buzzer 23809 at 23821; and closes alarm lamp L-23-2 at 23823.

- 5 The operator acknowledges the alarm by momentarily actuating key K-23-4, thereby opening the locking circuit of relay 23820 (relay 23820 now falls away, because relays 23800 and 23810 have presumably reenergized in the meantime), originates a call to the tandem exchange as described under item L1, and dials the test number as described below.

H6b—Operator dials test number

15 Connector bank terminals 6008, 6009 and 6010, shown in Fig. 6, are accessible to wipers 37904, 37905, and 37906 of incoming connector IC-1, Fig. 37. When the control operator dials the test number assigned thereto, the incoming connector will seize the dialled line as described under item L1g, whereupon ground on bank contact 6010 will close the circuit of relay 6620.

20 Relay 6620 operates; connects test tone conductor 8008 to bank contact 6009 by way of 6612 and 6622; places ground on motor start conductor 7006 at 6623; and closes a circuit by way of 6621, 6611, relay 6600, 6008, and thence through relay 37500.

25 Relay 37500 operates to cut off the ring as described under item L1h.

30 Relay 6600 operates and closes relay 6610 at 6602.

35 Relay 6610 operates; locks by way of 6611 and 6621; and opens relay 6600 and the circuit to the connector at 6611.

The operator's talking circuit is now connected to the test tone circuit, which may be connected to generator #1 conductor 7003, to generator #2 conductor 7007, or connected to neither. The 40 reception of generator #2, in response to the calling of the test number, is an indication of the normal function of the tandem exchange equipment. The reception of generator #1 indicates a no-danger trouble alarm, while the absence 45 of any tone indicates an emergency alarm.

Ground on bank contact 6010 passing by way of 6011 and 22552 (or 22582) to relay 22560 (or relay 22570).

50 Relay 22560 (or 22570) operates and closes its lower winding in series with relay 22550 (or relay 22580) by way of 22562 (or 22572). In the event that relay 8510 (or 8550) has restored in the meantime, this circuit is ineffective for the reason that the lower winding of relay 22560 (or 55 22570) will not maintain the said relay operated in parallel with resistance 8900, and relay 22560 will restore without effect when connector IC-1 removes ground from back contact 6010.

In the event that relay 8510 (or 8550) is still 60 energized, relay 22560 will lock in series with relay 22550 (or relay 22570) will lock in series with relay 22580, and relay 22550 (or 22580) will again operate to close the circuit of relay 22580. Thus it will be seen that the forwarding 65 of a "no danger" alarm does not preclude the forwarding of an emergency alarm.

ITEM I

CIRCUIT DESCRIPTION—MAGNETO MANUAL EXCHANGE

- 70 **11—Magneto manual exchange calls tandem exchange station**

11a—Making the called line busy

When the operator at the magneto manual exchange "C" desires to call a tandem exchange

station, she inserts the plug of an idle cord circuit (not shown) into the "talk" jack J2, of an idle trunk, which will be assumed to be TE of Fig. 9, she then inserts the plug P of the dial cord circuit DC into the "dial" jack J1 and momentarily operates the start key K3, thereby closing the circuit of relay 9530 by way of 9533, ring of jack J1 and of plug P, keys K1, K3, and resistance 8911.

10 Relay 9530 operates; locks its lower winding by way of 9534 and the contacts of jack J2; lights lamp 9909 at 9536; closes the polarizing winding of relay 9540 at 9531; closes relay 9510 at 9531; and closes the loop circuit of line relay 15 10510 by way of 10523, 10503, 9002, 9533, ring of jack J1 and of plug P, contacts of keys K1 and K2, dial impulse springs 9910, contacts of keys K2 and K1; tip of plug P and jack J1, 9535, 9001, 10501, and 10521.

20 Relay 10510 operates, closes start relay 5510 by way of 10518, 10534, and 5001; and places ground on test contact 10907 at 10514 to make the calling line busy.

25 Operation under items H1b, c and d are applicable here and will not be described again.

The operator next dials the tandem subscriber's number by means of the dial associated with the dial cord DC. Operation under items H1e, f and g are applicable here and will not be described again. If the operator should desire to 30 release the connection, she may do so by momentarily operating recall key K1, thus opening the circuit to the tandem office.

35 When the dialling is completed, the operator will remove plug P from jack J1, thereby bridging the operating winding of relay 9540 across the calling line by way of 9001, 9535, tip contacts J1, 9907, 9540, 9903, ring contacts J1, 9533 and 9002. Due to the normal polarity of the line the direction of current flow at this time is 40 such that relay 9540 will not operate.

11b—Called party answers

45 Operation under H1h is applicable here and will not be again described. Attention is, however, called to the fact that the reversal of polarity on the calling line, resulting from the operation of relay 3520, will cause the energization of relay 9540.

50 Relay 9540 operates and opens lamp 9909 at 9542, thereby giving the operator answering supervision.

Attention is directed to the fact that relay 10500 will not operate following the energization 55 of relay 3520, (as did message register 2540 as described under item H1h) for the reason that relay 10500 is connected to negative battery, as is resistance 4916.

60 *11c—Release of the connection*

When the called party hangs up his receiver, the polarity of the calling line is restored to normal, as previously described under item H1a 65 and, as a result, relay 9540 will deenergize and give the operator disconnect supervision by closing the circuit of lamp 9909 at 9542. The operator will now remove the plug (not shown) from talk jack J2, thereby opening the circuit of relay 9530.

70 Relay 9530 restores; opens lamp 9909 at 9536; and opens the loop to the tandem office at 9533 and 9535, whereupon the equipment therein releases as previously explained under item H1i. 75

12—*Magneto manual exchange calls control center*

When the operator at magneto manual exchange "C" desires to call the control center, she will initiate the call as described under item 11a. The dialling of the digit 0 by the operator will cause connector C1 to function as previously described under items H2a, b, etc., and the only peculiarity of operation which we need consider at this time relates to the extinguishment of lamp 9909 when the control operator answers.

When the operator at the control center answers, circuit changes take place as described under item H2d, and the magneto manual exchange operator will pass the number of the called party, after which she restores key K2 and removes the dial cord plug P from dial jack J1. The operating winding of relay 9540 is now bridged across the calling line.

At this time metering conductor 3003 has ground impressed upon it by relay 3510 at 3513 (as was previously explained under item H2d), a circuit is therefore closed to relay 10500 by way of 10903 and 2907.

Relay 10500 operates and reverses trunk conductors 9001 and 9002 with respect to talking conductor 3000 and 3001. Inasmuch as trunk conductors 3000 and 3001 have normal polarity impressed upon them at this time (as will be apparent from a reconsideration of items H2a and H2d), it follows that relay 10500 will function to impress reversed polarity on conductors 9001 and 9002, with the result that the direction of current flow is such that relay 9540 will operate to extinguish lamp 9909.

When the control operator disconnects, the connection is released (as described under item H2g), whereupon LC-2 goes into the locked-out position (as described under item H1d), and normal polarity is re-established on conductors 9001 and 9002, thereby causing relay 9540 to restore and light lamp 9909 as a disconnect signal.

ITEM J

45 CIRCUIT DESCRIPTION—SUB-TANDEM EXCHANGE
J1—*Local subscriber initiates call*J1a—*Marking the calling line (no relays operated)*

With reference to Fig. 24, when the subscriber originates a call by turning his magneto at telephone T-2, assumed to have the number 913, generator passes over conductors 24000 and 24001 and energizes relay 24500 by way of 24501 and 24511.

Relay 24500 operates; locks its lower winding by way of 24502 and 24512; opens its operating winding at 24501; closes relay 24560 by way of 24553 and 24508; closes a start circuit by way of 24506, 24555, 24014, relay 25520, 25012, 26518-3, 26528, 26013, bank contact and wiper 29903, 29541, and motor magnet 29540; closes similar start relays in other finder switches by way of 24506, 24013, 25521 and 24015; and connects battery through relay 24510 by way of 24504 and conductor 24003 to the contact associated therewith in the bank accessible to wiper 25902, to mark the calling line.

Relay 24560 operates; and prepares a circuit to relay 24550, and its own locking circuit at 24561.

J1b—*Idle finder connector link finds calling line*
(Relays operated 24500 and 24560)

The start relay of each finder in the group will attempt to energize but, because of the chain cir-

cuit starting at 26521, relay 25520 only will become fully energized.

Relay 25520 operates in series with the motor magnet 29540; and closes motor magnet 25500 by way of 25536, 25512, and 25523. Motor magnet 29540 does not energize at this time due to the high resistance of relay 25520.

Motor magnet 25500 operates; and closes relay 25510 at 25501.

Relay 25510 operates; and opens motor magnet 25500 at 25512.

Motor magnet 25500 restores; advances wiper 25900 to 25905, inclusive; and opens relay 25510 at 25501.

Relay 25510 restores; and recloses motor magnet 25500 at 25512. The above explained interaction between motor magnet 25500 and relay 25510 will cause the wipers to be advanced step-by-step until battery through a cut-off relay is encountered by wiper 25902. When wiper 25902 encounters the bank contact associated with conductor 24003 a circuit is closed by way of relay 24510, 24503, 24003, 25902, 25525, relay 25510, relay 25530, 25002 and 26535.

Relay 25510 already operated; remains operated over the above circuit, and further rotation of F-2 is prevented at 25512.

Relay 24510 operates; locks to its energizing circuit at 24514; opens the locking circuit of relay 24500 at 24512 and opens the operating circuit of relay 24500 at 24511.

Relay 25530 operates; locks its lower winding by way of 25532, 25003, 26521, 25004, and 25545; connects direct ground to relay 24510 at 25533, thereby shunting out relay 25510 and its own upper winding; extends the calling line by way of 25531 and 25535 to windings 2 and 4 of repeating coil R-27; and closes relay 26510 at 25534.

Relay 25510 restores; but without effect at this time.

Relay 24500 restores and removes ground from start conductor 24013 at 24506, thereby rendering effective a circuit from 24512, relay 24550, 24551, 24561 and relay 24560.

Relay 24550 operates; locks both of its windings in series at 24552; and opens relays 24560 and 25520 at 24551.

Relay 24560 restores; but without effect at this time.

Relay 25520 restores; but without effect at this time.

Relay 26510 operates; ground trunk start conductor 30000 by way of 26501, 26512 and 26533; extends pay station tone (in the event that the calling line is a pay station) to trunk conductor 30006 by way of 27903, 26011, 26542, 26516, 25009, wiper 25903, 24004, 24900 and paystation tone conductor 31088; and marks the calling link by placing ground on conductor 30003 by way of 26518-5, 26018, normal bank contact and wiper 29904, 29538 and 29514.

J1c—*Idle tandem exchange trunk switch finds calling link*

(Relays operated 24510, 25530 and 26510)

Ground on start conductor 30000 passes to relay 30580 by way of 30581; to the upper winding of differentially wound relay 30590 by way of 30581; to the lower winding of the same relay by way of 30592; and to relay 30530 by way of 30574, 30508 and 30591.

Relay 30580 operates and establishes a local locking circuit for the upper windings of itself and relay 30590 at 30581.

- Relay 30530 operates; and closes motor magnet 30600 by way of 30542, 30572, and 30534. Motor magnet 30600 operates; and closes relay 30540 at 30601.
- 5 Relay 30540 operates; and opens motor magnet 30600 at 30542. Motor magnet 30600 restores; advances wiper 30900 to 30905, inclusive, one step; and opens relay 30540 at 30601.
- 10 Relay 30540 restores; and recloses motor magnet 30600 at 30542. The above explained interaction between motor magnet 30600 and relay 30540 will cause the wipers to be advanced step-by-step until ground is encountered by wiper 30901. When wiper 30901 encounters the bank contact associated with conductor 30003, a circuit will be closed from ground thereon by way of wiper 30901, 30504, 30532, relay 30540 to lower winding of relay 30570.
- 20 Relay 30540 already operated, remains operated over the above circuit, and further rotation of TS-3 is prevented at 30542.
- Relay 30570 operates; prepares a locking circuit for itself in series with relay 36500 by way of 25 30573, wiper 30905, bank contact and conductor 30007, 27544, 26004, 26522 and relay 25500; opens relay 30530 at 30574; closes relay 30550 by way of 30531 and 30571; connects windings 1 and 3 of repeating coil R-27 by way of conductors 30005 and 30006, wipers 30903 and 30904, contacts 30555 and 30557, and contacts 30575 and 30577 to tandem exchange trunk conductors 14000 and 14001; and opens motor magnet 30600 at 30572.
- 35 Relay 30530 restores and opens relays 30540 and 30570 at 30532.
- Relay 30540 restores; but without effect at this time.
- Relay 26500 operates (following the restoration 40 of relay 35030); removes ground from trunk start conductor 30000 at 26501; and remove marking potential from conductor 30003 at 26502.
- Relay 30590 operates when ground is removed from conductor 30000, because of its energized 45 upper winding; and prepares the restoring circuit of differential relay 30580 at 30592.
- Relay 30550 operates; locks to its operating circuit at 30553; places negative battery by way of 30906, 30557 and 30577 on tandem exchange 50 trunk conductor 14001; and closes relay 30560 at 30551.
- Relay 30560 operates; locks by way of 30561 and 30571; and opens relay 30550 at 30561.
- Relay 30580 restores; removes battery from 55 trunk conductor 14001 at 30557; and reconnects the said conductors to repeating coil R-27.
- J1d—Idle control group trunk switch finds calling sub-tandem exchange trunk*
- 60 (Relays operated, 24510, 25530, 25500, 26510, 30560 and 30570).
- The splash of negative battery over conductor 14001 energizes relay 14510 by way of 14565 and 14543.
- 65 Relay 14510 operates; closes the lower winding of differential relay 14530 by way of 14511 and 14521, and the upper winding of the same relay by way of 14511 and 14531; and closes the lower winding of relay 14520 by way of 14511 and 14521.
- 70 Relay 14520 operates; locks by way of 14521 and 14561; closes relay 14570 at 14524; and places ground on holding conductor 13002 by way of 13517, 13018 and 14522 to make the sub-tandem exchange trunk busy in the banks of the incoming connectors.
- Relay 14570 operates; and disconnects the charge lead 14002 from trunk conductor 14000 at 14571.
- Relay 14510 restores at the end of the splash of negative battery on trunk conductor 14001, and opens the upper winding of relay 15430 at 14511.
- Relay 14530 operates by virtue of its lower winding; marks the calling trunk by placing ground on conductor 14007 by way of 14900, 14526, and 14536; closes a multiple circuit to 10 relay 14570 at 14534; and ground start conductor 14003 at 14538.
- Ground on start conductor 14003 energizes the upper winding of differential relay 14590 by way of 14591; energizes the lower winding of the same relay by way of 14581; closes relay 14580 by way of 14581; and closes relay 15520 by way of 15592, 14008, 14593, and 14538.
- Relay 14580 operates; and locks locally at 20 14581.
- Relay 15520 operates; removes ground from conductor 19008 at 15527 to make RCG—I busy to calls from the control center; grounds hold conductor 13011 by way of 13547; 13018 and 15525 to make RCH—I busy to calls from the tandem office; closes motor magnet 15510 by way of 15521, 15532 and 15572; and prepares the stepping circuit at 15523.
- Motor magnet 15510 operates; and closes relay 15530 at 15511.
- Relay 15530 operates; and opens motor magnet 15510 at 15532.
- Motor magnet 15510 restores; advances wipers 15900 to 15904, inclusive, one step; and opens relay 15530 at 15511.
- Relay 15530 restores; and recloses motor magnet 15510 at 15532. The above explained interaction between motor magnet 15510 and relay 15530 will cause the associated wipers to be advanced step-by-step until ground is encountered by wiper 15903. When wiper 15903 encounters the bank contact associated with conductor 14007, a circuit will be closed from ground thereon by way of wiper 15903, 15523, and lower winding of relays 15530 and 15510 in series.
- Relay 15530 already operated; remains operated over the above circuit, and further rotation of the motor magnet 15510 is prevented at 15532.
- Relay 15570 operates; locks itself in series with relay 14560 by way of 14006, back contact 15907, wiper 15902, 15021, 16573, 15022 and 15571; places multiple grounds on hold conductor 13011 by way of 15575, 15020, and 18583; closes relay 15590 at 15573; closes relay 20504 by way of 19011, 19582, 17030, 17555, 15023, and 15573; closes relay 15580 at 15572; and short circuits the upper winding of relay 20580 by way of 15030 and 15574.
- Relay 14560 operates in series with the upper winding of relay 15570; opens relays 14520 and 14530 at 14561; maintains ground on hold conductor 13002 by way of 13517, 13018, 14522, 14532 and 14562; maintains relay 14570 at 14564; and extends the trunk to RCG—I by way of 14563 and 14565.
- Relay 14530 restores; removes ground from ground conductor 14007 at 14536, and from conductor 14003 at 14538.
- Relay 14520 restores but without effect at this time.
- The removal of ground from start conductor 14003 causes relay 14590 to energize by virtue of its lower winding.
- Relay 14590 operates; extends start conductor 14003 to the next idle control relay group at 75

14583; and at 14591 prepares the restoring circuit of relay 14580.

Relay 15590 operates; switches start conductor 14008 to the next available remote control group at chain contact 15592; removes ground from ATB-2 conductor 15031 at 15584; and opens relay 15520 at 15592.

Relay 15520 restores; and opens the lower windings of relays 15530 and 15570 at 15523.

10 Relay 15580 operates; connects the calling trunk through to windings 1 and 3 of repeating coil R-19 at 15589 at 15589-2; closes relay 18560 by way of 15028 and 15586; and closes relay 19570 by way of 15028, 15562 and 15586.

15 Relay 15530 restores; but without effect at this time.

J1e—Idle control center trunk switch finds calling control group. (Relays operated 14560, 14570, 15570, 15580, 15590, 24510, 25530, 26500, 26510, 20 30560 and 30570)

Relay 19570 operates; opens the circuit to conductor 19008 at 19571, so ground will not be replaced thereon at the restoration of relay 15520; 25

25 and reverses battery 20000 and 20001 at 19573 and 19575, in order that "answering supervision" may later be given to the control operator.

Relay 18560 operates; locks its upper winding by way of 18561, 15023 and 15573; and at 18563 30 prevents dial tone from being connected to the trunk when the operator answers.

Relay 20540 operates; grounds motor start conductor 7006 at 20545 to start the ringing equipment; places marking potential on the 35 associated contact accessible to wiper 21930 by way of conductor 20002, 20583, 20543, 15017 and 15527; closes relay 20560 at 20542; closes the lower windings of relays 21600 and 21590 by way of 21591, 20003, 20541, 20581, 15030 and 21571; 40 closes the upper winding of relay 21600 by way of 21601, 20003, 20541, 20581, 15030, and 21571, and closes relay 21530 by way of 21524, 21552, 21603, 20003, 20541, 20581, 15030 and 21571.

Relay 21590 operates and locks locally at 21591. 45 Relay 21600 does not operate at this time because of its differential windings.

Relay 21530 operates; closes the circuit of motor magnet 21500 by way of 21512, 21522 and 21532; and prepares a stopping circuit at 21531.

50 Motor magnet 21500 operates and closes relay 21510 at 21501.

Relay 21510 operates and opens motor magnet 21500 at 21512.

Motor magnet 21500 restores; advances wipers 55 21900 to 21904, inclusive; and opens relay 21510 at 21501. Relay 21510 and motor magnet 21500 continues to operate as above described, and advanced the associated wipers step-by-step until test wiper 21903 engages the marked bank contact.

60 When wiper 21903 engages the bank contact associated with conductor 20002 a circuit is closed from ground at 15527, 15017, 20543, 20583, 20002, 21903, 21531, 21905; and relays 21520 and 21510.

65 Relay 21510 will remain operated and thus prevent further operation of motor magnet 21500.

70 Relay 21520 operates; locks its upper winding by way of 21521, 21904 and the contact upon which it is standing, 17013, 17523, 16008, 16577, 16563, 16009 and relay 19580; connects RCG-1 through to the control center trunk conductors 21000 and 21001 by way of 21525 and 21527; switches start conductor 20003 through to the next available control center trunk switch at

21524; removes ground from ATB-1 conductor 21006 at 21526; and opens relay 21530 at 21524.

75 Relay 21530 restores and opens relays 21520 and 21510 at 21531.

Relay 21510 restores; but without effect at this time. Relay 21520 remains operated because of its locked second winding.

Relay 20560 operates; locks at 20561 to ground on delay ground conductor 20004 at 20571; closed relay 20550 by way of delay conductor 20005 and 10 20562; and prepared to send generator over the control trunk by way of 20563 and 20565.

Relay 20550 operates when generator becomes available, and opens relay 20570 at 20552.

Relay 20572 restores and removes ground from 15 delay ground conductor 20004 at 20571; thus opening the locking circuit of relay 20560.

J1f—Signalling the control center operator (Relays operated 14560, 14570, 15570, 15580, 15590, 20 18560, 19570, 20540, 20550, 20560, 21520, 24510, 25530, 26500, 26510, 30560, 30570)

For the purpose of the present description it will be assumed that trunk switch TS-1 found 25 RCG-1, whereupon the control center is signalled from generator or conductor 7008 by way of 20565, 20000, 21900, 21527, 21000, 23513, 23554, 23612, 23571, relay 23560, 23906, 23515, 21001, 21525, 21901, 20001, 20563 and 20902.

Relay 19580 operates; opens relay 20540 at 30 19582; provides a multiple holding circuit for relay 15590 by way of 15023 and 19584; closes relay 20580 by way of 19012, 19586 and 19584; and provides ring back tone by connecting interrupted generator conductor 7007 by way of 19585, 35 19900, 18005, 18579-1, 16004, 16579-2, 15004, 15589-2, 15543, 15900, 14004, 14565 and 14543 to trunk conductor 14001.

Relay 20540 restores; removes ground from conductor 20002 at 20543; removes ground from 40 start conductor 20003 at 20541; and opens relay 20560 at 20542.

Relay 20560 restores (assuming that relay 20570 has already restored); removes generator from the control trunk at 20453 and 20565; and 45 opens relay 20550 at 20562. Under the assumed condition, the duration of the splash ring on the control trunk is determined only by the fall-away time of slow-to-release relay 20560.

Relay 20550 restores and closes relay 20570 at 50 20552.

Relay 20580 operates; locks at 20582 to conductor 15023; opens conductor 20003 at 20581; and opens conductor 20002 at 20583.

Relay 20570 operates and again places ground 55 on ground delay conductor 20004.

Relay 21600 operates when ground is removed from start conductor 20003, because its lower winding only is now effective; and switches the chain circuit through to the next available control center trunk switch.

J1g—Control center operator answers (Relays operated 14560, 14570, 15570, 15580, 15590, 18560, 19570, 19580, 20580, 21520, 24510, 25530, 65 26500, 26510, 30560, 30570)

Relay 23560 operates in response to the splash of ringing current impressed upon the control trunk and mechanically locks armature springs 70 23561 and 23562 under control of cut-off relay 23570; closes a multiple circuit to relay 23610 at 23562; and closes the circuit of answering lamp L-23-1 at 23561.

The operator answers the call by inserting the 75

answering plug of an idle cord circuit (not shown) in the combined answering and calling jack J-23, thus closing the circuit of cut-off relay 23570 by way of the sleeve of the jack.

- 5 Relay 23570 operates; releases the springs of relay 23560 mechanically; removes relay 23560 from across the trunk at 23571; closes a multiple circuit to relay 23510 at 23572; removes high resistance relay 23560 from across the trunk at 10 23574; connects relay 23540, in series with windings 1 and 2 of repeating coil K-23, across the trunk at 23574; and closes relay 23550 at 23576.

Relay 23560 restores and extinguishes answering lamp L-23-1 at 23581.

- 15 15 Relay 23550 operates; but without effect at this time.

The bridging of relay 23540 across the trunk completes a circuit from ground at relay 19540, differential relay 19560, 19575, winding 4 of repeating coil R-19, 19889, 20563, 20001, 21901, 21525, 21001, 23515, winding 1 of repeating coil R-23, polar relay 23540, 23531, winding 3 of repeating coil R-23, 23574, 23513, 21000, 21521, 21980, 20000, 20565, 19801, winding 2 of repeating coil R-19, 19573, differential relay 19560, relay 19540, and marginal relay 19530.

Relay 19560 does not operate at this time because its windings are opposed.

- 30 Relay 19530 operates and prevents the operation of relay 18540 at 19532.

Relay 18540 operates and closes relay 18580 by way of 18808, 19542, and 19552.

Relay 18580 operates, removes a short circuit from the lower winding of relay 20510 at 18583, thereby supplying ground through this winding to guard conductor 18011; shunts contact 15575 at 18583; and closes relay 18570 at 18582.

Relay 18570 operates; removes ring back tone from the calling line at 18579-1; closes a multiple circuit to relay 19580 at 18575; closes the circuit of relay 20530 by way of 18011, 18574, 17029, and 18512; and connects battery through the windings of differential relay 15560 and impedance 16510 to both sides of the sub-tandem exchange trunk, so as to place the equipment therein under control of the operator. The mid-part of relay 15560 is connected to battery by way of 15814, 17547, 17011, 18577, 17010, 18551, and 19883. The upper winding of relay 15560 is connected to conductor 14001 by way of 14543, 14565, 14001, 15905, 15900, 15543, 15589-2, 15004, 16587, 16005, 16589-1, 15007 and the left-hand winding of impedance 16510 and 15006. The lower winding of relay 15560 is connected to conductor 14008 by way of 14541, 14563, 14005, 15906, 15801, 15841, 15589, 15809, 16585, 15010, 15587, 15811, right-hand winding of impedance 16510, 16807, 18513, and 15008. Relay 15560 is differentially wound and does not operate at this time.

- 60 Relay 23540 operates since the polarity of the trunk is reversed due to the energization of relay 19570, and closes relay 23580 at 23541.

65 Relay 23580 operates and at 23583 and 23585 removes battery and ground from the tip and ring of jack J-23 in order to give answering supervision in the cord circuit (not shown).

70 Relay 20530 operates; closes relay 20520 at vibrating contact 20531; and bridges the upper winding of impedance 20510 across the trunk at 20533, but without effect at this time.

75 Relay 20520 operates after a time; removes the upper winding of impedance 20510 from the trunk at 20523 and 20525; and shunts the lower winding of said impedance at 20521.

J1h—Forwarding paystation tone (Relays operated 14560, 14570, 15570, 15580, 15590, 18560, 18570, 18580, 19530, 19540, 19570, 19580, 20520, 20530, 20580, 21520, 24510, 25530, 26500, 26510, 30560 and 30570)

The circuit over trunk conductors 14000 and 14001 is completed at ground at relay 26570 by way of 26000 of differential relay 27500, contacts 27513 and 27511, windings 1 and 3 of the repeating coil R-27, conductors 30005 and 30006, wipers 30903 and 30904, contacts 30557 and 30555 and contacts 30577 and 30575.

10 Relay 26570 operates and closes relay 26580 by way of 26572 and 26581.

15 Relay 26550 operates; prepares the circuit of relay 29520 and motor magnet 29540 at 26550, and closes relay 26530 at 26554.

20 Relay 26530 operates; closes relay 26520 at 26533; and closes relay 26540 at vibrating contact 26531. Due to the vibration of the weighted spring 26531, relay 26540 will not immediately energize.

25 In the event that the calling telephone is a paystation, the operator will hear paystation tone prior to the energization of relay 26540. The placing of this tone on conductor 30006 was discussed under item J1b.

30 Relay 26540 operates and removes paystation tone at 26542. It will be noted that the operator cannot cause the splash of paystation tone to be repeated, as she could in connection with a call from the tandem exchange, as explained under item H2f.

35 Relay 26520 operates and removes ground from the bank accessible to wiper 28903 at 26523.

The transmission circuit is now complete between the calling subscriber and the control center. For the purpose of the present explanation it will be assumed that the operator completes the call to the desired party via the control center exchange equipment.

J1i—Release of the connection (Relays operated 14560, 14570, 15570, 15580, 15590, 18560, 18570, 18580, 19530, 19540, 19570, 19580, 20520, 45 20530, 20580, 21520, 25530, 26500, 26510, 26520, 26530, 26540, 26550, 26570, 30560 and 30570)

50 When the conversation has been completed the calling subscriber may ring off and signal the distant operator. Generator on the calling line will operate relay 27550 by way of 27001, 28535, 27002, and 27502.

55 Relay 27550 operates; and closes relay 27530 at 27582.

Relay 27530 operates; and closes relay 27520 at 27534.

60 Relay 27520 operates; opens one side of the trunk at 27523, and at the same point closes a circuit to keep relay 27500 in balance so that it will not operate. The unbalancing of the trunk causes the operation of relay 15560.

Relay 15560 operates; and opens relay 19570 at 15562.

65 Relay 19570 restores; reversing the battery in the trunk to the control center to give disconnect supervision as described under item H2g.

70 Relays 18530 and 18540 restore when the operator disconnects.

Relay 19549 restores; opens relay 18580 at 70 19542, closes relay 18580 by way of 17207, 17514, 17026, 18572, 18010, 19542, and 18552.

75 Relay 18550 operates and closes relay 18570 by way of 16016 and 18554.

Relay 16570 operates momentarily and opens 75

- relays 21520 and 19580 at 18577; and opens relays 15570 and 14560 at 18573.
 Relay 18580 restores; and opens relay 18570 at 18582.
 5 Relay 18570 restores; removes battery from the simplex of the trunk at 18577 to cause the tandem exchange equipment to release; opens relay 15570 at 18571, opens relay 20530 at 18574, and opens relay 18550 at 18572.
 10 Relay 15570 restores and opens relay 15580 at 18572; opens relays 15580, 18580 and 20580 at 18573.
 Relay 20530 restores and opens relay 20520 at 20531.
 15 Relay 18550 restores and opens relay 18570 at 18564.
 Relay 15580 restores and opens relay 18570 at 18586.
 Relay 14560 restores and opens relay 14570 at 14564.
 20 Relay 26570 restores and opens relay 26550 at 26571.
 Relay 26550 restores and opens relay 26530 at 26554.
 25 Relay 26530 restores; opens relay 26520 at 26533; opens relay 26540 at 26531; and opens 25530 at 26535.
 Relay 26520 restores and opens relays 26500 and 30570 at 26522.
 30 Relay 25530 restores; opens relay 24510 at 25533; and opens relay 26510 at 26534.
 Relay 30570 restores and opens relay 30560 at 30571.
 The equipment is now at normal.

35 **J2—Miscellaneous operations—Sub-tandem exchange**

- J2a—Link alternating relays TAR—5**
- Link alternating relays 24550, 24560 and 24570 are provided so that, assuming only one call is made at a time, the first and second links will be used alternately.
 When ground is first placed on start conductor 24013, the circuit of relay 24560 is closed by way of 24553.
 45 Relay 24560 operates and prepares a locking circuit for itself by way of 24561, 24551, upper winding of relay 24550 and 24572.
 When ground is removed from start conductor 50 24013 the above-traced locking circuit becomes effective, and—
 Relay 24550 operates; locks its two windings in series by way of 24552 and 24572; opens relay 24560 at 24551; prepares the circuit of relay 55 24570 at 24554; and opens conductor 24014 at 24555, thereby insuring that the next call must pass to the second finder.
 Relay 24560 restores and prepares the circuit of relay 24570 at 24562.
 60 When ground is again placed on start conductor 24013, it passes to the second finder by way of 24013, 25521, and 24015. The relays of the second finder function as did those of F-2 (explained under item J1b) and, when the equivalent of relay 26510 operates, the circuit of relay 24570 is closed by way of 24562, 24544 and 24016 and the equivalent of 26019 and 26518—4.
 Relay 24570 operates and opens the circuit of relay 24550 at 24572.
 70 Relay 24550 restores; opens the circuit of relay 24570 at 24554; prepares the circuit of relay 24560 at 24553 and 24551; and reconnects start conductor 24013 to conductor 24014 at 24555.
 Relay 24570 restores, but without effect at 75 this time.

J2b—Trunk alternating relays TAR—6

Trunk alternating relays 30580 and 30590 are provided so that, assuming only one call is made at a time, the first and second trunks to the tandem exchange will be used alternately. 5

When ground is placed on start conductor 30000, the circuit of the upper winding of differential relay 30580 is closed by way of 30581. The upper winding of differential relay 30590 is closed by way of 30591, and the lower winding by way of 30592, but without effect at this time.

Relay 30580 operates and locks at 30581.

When ground is removed from start conductor 30000, the circuit of the lower winding of relay 30580 is opened. 15

Relay 30590 operates; directs start conductor 30000 to the second trunk switch at 30591; and prepares the circuit of relay 30580 at 30592.

The next time ground is placed on start conductor 30000, the second trunk switch will be actuated (as was TS3, see item J1c), and the lower winding of differential relay 30580 will energize to neutralize the upper winding of that relay, whereupon relay 30580 restores. Relay 30580 remains operated from the ground on start conductor 30000. 20

Then ground is next removed from start conductor 30000, relay 30590 will restore and redirect start conductor 30000 to the first trunk switch. 30

The next time ground is placed on start conductor 30000, the circuit of relay 30580 will again be closed, and the above explained cycle of operations will be repeated.

J2c—Timing equipment TE

When the timing equipment TE, Fig. 31, is standing in normal position, ground is impressed upon "time-in" conductor 31000 at 31000. Ground placed on time start conductor 31003 40 closes the circuit of relay 31500.

Relay 31500 operates; closes relay 31510 by way of 31532 and 31502; and places ground on wiper 31901 or 31502.

Relay 31510 operates and closes relay 31520 45 by way of 31511 and 31502.

Relay 31520 operates; locks by way of 31521, vibrating contacts 31511 and 31502; and closes relay 31530 by way of 31523 and 31502.

Relay 31530 operates and opens relay 31510 at 50 31532.

Relay 31510 restores and, when its vibrating contact comes to rest, opens relay 31520 at 31511.

Relay 31520 restores; closes motor magnet 31550 by way of 31522, 31532, and 31502; and 55 opens relay 31530 at 31523.

Motor magnet 31550 operates without effect at this time.

Relay 31530 restores; opens motor magnet 31550 at 31532; and closes relay 31510 by way 60 of 31532 and 31502.

Motor magnet 31550 restores and advances wipers 31900, 31901 and 31902 one step.

The foregoing cycle is repeated, and wipers 31900, 31901 and 31902 are advanced slowly over 65 their respective bank contacts. When wiper 31901 reaches the next to the last contact in its bank, ground is placed on "ground off" conductor 31001 by way of 31531, 31901 and 31502. When wiper 31901 reaches the last contact in 70 its bank, the circuit of relay 31540 is closed by way of 31901 and 31502.

Relay 31540 operates and removes ground from "ground on" conductor 31002 at 31541.

The removal of ground from start conductor 75

31003 will cause the deenergization of relay 31500, whereupon a restoring circuit is closed for motor magnet 31550 by way of 31551, multipled bank contacts, wiper 31902 and 31502. Motor magnet 5 31550 now operates as a buzzer to advance wiper 31900, 31901, and 31902 to their normal position.

J2d—Unanswered call released by timing equipment

10 We will next assume that a local subscriber has rung in, that an idle link has found the calling line, and that the tandem exchange trunk switch has associated itself with the calling link; but that for some reason or other the call is not answered by the control operator within a predetermined interval of time.

Following the operation of relay 26510 (described under item J1b), the next pulse of ground on "time in" conductor 31000 will close relay 20 25540 by way of 25007, 26551, 26511, 25006, and 25541.

25 Relay 25540 operates; locks at 25541; grounds time start conductor 31003 at 25542; replaces ground at 25545 by that on "ground in" conductor 31002; and extends "ground off" conductor 31001 by way of 25543 and 25005 to relay 27510, thereby placing the release of the link under the control of timing equipment TE, Fig. 31, which 30 will release the connection unless the control center operator answers within a predetermined length of time. After an interval of time, an impulse of ground on "ground off" conductor 31001 will close relay 27510 by way of 25005 and 25543.

35 Relay 27510 operates; closes relay 18550 by way of 18507, 18579, 17009, 17525, 17547, 15014, relay 18560, 15006, impedance 16510, 15007, 15589-1, 15005, 16587, 15004, 15589-2, 15543, 15000, 15905, 14004, 14565, 14543, 14001, 30577, 30557, 30904, 40 30006, winding 1 of repeating coil R-27, 27513 and 27900; and closes relay 36540 at 27512.

Relay 26530 operates and closes relay 26520 at 26533.

45 Relay 27510 restores at the end of the pulse of ground on conductor 31001, and opens relay 26530 at 27512.

Relay 26530 restores; opens slow to release relay 26520 at 26533; and opens relays 26500 and 30570 at 26532.

50 Relay 26520 restores after a delay sufficient to release relays 26500 and 30570.

After a further interval of time ground will be removed from "ground on" conductor 31002, thus opening the circuit of relay 25530.

55 Relay 25530 restores; opens relay 24510 at 25533; and opens relay 26510 at 25534.

Relays 24510 and 26510 restore without effect at this time and the link is again at normal.

Relay 18550 operates; shunts contact 18579 at 60 18583; opens the battery feed from 19903 at 18581; and closes relay 18580 by way of 18008 and 18582.

Relay 18580 operates and closes relay 18570 at 65 18582.

Relay 18570 operates and prepares the circuit of relay 18550 at 18572.

70 Relay 18550 restores, following the deenergization of relay 27510, and closes relay 18550 by way of 17027, 17514, 17026, 18572, 18010, 19542 and 19552.

75 Relay 18550 operates and closes relay 16570 by way of 18016 and 18554.

Relay 16570 operates and opens the circuit of 75 relays 15578 and 14580 at 18573.

Relay 14580 restores and causes the trunk relay group to return to normal.

Relay 15570 restores and causes the remote control group CG-1 to return to normal.

For control center functioning in connection with stored or blocked calls see item L4b.

J2e—Ringing converter RC-2

When ground is placed on motor start conductor 31009, relays 31590 and 31600 are closed. 10 Relay 31600 operates with large amplitude for starting, and prepares to short circuit itself at 31601.

Relay 31590 operates after a slight delay; removes the shunt from around resistor 31810 at 15 31592; short circuits relay 31600 at 31592; and closes relay 31580 at 31591.

Relay 31580 operates; removes the shunt circuit from its upper winding at 31581; and connects primary windings 31912 and 31913 of the transformer to the contacts 31601 or relay 31600 at 20 31781 and 31583.

Relay 31600 restores because of the short circuit; removes the short circuit from its winding, and, because of the momentum of the weighted 25 reed, closes winding 31912 by way of 31583, 31905, and 31601.

Relay 31600 now operates with normal amplitude (because now in series with resistance 31910); short circuits its own winding; and closes 30 winding 31916 by way of 31581, 31909 and 31601.

Relay 31600 restores; removes its own short circuit and closes winding 31912 as above described, and continues to operate and release until its circuit is opened by ground being removed from motor start conductor 31009. 35

The relation of the windings of the transformer is such that the alternate closure of 31912 and 31916 will induce an alternating current in secondary windings 31991 and 31915 which is suitable for the operation of telephone ringers. 40

J2f—Tone relays TRC-2

When ground is placed on motor start conductor 31009, the lower winding of relay 31570 is closed, as is relay 31560. Relay 31570 operates 45 and closes its upper winding, which is in opposition to its operating winding. The relay therefore restores and the cycle repeats so long as ground is maintained on conductor 31009. The rapid operation of relay 31570 places a characteristic tone on conductors 31007 and 31008.

Relay 31560 operates in series with resistance 31921 and short circuits itself at 31562. Relay 31560 restores, because of the short circuit, and the cycle repeats so long as ground is maintained 55 on conductor 31009. The slow operation of relay 31560 serves to impress the tone generated by relay 31570 upon conductor 31006 at 31561, thereby producing a typical busy tone.

J2g—All links busy

When all local links are busy, due to the operation of the equivalent of relay 26510 (or 26530) in each link, ground is removed from conductor 30001, so as to prevent the operation of TS-3 on 65 a call to the sub-tandem exchange from the control center.

ITEM K

CIRCUIT DESCRIPTION—SATELLITE EXCHANGE

K1—Local subscriber initiates call

70

K1a—Marking the calling line (no relays operated)

75

With reference to Fig. 32, when the subscriber initiates a call by turning his magneto at tele-

phone T3, assumed to have the number 9111, generator passes over the line conductors and energizes line relay 32500.

- Relay 32500 locks its upper winding by way of 32501 and 32513; opens its operating winding at 32502; places marking potential on the associated bank contact accessible to wiper 32903 by way of 32504, 32014, 34502, 32012, and 32907; and closes motor magnet 32520 by way of 32506, 32013, 33512, 10 33524, 32014, 34502, 32012, and 32907, in the event that the single connector C-3 is at normal.

K1b—Link (if available) finds calling line (Relay operated 32500)

- 15 Motor magnet 32520 operates; and closes relay 33510 by way of 32010 and 32521.

Relay 33510 operates; and opens motor magnet 32520 at 33511.

- 20 Motor magnet 32520 restores; advances wipers 32900 to 32903, inclusive, one step; and opens relay 33510 at 32521.

Relay 33510 restores; and recloses motor magnet 32520 at 33512. The foregoing operation continues, and the associated wipers are advanced step by step until wiper 32903 encounters the marked bank contact, at which time a circuit is closed by way of 32907, 32012, 34502, 32014, 32504, bank contact and wiper 32903, 32009, relays 33520 and 33510.

- 25 30 Relay 33510 already operated; will remain operated over the above traced circuit, and the rotation of the wipers will cease.

Relay 33520 operates; locks its wiper winding by way of 33521 and 33541; closes relay 34580 by 35 way of 34573, 33005, 33523, 33521 and 33541; closes relay 32510 by way of 32902, 32007 and 33527; and opens the circuit of motor magnet 32520 at 33524.

Relay 32510 operates; opens the holding circuit of relay 32500 at 32513; and the operating circuit 40 of the same relay at 32511.

Relay 32500 restores; opens the operating circuit of relay 33520 and the holding circuit of relay 33510 at 32504.

Relay 33510 restores, but without effect at this 45 time.

K1c—Extending call to sub-tandem exchange (Relays operated 32510 and 33520)

- 50 Relay 34580 operates; places battery on trunk conductor 24005 by way of 34581 and 34901; and closes relay 34510 at 34582.

Relay 34570 operates; locks by way of 34573, 33005, 33523, 33521 and 33541; opens relay 34580 at 34573; closes trunk conductor 24006 through to repeating coil R-33 at 34575, and disconnects the charging lead from conductor 24008 at 34575.

Relay 34580 restores; and closes trunk conductor 24005 through to repeating coil R-33 at 34582.

The splash of negative battery impressed upon conductor 24005 by relay 34580 passes by way of 24533 and 24523 to relay 24520.

65 Relay 24520 operates; locks its lower winding by way of 24522 and 24532; grounds start conductor 24013 at 24528; marks the calling line in the finder switch banks by connecting cut-off relay 24530 by way of 24524 to conductor 24012; grounds guard conductor 24007 at 24526 to make the trunk to the satellite exchange busy in the banks of connector C-2; and closes relay 24540 at 24521.

70 Relay 24540 operates and disconnects the 75 charging lead from conductor 24006 and 24542.

K1d—Idle finder connector link finds calling line (Relays operated 32510, 33520, 34570, 24520 and 24540)

This operation takes place as described under item J1b, with the exception that finder F-2 associates itself with LC-5 instead of LC-3.

Relay 25530, upon energizing, closes relay 24530 by way of 24524, 24012, 25502 and 25533.

Relay 24530 operates; opens the energizing circuit of relay 24520 at 24533; maintains relay 24540 at 24531; opens the holding circuit of relay 24520 at 24532; and locks to its operating circuit at 24534.

Relay 24520 restores; but without effect at this time. 15

K1e—Idle tandem exchange trunk switch finds calling line (Relays operated 24530, 24540, 25530 and 26510)

This operation takes place as described under item J1c, and need not be again discussed. 20

K1f—Idle remote control group trunk switch finds calling sub-tandem exchange trunk

This operation takes place as described under item J1d, and need not be again discussed. 25

K1g—Idle control center trunk switch finds calling remote control group

This operation takes place as described under item J1e, and need not be again discussed. 30

K1h—Signalling the control center operator

This operation takes place as described under item J1f, and need not be again discussed. 35

K1i—Control center operator answers

This operation takes place as described under item J1g, and need not be again discussed, except to mention that relay 26520, upon operating, closes battery through resistance 25900 by way of 26016, 28566 and 28564, 26015 and 26014, 26526 and 26524, 26518-2 and 26518-1, 25011 and 25010, 25905 and 25904, 24008 and 24009, windings 3 and 1 of repeating coil R-24, 24806 45 and 24005, 34575 and 34581, 33000 and 33003, windings 4 and 2 of repeating coil R-33, 33001 and 33002, upper and lower windings of differential relay 34520 to relay 34510.

Relay 34510 operates and closes relay 34500 by 50 way of 34512, 32012 and 32907.

Relay 34500 operates; closes the upper winding of relay 33500 by way of 33525, 33004 and 34503; and closes a holding circuit to relay 34570 at 34501. 55

Relay 33560 operates and closes relay 33580 at 33562. Relay 33580 will not operate until the vibrating spring 33562 has come to rest.

Relay 33500 operates and closes its lower winding at 33501. As this is a differential relay, 60 an interrupter action is established at 33501 which will cause paystation tone to be impressed on conductor 32008.

K1j—Forwarding paystation tone 65

In the event that the calling line is a paystation, paystation tone will be impressed on trunk conductor 24006 by way of 34575, 33003, 33581, 33903, 32009, 32903, 32504 and 32908.

Relay 33580 operates after a time, and removes the paystation tone at 33581. 70

It will be noted that the operator cannot cause the splash of paystation tone to be repeated, as she could in connection with a call from the tandem exchange, as explained under item H2f. 75

The transmission circuit is now complete between the calling subscriber and the control center. For the purpose of the present explanation it will be assumed that the operator completes the call to the desired party via the control center exchange equipment.

K1k—Release of the connection (Relays operated 14560, 14570, 15570, 15580, 15590, 18560, 18570, 18580, 19530, 19540, 19570, 19580, 20520, 20530, 20580, 21520, 24530, 24540, 25530, 26500, 26510, 26520, 26530, 26540, 26550, 26570, 30560, 30570, 32510, 33500, 33520, 33560, 33580, 34500, 34510, and 34570)

15 When the conversation has been completed, the calling subscriber may ring off and signal the distant operator. Generator on the calling line will pass to the sub-tandem exchange and operate relay 27550, which will set in motion the operations described under item J14. It may be mentioned further, that the restoration of relay 26520 will remove battery through 25900 from trunk conductors 24005 and 24006, thereby opening the circuit of relay 34510.

25 Relay 34510 restores; opens relay 34500 at 34512; closes motor magnet 34530 of connector C—3 (prior to the deenergization of slow to release relay 34500), by way of 32015, 33564, 33009, 34512 and 34502; and closes relay 33570 by way of 33566, 33564, 33009, 34512 and 34502.

Relay 33570 operates; short circuits its upper winding at 33571 to make the relay slow to release; and closes relay 33540 at 33573.

Relay 33540 operates and opens relay 32510 at 33543.

Relay 32510 restores and reconnects line relay 32500 across the line at 32511.

Relay 34500 restores; opens relays 33500 and 33560 at 34503; opens relays 34570 and 33520 at 40 34501; and opens motor magnet 32530 and relay 33570 at 34502.

Relay 33570 restores and opens relay 33540 at 33573.

Motor magnet 32530 restores and advances 45 wipers 32804 to 32807, inclusive, one step, thereby closing a restoring circuit by way of wiper 32907 and the multiple bank contacts accessible thereto, 32811, 33010, 33568, 32018, 32531. A branch of this circuit passes to relay 33570 by way of 33566.

50 Motor magnet 32530 operates; opens its own circuit at 32531, and continues to act as a buzzer to advance the wipers of connector C—3 until wiper 32907 again engages the bank contact associated with conductor 32012.

55 Relay 33570 operates and closes relay 33540 at 33573.

Relay 33540 operates and opens the circuit to wiper 32906 at 33543.

60 Relay 33570 restores, shortly after the connector C—3 regains its normal position, and opens relay 33540 at 33573.

Relay 33540 restores, but without effect at this time.

The equipment is now at normal.

65 **ITEM L**

CIRCUIT DESCRIPTION—CONTROL CENTER

L1—Control center calls tandem exchange station

70 **L1a—Selecting idle trunk to tandem exchange**

The operator selects an idle trunk to the tandem exchange by means of a tip test with the calling plug of her cord circuit (not shown). It will be assumed that the trunk so selected is that terminating in the equipment shown in Fig. 23.

When the operator plugs into jack J23, the circuit of relay 23570 is closed by way of the sleeve of the jack.

Relay 23570 operates; disconnects relay 23560 from across the trunk at 23571; maintains relay 5 23510 at 23572, removes relay 23500 from across the trunk at 23574; connects relay 23540 in series with windings 1 and 3 of the repeating coil R—23 across the trunk at 23574; and closes relay 23550 at 23576. 10

Relay 23550 operates, but without effect at this time.

Polarized relay 23540 does not operate at this time because the current flow on the trunk is in such a direction as to maintain the relay in its 15 normal position. Relay 23580 also remains at normal, and maintains battery and ground on the tip and ring of the jack in order to keep the supervisory lamp in the cord circuit (not shown) lighted. 20

L1b—Seizing an idle control relay group (Relays operated 23550 and 23570)

The bridging of relay 23540 across trunk conductors 21000 and 21001, closes the circuit of 25 relays 21550 and 21560 in series, by way of 21525 and 21527.

Relay 21550 operates; switches the chain circuit through to the next idle control center trunk switch at 21552, in order to make TS—1 busy to 30 calls from the control relay groups; and removes ground from ATB—1 conductor 21006 at 21554.

Relay 21560 operates; closes relay 21540 by way of 21562, 21005, and 22532; and closes motor magnet 21500 by way of 21512, 21522, 21532, 21564 35 and ATB—2 conductor 15031; which is grounded (as at 15594) in the event that there are no more idle remote control groups at this time.

Motor magnet 21500 operates and closes relay 21510 at 21501. 40

Relay 21510 operates and opens motor magnet 21500 at 21512.

Motor magnet 21500 restores; advances wipers 21900 to 21904, inclusive, one step; and opens relay 21510 at 21501. 45

Relay 21510 and motor magnet 21500 continue to operate as above described, and advance the associated wipers in search of an idle control relay group.

Relay 21540 operates after a delay sufficient to 50 allow the wipers to advance at least one step, and connects relay 21510 in series with relay 21520 by way of 21905, 21531, and 21541 to test wiper 21902, to provide a means for stopping TS—1 on an idle control relay group. The feature just described insures that successive calls through this switch will be routed to different control relay groups. 55

When wiper 21902 reaches the first idle remote control group, assumed to be RCG—1, relay 21510 will be held operated by way of relay 21520, 21905, 21531, 21541, 21902, 19008, 19581, 19577, 19010, 20543, 15017, and 15527, the rotation of TS—1 will therefore cease. 60

Relay 21520 operates; locks its upper winding by way of 21521, 21904, 17013, 17523, 16008, 16577, 16563, 16009, and relay 19580; opens relays 21550 and 21560 at 21525 and 21527, respectively; and at the same contacts extends the trunk to relays 19530, 19540, and 19560; maintains the switching of the chain circuit at 21524; and maintains the removal of ground from the ATB—1 conductor 21006 at 21526. 70

Relay 21550 restores, but without effect at this time. 75

Relay 21560 restores and opens relay 21540 at 21562.

Relay 21540 restores and opens the holding circuit of relay 21510 and the operating circuit of 5 relay 21520 at 21541.

Relay 21510 restores, but without effect at this time.

Relay 19580 operates; removes ground from conductor 19008 at 19581 to make RCG—I busy 10 to calls from other control center trunk switches; closes relay 20520 by way of 19013, 19588, and 19571; closes relay 15590 by way of 15023 and 19584; grounds motor start conductor 7006 by way of 19005 and 19587; and connects dial tone 15 conductor 6005 to trunk conductor 19007 by way of 19004, 19583, 18006 and 18563.

Relay 20520 operates; but without effect at this time.

Relay 15590 operates; removes ground from 20 the ATB—2 conductor 15031 at 15594; and switches chain circuit conductor 14008 to the next idle control relay group at 15592, to make RCG—I busy to calls from the sub-tandem exchange.

25 Relay 19540 operates over the trunk loop, and closes relay 18580 by way of 18008, 19542 and 19552.

Relay 18580 operates and places ground on hold conductor 13011 by way of 13547, 13019, 30 18583, 15020, and impedance 20510, to make RCG—I busy to calls from the tandem exchange; and closes relay 18570 at 18582.

Relay 18570 operates; closes relay 20530 by way of 18011, 18574, 17029 and 19512; prevents 35 the placing of ring-back tone on the connection at 18579—I; and connects battery to pulse conductor 17003 of incoming connector IC—I (IC—I being individual to RCG—I) by way of 19903, 19551, 17010, 18577, 17011, 19541, 17012, and 40 17547 to place IC—I in condition to be operated by the dial at the control center.

Relay 19530 operates, but without effect at this time.

45 *L1c—Operator dials called number* (Relays operated 15590, 18570, 18580, 19530, 19540, 18580, 20520, 20530, 21520, 23550 and 23570)

The tandem exchange equipment returns dial tone to the control center, following the operation of relay 19580, as an indication that the connection has been extended to an incoming connector, and that the operator may now dial the called number.

The operator next actuates the dial key 55 K—23—3, which is without effect at this time.

We will now assume that the operator dials the number 11, assigned to telephone T—I, Fig. 2. When the dial is moved off normal, a circuit is closed to slow-to-release relay 23520 by way of 60 23552, key K—23—3 and dial shunt springs 23908.

Relay 23520 operates; extends its energizing circuit to relay 23510 at 23522, and bridges condenser 23900 across the trunk at 23521.

Relay 23510 operates and at make-before-break springs 23513 and 23515 bridges dial impulse springs 23907 across trunk conductors 2100 and 21001 in place of relay 23540.

As the dial returns to normal, impulse springs 23907 open the loop to the tandem office in accordance with the digit dialled, thereby causing the operation of relays 19530 and 19540. The circuit of relays 23510 and 23520 is opened when the dial reaches normal position.

Relay 23510 restores and again bridges relay 75 23540 across the trunk at 23513 and 23515.

Relay 23520 restores, after a slight delay, and removes condensers 23900 from across the trunk at 23521. The click in the operator's head-set is reduced because of the fact that condenser 23900 is maintained across the trunk for an interval of 5 time following the restoration of relay 24510.

L1d—Repeating impulses to the associated connector (Relays operated 15590, 18570, 18580, 19530, 19540, 19580, 20520, 20530, 21520, 23550 and 23570) 10

Relay 19530 responds to the impulses from the operator's dial, but without effect, as slow-to-operate relay 18540 will not energize on momentary closure of its circuit.

Relay 19540 responds to the first series of impulses from the operator's dial; at each restoration a circuit is closed by way of 19552, 19542, 18010, 18572, 17026, 17564, 17556, and 17024 to operating magnet 18510 of the register switch; at 20 each restoration a further circuit is closed by way of 19552, 19542, 18010, 18572, 17026, 17524 and 17027 to relay 18550; and at each restoration pulsing conductor 17003 is opened at 19541.

Operating magnet 18510 responds to the pulses 25 and upon energization advances the wipers 18901 and 18902 step by step, to the dialled bank contact.

Off-normal springs 18903 operates at the first step, but without effect at this time.

Off-normal springs 18900 operate at the first step and close relay 18560 by way of 17015, 17563, 17575, 17013, 18900, 15023 and 19584.

Relay 18560 operates; locks to its operating circuit at 18561, and removes dial tone from the 35 trunk at 18563.

Relay 18550 operates and remains operated throughout the first series of impulses; but without effect at this time.

Relay 18550 restores, shortly after the termination of the first series of impulses, and closes relay 17550 by way of 17543, 17019, multiple bank contacts, wiper 18901 standing on the first bank contact (the first digit of numbers in the tandem exchange are either 1, 2, 3, 4, 5, 6, 7 or 8), 40 17020, 17564, 17021, 18551, 18581, 15023 and 19584.

Relay 17550 operates; locks under control of relay 18580 by way of 17551, 17541, 15023 and 19584; prevents further operation of register operating magnet 18510 at 17556; and closes relay 18580 by way of 16014, 17512, 17522 and 17552.

Relay 16580 operates and at 16585 and 16587 connects talking conductors 16002 and 16003 from incoming connector IC—I through to windings 1 45 and 3 of repeating coil R—19.

Relay 19540 responds to the second series of impulses from the operator's dial; and at each restoration opens pulsing conductor 17003 at 19541.

L1e—Dialling the associated conductor (Relays operated 15590, 16580, 17550, 18560, 18570, 18580, 19530, 19540, 19580, 20520, 20530, 21520, 23550 and 23570) 50

When relay 18570 connected battery to pulse conductor 17003 at 18577 a circuit was closed to relay 36530.

Relay 36530 operates; closes slow-to-release relay 36540 at 36532; and closes relay 36550 by 70 way of 36902 and 36532.

Relay 36540 operates and opens the circuit to release magnet 36550 at 36542.

Relay 36550 operates; prepares the circuit for its lower winding and vertical magnet 36570 at 75

36562; and closes relay 37580 by way of 26805, 36584 and 36544.

5 Relay 36530 follows the first series of pulses received over conductor 17003, and at each restoration closes vertical magnet 36570 in parallel with slow-to-release relay 36580 by way of 36562, 36542 and 36532.

10 Vertical magnet 36570 responds to the pulses; and upon energization, lifts wipers 37804 to 37807, inclusive, step by step, to the desired level of bank contacts.

Vertical off-normal springs 36902 operate on the first vertical step and open the operating circuit of relay 36580.

15 Relay 37580 operates and locks by way of 37582, 36801, 36584, and 36544.

Relay 36580 restores shortly after the end of the first series of impulses, and transfers the operating circuit to rotary magnet 37580 to 26802.

20 Relay 36530 follows the second series of impulses received over conductor 17003, and at each restoration closes rotary magnet 37580 in parallel with relay 37580 by way of 36582, 36542, 36562, 36800, 37532, 37574, and 27584.

25 Rotary magnet 37580 responds to the pulses and, upon energization, rotates wipers 37804 to 37807, inclusive, step by step, to the desired bank contact in the previously selected level. For the purpose of the present explanation it will be assumed that bank contacts 37803 to 37810, inclusive, are multiplied with bank contacts 4913 to 4915, inclusive, thereby affording access to telephone T-1, Fig. 1.

30 Relay 37580 operates and closes relay 37540 at 37582.

35 Relay 37540 operates and prepares the busy test circuit at 37541.

L1f—Dialed line busy (Relays operated 15590, 16580, 17550, 18580, 18570, 18580, 19530, 19540, 19580, 20520, 20530, 21520, 23550, 23570, 36530, 36540, 37500, 37540, and 37580).

40 In the event that the called line is busy, test wiper 37806 will encounter ground on bank contact 37910, thereby closing relay 37580 by way of 37573 and 37541.

45 Relay 37530 operates; prepares its locking circuit at 37533, and prepares the busy tone circuit at 37535.

50 Relay 37580 restores, shortly after the end of the second series of impulses, and opens relay 37540 at 37582.

55 Relay 37540 restores; completes the locking circuit of relay 37530 by way of 37573, 37541, 37533, 37521, 39504, and 36541; and places busy tone on the trunk by way of 6014, 37543, 37535, 37582, 37523, 35903, and winding 4 of repeating coil R-5.

60 The control operator may offer the call to the busy line by operating "ring and offer" key K-23-2 momentarily.

65 The application of ground, by way of K-23-2, 23551, 23531, relay 23540, winding 1 of repeating coil R-23, and 23515 to trunk conductor 21001, unbalances differential relay 19560 by shunting out its upper winding.

Relay 19560 operates and closes relay 19510 by way of 19582, 19542, and 19552.

70 Relay 19510 operates and closes relay 37520 by way of 37522, 37514, 37536, 37544, 35909, 35544, 35906, 19000 and 19515.

75 Relay 37520 operates; locks by way of 37522, 37571, 35904, and 36541; short circuits the lower winding of relay 37530 at 37524, thus rendering relay 37530 slow to release; transfers the holding

circuit of relay 37530 to test wiper 37806 by way of 37521, 37533, 37541 and 37573; disconnects busy tone and connects the operator to the calling line by way of 37523 and 37527, and condenser 37903 and 37901; and places tick-tone on the called line by way of 6006, 37800, 37526, and condenser 37901 to inform the parties on the busy connection that the operator has cut in on their call.

The operator can thus offer the call to the busy line. If the called party desires to accept the call 10 being offered, both parties must release their present connection in order to permit the connector to seize the called line and ring the called station.

When the parties on the busy line release their 15 connection, ground is removed from bank contact 37910, thus opening the circuit of relay 37530.

Relay 37530 restores after an interval, and the 20 called line will be seized in the same manner as when an idle line has been called. (See item L1g.)

L1g—Seizure of idle line (Relays operated 15590, 16580, 17550, 18580, 18570, 18580, 19530, 19540, 19580, 20520, 20530, 21520, 23550, 23570, 36530, 36540, and 37500).

If the called line is idle, a circuit will be closed (following the restoration of relay 37540) from relay 2520 by way of 2514, 2005, 4915, 37810, 30 37906, 37541, relay 37570, 37531, 35904 to ground at 36541.

Relay 37570 operates; locks its lower winding by way of 37572, 35906, and 36544; grounds bank contact 37906 by way of 37906 and 37575 to busy 35 the called line; and prepares the circuit for ringing the called station at 35779 and 35779-2.

L1h—Operator starts automatic ringing on called line (Relays operated 15590, 16580, 17550, 18560, 18570, 18580, 19530, 19540, 19580, 20520, 20530, 21520, 23550, 23570, 36530, 36540, 37500 and 37570).

When the operator desires to start ringing the 45 called station, she momentarily operates "ring and offer" key K-23-2 twice. Relay 19560 will function to close relay 19510, as explained under item L1f.

At each momentary energization of relay 19510, the circuit of relay 36580 is closed by way of 50 35907, 35514, 35908, 37536, 37544, 35909, 35544, 35905, 19000, and 19515.

Relay 36580 operates and closes both windings of differential relay 36590 by way of 36592 and 36582. Relay 36590 has two balanced windings 55 differentially connected in parallel, one on the heel end of the core and the other on the armature end.

Relay 36580 restores at the end of the pulse and opens the circuit to differential relay 36590 at 60 36582.

Relay 36580 operates due to the difference in die-away time of the two magnetic fields, which will permit the last surviving lines of force to act upon armature 36591 and cause it to establish a 65 locking circuit by way of 36541, 36591, and the upper and lower windings of relay 36590 in series aiding; and opens its operating circuit at 36592; and opens contact 36594, thus preparing for the eventual deenergization of relay 37500.

Relay 36580 again operates momentarily, and opens the locking circuit of relay 37500 at 36584.

Relay 37500 restores; connects interrupted generator to one side of the calling line by way of 70 70807, 37501, 37570, and wiper 37805; connects 75

- its upper winding to the other side of the called line by way of 37503, 37579—2 and wiper 37904. At this time interrupted generator is passed to the operator as a ring-back indication by way of 5 37579—1, 37902 and 37523. The interrupted generator flows over the line, through the station condenser and ringer, and back through relay 37500. The ringer operates at this time, but relay 37500 will not respond to alternating current.
- 10 *L1i—Called party answers* (Relays operated 15590, 16580, 17550, 18560, 18570, 18580, 19530, 19540, 19580, 20520, 20530, 21520, 23550, 23570, 36530, 36540, 36590 and 37570)
- 15 When the called party answers, a direct current circuit is closed for the upper winding of relay 37500 at the called telephone. Relay 37500 operates; locks by way of 37502, 36001, 36584 and 36544; removes interrupted generator and itself from the called line at 37501 and 37503; and extends the circuit of battery feed relay 35530 to the called line by way of 35513 and 35515, windings 4 and 2 of repeating coil R—35, 35903 and 35900, 37501, and 37503, 37579 and 37579—2, 37905 and 37904, and 37909 and 37908.
- 20 Relay 35530 operates and closes relay 35520 and 35532.
- 25 Relay 35520 operates and closes relay 17530 by way of 17553, 17004 and 35521.
- 30 Relay 17530 operates and closes relay 19570 by way of 15029, 15562, 15028, 17534, 16015, 16562 and 16544.
- 35 Relay 19570 operates and reverses battery to the control center at 19573 and 19575.
- 40 Relay 23540 operates because of the reversed current flow; and closes relay 23580 at 23541.
- 45 Relay 23580 operates; and removes battery and ground from the cord circuit (not shown) at 23583 and 23585, thus giving the operator answering supervision.
- A transmission circuit between the operator and the tandem exchange subscriber is now complete through repeating coils R—35, R—19, and R—23.
- 50 *L1j—Release of the connection* (Relays operated 15590, 16580, 17530, 17550, 18560, 18570, 18580, 19530, 19540, 19570, 19580, 20520, 20530, 21520, 23540, 23550, 23570, 23580, 35520, 35530, 36530, 36540, 36590, 37500 and 37570)
- 55 When the tandem exchange subscriber hangs up his receiver, the circuit of relay 35530 will be opened at the telephone.
- 60 Relay 35530 restores and opens relay 35520 at 35532.
- 65 Relay 35520 restores and opens relay 17530 at 35521.
- 70 Relay 17530 restores and opens relay 19570 at 17534.
- 75 Relay 19570 restores and reverses the battery to the control center at 19573 and 19575.
- 80 Relay 23540 restores due to the reversal of current flow in the trunk, and opens relay 23580 at 23541.
- 85 Relay 23580 restores and replaces battery and ground on the cord circuit (not shown) at 23583 and 23585, thereby giving the operator disconnect supervision.
- 90 The operator now withdraws the calling plug (not shown) from jack J—23, thereby opening the circuit of relay 23570.
- 95 Relay 23570 restores; removes relay 23540 from across the trunk at 23574; reconnects relay 23560 across the trunk at 23571; and reconnects high resistance relay 23600 across the trunk at 23574. The resulting decrease in current flow over the trunk will cause the deenergization of relays 19530 and 19540.
- 100 Relay 19530 restores, but without effect at this time.
- 105 Relay 19540 restores; opens relay 18580 at 18542; closes relay 18550 by way of 18552, 18542, 18010, 18572, 17026, 17524 and 17027; and opens relay 36530 at 19541.
- 110 Relay 18580 restores; opens relay 18570 at 18582; and removes ground from conductor 13011 at 18583, thus making RCG—1 again available to calls from the local connectors.
- 115 Relay 18550 operates momentarily and closes relay 16570 by way of 16016 and 18554.
- 120 Relay 18570 restores; closes release magnet 18520 of the register by way of 18903, 18572, 18010, 19542 and 19552; opens relay 20503 at 18574; and opens relay 18550 at 18572.
- 125 Relay 16570 operates momentarily and opens the circuit of relays 19580 and 21520 at 16571.
- 130 Relay 19580 restores and opens relays 18580 and 18560 at 19584.
- 135 Release magnet 18520 operates to restore wipers 18901 and 18902 to their normal position, its own circuit being opened at off-normal springs 18903. The return of wiper 18901 to normal opens the circuit of relay 17550.
- 140 Relay 17550 restores and opens relay 18580 at 17552.
- 145 Relay 36530 restores and opens relay 36540 at 36532.
- 150 Relay 36540 restores; opens relay 36590 at 36541; opens relays 37500 and 37570 at 36544; and closes release magnet 36550 by way of 36903, 36542 and 36532.
- 155 Release magnet 36550 operates to restore wipers 37904 to 37907, inclusive, to normal position its own circuit being opened by off-normal springs 36903.
- 160 Relay 20530 restores and opens relay 20520 at 20531.
- 165 Relays 36590, 37502, 37570, 15590, 16580, 18560, 20520 and 21520 restore; but without effect at this time.
- 170 The equipment is now in position to receive other calls.
- 175 *L2—Control center calls station in sub-tandem exchange D*
- 180 *L2a—Selecting idle trunk to the tandem exchange*
- 185 This operation takes place as described under item L1a, and need not be again described.
- 190 *L2b—Seizing an idle control relay group*
- 195 This operation takes place as described under item L1b, and need not be again described.
- 200 *L2c—Operator dials called number*
- 205 For the purpose of explanation, it will be assumed that there are at least two sub-tandem exchanges in the network. The first digit dialled by the operator will be "9" thus indicating to the control relay group and its associated incoming connector that the call is being directed to one of the sub-tandem exchanges. The second digit dialed will select the particular sub-tandem exchange desired, after which the incoming connector will automatically seize the first idle trunk line in the previously selected group.
- 210 The operation described under item L1c is applicable here.

L2d—Repeating impulses to the associated connector

Relay 18540 responds to the first series of impulses from the operator's dial; at each restoration a circuit is closed by way of 18552, 18542, 18810, 18572, 17826, 17544, 17868 and 17824 to operating magnet 18510 of the register switch; at each restoration a circuit is closed by way of 18552, 18542, 18810, 18752, 17826, 17524 and 17827 to relay 18550; and at each restoration pulsing conductor 17803 is opened at 18541.

Operating magnet 18510 responds to the pulses and upon energization advances the wipers 18901 and 18902, step by step, to the ninth bank contact.

Off-normal springs 18903 operate at the first step; but without effect at this time.

Off-normal springs 18900 operate at the first step; and close relay 18560 by way of 17815, 17863, 17875, 17814, 18900, 15023 and 18534.

Relay 18560 operates, locks under control of relays 18568 by way of 18584 and 18561; and removes dial tone from the trunk at 18562.

Relay 18560 operates, and remains operated throughout the first series of impulses; but without effect at this time.

Relay 18560 restores, shortly after the first series of impulses; and closes relay 17560 by way of 17571, 17818, ninth bank contact and wiper 18901, 17828, 17564, 17821, 18551, 18551, 18523, and 18584.

Relay 17560 operates; locks by way of 17561, 17575, 17814, 18900, 15023, and 18584; prepares the circuit of relay 17570 at 17562; and closes release magnet 18520 by way of 17825, 17876 and 17566.

Release magnet 18520 operates to restore wipers 18901 and 18902 to their normal position.

The opening of off-normal springs 18900 removes a shunt from around relay 17570, thereupon the latter relay energizes in series with relay 17560 (already operated) by way of 17862, 17816, 18581, 15023 and 18584.

Relay 17570 operates and opens the circuit of release magnet 18520 at 17576.

Relay 18540, in responding to the second series of impulses, again operates relay 18550, actuates operating magnet 18510, and repeats impulses to the associated connector over pulse conductor 17803.

Relay 18550 restores shortly after the termination of the second series of impulses; and closes relay 17560 by way of 17543, multiplied bank contacts and wiper 18901, 17828, 17572, 17821, 18551, 18581, 15023 and 18584.

Relay 17560 operates; locks by way of 17561, 17541, 15023 and 18584; prevents further operation of operating magnet 18510 at 17566; and closes relay 16580 by way of 16014, 17512, 17522 and 17562.

Relay 16580 operates; and at 16585 and 16587 connects talking conductors 16002 and 16003 from incoming connector IC-1 to the windings 1 and 3 of repeating coil R-19.

L2e—Dialling the associated connector

This operation takes place as described under item L1e, but as the first digit dialled is "9", it follows that springs 35004 and 39005 will be operated when the shaft is raised to that level, thereby closing the circuit of relay 35510.

Relay 35510 operates and changes the circuit of IC-1 in such a manner that it will automatically seize the first idle trunk in the group selected by the second digit dialled.

For the purpose of explanation it will now be assumed that bank contacts 37908, 37909 and 37910 are connected to conductors 13000, 13001 and 13002, respectively, thereby becoming the terminus of the first trunk to the sub-tandem exchange D. It will further be assumed that bank contacts 37908, 37909 and 37910 are the first choice in the ninth level, and that four more trunks to exchange D occupy adjacent bank contacts. The remaining contacts in the level, sixth to tenth choice, inclusive, will be assumed to be trunked to a second sub-tandem exchange.

It becomes apparent, then, that the dialling of a first digit "9" will indicate to the incoming connector that the call is being directed to one of the sub-tandem exchanges, and that the dialling of the second digit, which must be either "1" to "6" in accordance with the previous assumption, indicates to the incoming connector the group of trunks within which it must seize the first idle trunk. In order that the connector may make such selection, bank contacts 37910 and 37911 are connected as indicated by the dotted conductor 37912. The same procedure is followed on each trunk in the group, except the last.

The second series of impulses will cause the line relay 36530 to operate rotary magnet 37580 and step wipers 37904 to 37907, inclusive, into engagement with the first trunk in the selected group.

L2f—Selecting idle trunk to sub-tandem exchange

If the first trunk in the selected group of trunks is busy, ground will be encountered on bank contact 37910 and on bank contact 37911 by virtue of conductor 37912. Prior to the restoration of relay 37560, a circuit is closed to relay 37530 by way of 37573, 37541, 37906 and 37910.

Relay 37530 operates and closes relay 37560 by way of 37581, 37534, 37542, 37566 restored, 37907, 37911, 37912 and 37910.

Relay 37560 operates, locks by way of 37581, 37562, 35904 and 36541; closes rotary magnet 37580 by way of 37574, 37566, 35906, and 36544; closes relay 37540 by way of 37552 restored, 37566, 35906 and 36544.

Rotary magnet 37580 operates; advances wipers 37904 to 37907, inclusive, one step; and opens relay 37560 at 37581.

Relay 37560 restores and opens rotary magnet 37580 and relay 37540 at 37580. If the second trunk in the previously selected group of trunks is busy, relay 37560 will again operate, and the above described interaction between relay 37560 and rotary magnet 37580 will continue until an idle trunk is found or the last trunk in the group is reached.

If all trunks in the selected group are busy, ground will be encountered by wiper 37906, but not by wiper 37907, due to the absence of the equivalent of conductor 37912. It follows then that relay 37560 will not again operate, that the rotation will cease, and that relay 37560 will shortly thereafter deenergize.

Relay 37540 restores; and at 37543 returns busy tone to the operator as an indication that all of the trunks to the desired tandem exchange are in use.

It will now be assumed that the trunk represented by bank contacts 37908 to 37911, inclusive, is idle. In this event relay 37540, upon restoring shortly after the completion of the second series of pulses, will close a circuit by way of 75

- relay 14540, 14562, 14532, 14522, 13018, 13517, 13002, 37910, 37906, 37541, relay 37570, 37531, 35904, and 36541.
- Relay 37570 operates; locks by way of 36572, 5 35906, and 36544, grounds bank contact 37910 by way of 37515 and 37906 to make this trunk busy to other calls; connects batter to the simplex of the trunk to the tandem exchange by way of 36900, 36531, differential relay 36520, 35901 and 10 35902, 35513, 35515, windings 4 and 2 of repeating coil R-35, 35900 and 35903, 37501 and 37503, 37579 and 37579-2, 37904 and 37905, 37908 and 37909, 13000 and 13001 and 14000 and 14001; and closes relay 17530 by way of 17533, 15 17004, 35511, 19001, 36515, 19002 and 37577.
- Relay 14540 operates; and clears trunk conductors 14000 and 14001 of attachments at 14541 and 14543.
- Relay 17530 operates; and closes relay 19570 by 20 way of 15029, 15562, 15028, 17534, 16015, 16562 and 16544.
- Relay 19570 operates; and reverses the battery over the trunk to the control center to darken the operator's supervisory lamp as described under item L1.
- L2g—Selecting idle finder-connector link*
- The application of battery to the simplex of trunk conductors 14000 and 14001 by relay 37570, 30 closes the circuit of relay 305000 by way of 30577.
- Relay 30500 operates; closes relay 30510 at 30502; and closes motor magnet 30600 by way of 30542, 30572, 30534, 30506, ATB conductor 30001, 35 to ground at an idle finder connector link, as for instance by way of 26518 and 26534.
- Relay 30510 operates; closes relay 30520 at 30511; and connects test wiper 30900 by way of 30512 and 30532 to relays 30540 and 30570.
- Relay 30520 operates; prepares its locking circuit at 30521; and extends dial tone to wiper 30902 by way of 30523 and 31007.
- Motor magnet 30600 operates; and closes relay 30540 at 30601.
- Relay 30540 operates; and opens motor magnet 30600 at 30542.
- Motor magnet 30600 restores; opens relay 30540 at 30601; and advances wipers 30900 to 30905, inclusive, one step. Relay 30540 and motor magnet 30600 continue to operate as above described, and advance the associated wipers in search of an idle finder connector link.
- When wiper 30900 reaches the first idle finder connector link, assumed to be FC-2, relay 30540 55 will be held operated by way of 29514, 29538, 29984, 26018, 26518-5, 26536, relay 26580, 30002, 30900, 30512, 30532 and relays 30540 and 30570, the rotation of TS-3 will therefore cease.
- Relay 26580 operates momentarily, as will be 60 apparent later, and closes relay 26550 at 26581.
- Relay 26550 operates; closes relay 26530 at 26554; and closes a circuit by way of 26554, 26003, relay 28550 and 28902.
- Relay 26530 operates; closes relay 26540 at 65 vibrating contact 26531; closes relay 26520 at 26533; and opens relays 26580, 30540 and the operating winding of relay 30570 at 26536.
- Relay 26520 operates, but without effect at this time.
- 70 Relay 26540 operates after a slight delay; but without effect at this time.
- Relay 28550 operates, but without effect at this time.
- Relay 30570 operates (prior to the operation 75 of relay 26530); locks its two windings in series by way of 30573, 30905; 30007, 27544, 26004, 26522 and relay 26500; closes the locking circuit of relay 30520 by way of 30521 and 30571; and extends trunk conductors 14000 and 14001 by way of 30575, 30577, 30555 and 30557, 30903 and 30904 5 to conductors 30005 and 30006; and opens relay 30500 at 30577.
- Dial tone, by way of conductor 31007, 30523, 30802, 30004, 28546, 26011, and 27904, is now impressed on trunk conductor 30006, and informs 10 the operator that she may dial the remaining digits.
- Relay 30500 restores and opens relay 30510 at 30502.
- Relay 30510 restores; opens the operating circuit of relay 30520 at 30511; and opens the circuit of relays 30540 and 26580 at 30512.
- Relay 26500 operates; places ground on motor start conductor 31009 at 26503; opens start conductor 30000 at 26501; and opens conductor 30003 20 at 26502.
- Negative battery on the simplex of trunk conductors 30005 and 30006 passes by way of windings 1 and 3 of repeating coil R-27, 27523, 27511 and 27513, upper and lower windings of differential relay 27500, conductor 26000, to ground through relay 26570.
- Relay 26570 operates; and prepares a holding circuit for slow-to-release relay 26550 at 26572, effective upon the restoration of relay 26580. 30
- Relay 26580 restores, but without effect at this time.
- Relay 30540 restores, but without effect at this time.
- L2h—Dialling connector at sub-tandem exchange*
- The operator, after receiving dial tone as an indication that the sub-tandem exchange switching equipment is in position to set up the connection, now dials the remaining digits of the 40 sub-tandem exchange subscriber's number.
- Relay 19540 responds to the series of impulses from the operator's dial and repeats same to relay 36530.
- Relay 36530 in turn repeats the pulses by removing battery from the simplex of sub-tandem exchange trunk at 36531.
- Relay 26570 responds to the impulses received over the simplex of the trunk, and at each de-energization closes motor magnet 29540 by way 50 of 29506, 28009, 28512, 28512, 26007, 26582, 26512 and 26581; closes relay 29520 by way of 26009, 26556, 26008, 19506, 28009, 28572, 28512, 26007, 26552, 26572 and 26581; and opens relay 26550 at 26571. 55
- Relay 26550 is slow to release and remains operated at this time.
- Relay 29520 operates; short circuits its upper winding at 29521, thus rendering itself slow to release in order that it may remain operated 60 throughout the dialling period; and closes relay 29510 at 29522.
- Relay 29510 operates; prepares the circuit of busy relay 29500 at 29511; removes ground from wiper 29904 at 29514; and closes relay 28540 by 65 way of 28002, 29513, 26002, 26521, 25004, and 25546.
- Motor magnet 29540 responds to the impulses and at each deenergization advances wipers 29900 to 29905, inclusive, step-by-step until they 70 reach the bank contacts associated with the called line.
- Relay 28540 operates; locks to its operating circuit at 28543; and removes dial tone from the trunk at 28546. 75

L2i—Dialed line busy

Assume now that the call is for telephone T—2, and that this telephone is busy on another connection. Ground therefore will be present on conductor 24002 and will complete the circuit of relay 29508 by way of 29511 and 29902.

Relay 29508 operates; locks by way of 29511 (after relays 29520 and 29510 restore), 29502, 26012, and 26534; and returns busy tone to the operator by way of 31006, 29508, 28010, 28514, 26011, 27504, and conductor 30006.

The operator cannot offer the call to the busy line, as she could to a tandem office subscriber. The operator now advises the calling party that the desired line is in use, and releases the connection as described below.

L2j—Seizure of idle line

Relay 28520 restores shortly after the last digit is dialled; and opens relay 29510 at 29522.

Relay 29510 restores; and closes relay 24510 by way of 24002, 29002, 28511, 28005, relay 28570, 28006, 29502, 26012, and 26534.

Relay 28570 operates; locks by way of 28511, 26002, 26521, 25004 and 25545; opens the circuit of rotary magnet 29540 at 28572; places ground on conductor 24002 by way of 29902, 28004 and 28575 to maintain relay 24510 operated; closes relay 29530 by way of 28003 and 28573; and extends the talking circuit to the called line by way of 28571 and 28579.

L2k—Operator rings called line

When the operator desires to ring the called station, she momentarily operates "ring and offer" key K—32—2 twice. Relay 19560 operates and closes relay 19510 as explained under item L1j. At each momentary energization of relay 19510 the circuit of relay 36500 is closed by way of 35901—1, 35514, 35908, 37536, 37544, 35909, 35544, 35905, 19006 and 19515.

Relay 36500 operates; unbalances differential relay 27500 by opening its lower winding 36503, and at the same point closes a circuit to keep relay 36520 in balance so that it will not operate; and closes both windings of differential relay 36510 by way of 36512 and 36502. Relay 36510 has two balanced windings differentially connected in parallel, one on the heel end of the core and the other on the armature-end.

Relay 36500 restores; again completes the simplex of the trunk at 36503; and opens the circuit to differential relay 36510 at 36502.

Relay 36510 operates; due to the difference in die-away time of the two magnetic fields, which will permit the last surviving lines of force to act upon armature 36511 and cause it to establish a locking circuit by way of 36511, 36511, and the upper and lower windings of relay 36500 in series; and opens its operating circuit at 36512.

Relay 36500 again operates momentarily; and operates the simplex of the trunk at 36503.

Relay 27500 operates as a result of the first unbalancing of the trunk; opens the circuit of relay 27500 at 27502; and closes relay 27500 at 27504.

Relay 27500 operates and closes relay 28510 by way of 28542, 28502, 27004, 27562, 26003, and 26534.

Relay 38510 operates; and prepares a locking circuit for itself by way of 28500, 28511, 26002, 26521, 25004, and 25545.

Relay 27500 restores when the trunk is again balanced; and opens the circuit of relay 27500 at 27504.

Relay 27500 restores and opens the circuit of relay 28510 at 27502.

Relay 28500 operates in series with the already operated relay 28510, over the locking circuit described above. Relay 27500 operates as a result of the second unbalancing of the trunk; and again closes relay 27500 at 27504.

Relay 27500 reoperates; and shunts down operated relay 28550 by way of 26554; 26003, 27562, 27004, and 28502.

Relay 28550 restores and closes relay 28530 by way of 28552, 26003 and 28554.

Relay 28530 operates; connects generator to the called line, and reverts ring-back tone to the operator by removing the shunt from condensers 28901 and 28900 at 28533 and 28537; and closes relay 28520 by way of 28541, 28531, 28501 and 28573.

Relay 28520 operates; but without effect at this time. Relay 27500 restores when the trunk is again balanced and opens relay 27500 at 27504.

Relay 27500 restores and removes the shunt from relay 28550 at 27502.

Relay 28550 reoperates and opens relay 28530 at 28552.

Relay 28530 restores and removes generator from the called line at 28533 and 28537.

A transmission circuit is now complete between the operator and the called party, the circuit from windings 4 and 2 is repeating coil R-27 extends by way of 27000 and 27003, 28513 and 28515, 28505 and 28567, 28545 and 28547, 28577 and 28579.

L2l—Ring off connection

When the conversation has been completed the called subscriber may ring off and actuate relay 27550 to signal the distant operator.

Relays 27550, 27530 and 27520 function to unbalance the trunk as described under item J1i; which, in the present case, causes the operation of differential relay 36520.

Relay 36520 operates momentarily and opens relay 17530 at 36522.

Relay 17530 restores and opens 19570 at 17534.

Relay 19570 restores and reverses the battery on the trunk to the control center, giving the operator disconnect supervision as described under item L1j.

L2m—Operator releases the connection

The operator now withdraws the calling plug (not shown) from jack J23, thereby initiating the release of connector IC and remote control group RCG—1, as described under item L1j.

Relay 36530 restores and opens the simplex of the trunk to the sub-tandem exchange at 36531.

Relay 26570 restores and opens relay 26550 at 26572.

Relay 26550 restores and opens relays 26530 and 28550 at 26553.

Relay 26530 restores; opens relay 26540 at 26531; opens relay 26520 at 26533; and opens relay 26500, in series with relay 30570, at 26532.

Relay 28550 restores, but without effect at this time.

Relay 26520 restores and opens relays 28500, 28510, 28520, 28540, and 28570 at 26521.

Relay 28570 restores and opens relay 29530 at 28573.

Relay 29530 restores and closes the restoring circuit of motor magnet 29540 by way of 26523, 26001, 29531, multiple bank contacts and wiper 29903, and self-interrupting springs 29541.

Motor magnet 29540 operates; opens its own circuit at 29541; and acts as a buzzer to advance the associated wipers step by step until wiper 29903 reaches its normal contact.

5 Relay 26500 restores during the interval between the restoration of relay 26530 and slow-to-release relay 26520; and releases conductors 30000 and 30003.

Relay 30570 restores during the interval between the restoration of relay 26530 and slow-to-release relay 26520; reconnects relay 30580 to trunk conductor 14001 at 30577; and opens relay 30520 at 30571.

Relay 30520 restores but without effect at this time.

10 Relays 26540, 28500, 28510, and 28540 restore, but without effect at this time.

The equipment is now in position to receive other calls.

20 L3—Control center calls station in satellite exchange

Items L2a to L2i, inclusive, are applicable here and no further comment is required, except to assume that the dialling of the satellite number will cause motor magnet 29540 to advance wipers 29900 to 29905, inclusive, into engagement with the bank contacts associated with conductors 24007 to 24011, inclusive.

30 L3a—Seizure of line to satellite

Relay 29520 restores shortly after the last digit is dialled; and opens relay 29510 at 29552.

35 Relay 29510 restores and closes relay 24530 by way of 24524, 24007, bank contact and wiper 29902, 29511, 28005, relay 28570, 28006, 29502, 26012, and 28534.

40 Relay 28570 operates; locks by way of 28741, 26002, 26521, 25004 and 25545; places ground by way of 28575, 28004 and 29902 on conductor 24007 to hold relay 24530 operated; connects wipers 29900 and 29901 through windings 2 and 4 of repeating coil R—27 at 28578 and 28577; opens the circuit of motor magnet 29540 at 45 28572 to prevent further rotation; and closes relay 29530 at 28573.

45 Relay 29530 operates; and closes the simplex of the trunk to the satellite exchange by way of 26900, 26574, 26017, 27564, 27008, 29538 and 29538—1, 29904 and 29905, (29532), 24008 and 24009, winding 1 and winding 3 of repeating coil R—24 to trunk conductors 24005 and 24006.

50 Relay 24530 operates; closes relay 24540 at 24531; and opens the operating circuit of relay 24520 at 24533.

55 Relay 24540 operates and opens the charging lead at 24542.

At the satellite exchange end of the trunk, the simplex extends from relay 34510, differential relay 34520, conductors 33001 and 33002, and windings 2 and 4 of repeating coil R—33, conductors 33009 and 33003, through normally closed contact 34581 to conductor 24005 and by way of normally open contact 34575 to conductor 24008. It follows then that the application of battery to the sub-tandem end of the simplex by relay 29530 will result in the energization of both relay 34510 and the unbalanced differential relay 34520.

70 Relay 34520 energizes without effect at this time, and will deenergize when contact 34575 is closed by relay 34570.

Relay 34510 operates and closes relay 34500 by way of 34512, 34012, and 32907.

75 Relay 34500 operates; closes relay 33560 by

way of 33004 and 34503; and closes relay 34570 at 34501.

Relay 33580 operates; closes relay 33580 at vibrating contact 33562; and prepares the pulsing circuit at 33564 and 33566.

Relay 34570 operates and extends conductor 24006 to winding 4 of repeating coil R—33 at 34575, thus causing the restoration of differential relay 34520.

Relay 33580 operates without effect at this time.

L3b—Dialling connector at satellite exchange

The operator now dials the remaining digit of the satellite subscribers' number.

Relay 19540 responds to the series of impulses from the operator's dial and repeats same to relay 36530.

Relay 36530 responds thereto and repeats the impulses to relay 26570.

Relay 26570 responds and repeats the impulses to relay 34510 at 26574. Further rotation of C—2 at this time is impossible because the circuit of motor magnet 29540 is open at 28572.

Relay 34510 responds to the impulses and at 25 each deenergization closes motor magnet 32530 by way of 32015, 33564, 33009, 34512 and 34502; and closes relay 33570 by way of 33586, 33564, 33009, 34512 and 34502.

Relay 34500 is slow to release and remains 20 operated at this time.

Relay 33570 operates; short circuits its upper winding at 33571, thus rendering itself slow to release in order that it may remain operated throughout the dialling period; and closes relay 33540 at 33573.

Relay 33540 operates; opens line wiper 32904 at 33545; and opens wiper 32906 at 33543.

Motor magnet 32530 responds to the impulses and at each deenergization advances wipers 41 32904 to 32907, inclusive, step by step until they reach the bank contact associated with the called line, which will be assumed to be that associated with telephone T—3.

L3c—Dialed line busy

There is no provision at the satellite exchange whereby a test may be made for a busy line, and in all events the line is seized as described below.

L3d—Seizure of called line

Relays 33570 restores shortly after dialling is completed and opens relay 33540 at 33573.

Relay 33540 restores; closes relay 32510 by way of 32906, 32006 and 33543; and recloses line wiper 32904 at 33545.

Relay 32510 operates and removes relay 32500 from across the called line at 32511.

The operator is now connected to the called line and will challenge on the line to make sure it is idle, before she starts to ring.

L3e—Operator rings called line

When the operator desires to ring the called station, she momentarily operates "ring and offer" key K—23—2 twice, with the result that relay 37560 energizes twice as described under item L2e.

Relay 27560, at each energization, unbalances the trunk to the satellite by opening the battery feed to one side of the trunk at 27564, thereby 70 causing the operation of differential relay 34520.

Relay 34520 operates and closes relay 34540 by way of 34522 and 34571.

Relay 34540 operates and closes relay 34560 by way of 34554, 34544, 32011 and 32907.

Relay 34560 operates and prepares a locking circuit for itself by way of 34560, 34561, and 34561.

6 Relay 34520 restores and opens relay 34540 at 34522.

Relay 34540 restores and opens the operating circuit of relay 34560 at 34544, thereby rendering the locking circuit of said relay effective.

10 Relay 34560 operates in series with relay 34560; prepares the circuit of relay 33550 at 34562; and opens the circuit of relay 34560 at 34564.

Relay 34560 reoperates and again closes the relay 34540 by way of 34522 and 34571.

15 Relay 34540 operates and closes relay 33550 by way of 33007, 34552, 34542 and 34501.

Relay 33550 operates; locks by way of 33551 and 33006 and 34501; and extends windings 1 and 3 of repeating coil R-33 to the called line by way of 33555 and 33559.

20 As explained under item L2k, the second operation of key K-23-2 causes relay 28530 to operate and impress generator on the called line which, in the present case, passes through repeating coils R-24 and R-33 and actuates the ringer at telephone T3. A portion of the ringing current also passes through relay 34530 in series with condenser 34900.

Relay 34530 operates and provides a holding circuit for relay 34540, during the ringing period, 30 by way of 34541, 34542 and 34571. This holding circuit is necessary because relay 28530, upon energizing to impress generator on the called line, also rebalances the trunk to the satellite at 28532, thus causing the deenergization of differential relay 34520. The rebalancing of the trunk during the ringing period is essential to the proper passage of ringing current through repeating coils R-24 and R-33.

35 Relay 34530 restores after the ringing period 40 and opens relay 34540 at 34532.

Relay 34540 restores without effect at this time.

A transmission circuit is now complete between the operator and the called party.

45 L3f—Ringing off connection

When the conversation has been completed, the called subscriber may ring off through repeating coil R-33, R-24, and R-27, and actuate relay

50 27550. Subsequent operations are the same as described under item L2l.

L3g—Operator releases the connection

The operator now withdraws the calling plug 55 (not shown) from jack J23, thereby initiating the release of connector C-2, incoming connector IC, and remote control group RCG-1 as described under item L2m.

60 Relay 26570 restores and opens the simplex of the trunk to the satellite at 26574, thereby opening the circuit of relay 34510.

Relay 34510 restores and opens relay 34500 at 34512.

65 Relay 34500 restores; opens relays 34550, 34560, 34570, and 33550 at 34501; and opens relay 33560 at 34503.

70 Relay 33560 restores; opens relay 33580 at 33562; closes motor magnet 32530 by way of 32531, 32016, 32568, 33010, 32011, multiple bank contacts and wiper 32907; and closes relay 33570 by way of 33566, 33568, 33010, 32011, multiple bank contacts and wiper 32907.

75 Motor magnet 32530 operates, interrupts its own circuit at 32531 and functions as a buzzer to advance wipers 32904 to 32907, inclusive, step

by step until wiper 32907 reaches its home position.

Relay 33570 operates and remains operated during the homing period; and closes relay 33540 at 33513.

80 Relay 33540 operates and opens wiper 32906 at 33543, in order that cut-off relays, such as relay 32510, will not be needlessly operated during the homing period.

Relay 32510 restores when wiper 32906 passes 10 beyond the bank contact associated therewith.

Relay 33540 restores when the home position of wiper 32907 is reached.

Relays 33550, 33580, 34550, 34560, 34570 restore without effect at this time.

15 The equipment is now in position to receive other calls.

L3h—Line to satellite busy

In the event that the line to the satellite is busy 20 from another call, either incoming or outgoing, ground will be present on test conductor 24007. When the busy line is called, a circuit will be closed for relay 29500 by way of 29511 (relay 29510 not yet having deenergized) and 29902.

Relay 29500 operates; locks by way of 29511 (after relays 29520 and 20510 restore), 29502, 26012, and 26534; and returns busy tone to the operator by way of 31006, 29508, 28010, 28562, 28514, 26011, 27904, and conductor 30006.

30 The operator now releases the connection as described above.

L4—Miscellaneous operations—Control center

L4a—Busying control center trunk

35 A control center trunk may be bussed at the control center by the operation of key K-23-5, which functions to close the circuit of relay 21550 by way of 21525, 21001, K-23-5 and 23901.

Relay 21550 operates and transfers the chain circuit through to the next idle control center 40 trunk switch at 21552, so that this trunk cannot be seized from the remote control relay group.

L4b—Stored call

If, when the operator answers, there is no response from the calling party, she assumes that she has received a stored call from a sub-tandem exchange party. The operator then momentarily actuates "ring and offer" key K-23-2 to unbalance differential relay 19560. Relays operated at 50 this time: 14560, 14570, 15570, 15580, 15590, 18560, 18570, 18580, 19530, 19540, 19570, 19580, 20520, 20530, 20580, 21520, 24510, 25530, 26500, 26510, 26520, 26530, 26540, 26550, 26570, 28550, 30560 and 30570.

55 Relay 19560 operates and closes relay 19510 by way of 19562, 19542, and 19552.

Relay 19510 operates and removes battery from one side of the trunk to the sub-tandem exchange at 19513, thus unbalancing differential relay 60 27500.

Relay 27500 operates; closes relay 27560 at 27504 and opens the circuit of relay 27550 at 27502.

65 Relay 27560 operates and shunts relay 28550 at 27562.

Relay 28550 restores and closes relay 28530 by way of 28552, 26003, and 26554.

70 Relay 28530 operates and impresses generator in the calling line at 28533 and 28537, thus recalling the originating subscriber.

Relays 19510, 19560, 27500, 27560 and 28530 restore when key K-23-2 is returned to normal.

75 For sub-tandem exchange functioning in connection with stored calls see item J2d.

ITEM M

CIRCUIT DESCRIPTION—CONTROL CENTER REVERTS CALL FROM TANDEM OFFICE

5 *M1—Tandem subscriber calls sub-tandem subscriber*

A call from a tandem subscriber to a sub-tandem subscriber is completed by the control center operator. Such calls are forwarded to the 10 control center operator from the local connector banks, through a control relay group and a control center trunk switch, as described under item H2.

15 The operator, after ascertaining the desired party's number, operates the dial key individual to the two-way trunk on which the call was received (key 23—3 for instance) and dials the wanted subscriber's number on her positional dial.

20 The detailed explanation of the setting up of a call to the sub-tandem exchange, as given under items L2c to L2k, inclusive, is in general applicable here, and need only be amplified by discussing certain operations peculiar to a reverted

25 call. Before entering into a detailed description of the circuit operation, there are two general principles of operation which should be considered broadly.

30 The first of these has to do with the switching of various talking circuits. The term "tandem exchange talking circuit" will at this time refer to conductors 13009 and 13010, particular attention being directed to Fig. 15. The term "operator's talking circuit" will refer to conductor 35 19007 and 19009, particular attention being directed to Fig. 19, while the term "sub-tandem exchange talking circuit" will refer to conductors 16002 and 16003, particular attention being directed to Fig. 16.

40 At this time the tandem exchange talking circuit extends by way of normal contacts relay 16570, normal contacts relay 16580, and normal contacts relay 16580 to repeating coil R—19, and thence to the control operator's talking circuit.

45 During the dialling of the first two digits required to set up the call to the tandem subscriber, break contacts on relay 16570 will disconnect the tandem exchange talking circuit so that "clicks" from the operator's dial will not annoy the calling subscriber.

50 At the completion of the dialling of the second digit, break springs on relay 16580 will disconnect the tandem exchange talking circuit from the operator's talking circuit at make-before-break contacts 16585 and 16587 so that the calling subscriber will not be annoyed by dial tone soon to be returned from the sub-tandem exchange. At this time make contacts 16585 and 16587 extend the operator's talking circuit to the

55 sub-tandem exchange talking circuit as previously explained under item L2k, the ringing of the sub-tandem exchange subscriber is accomplished by the momentary operation of the "ring and offer" key K—23—2, the first momentary operation of this key results in the restoration of relay 16580, and the energization of relay 17520. The sub-tandem exchange talking circuit is now disconnected from the operator's talking circuit, and the tandem exchange talking circuit is re-

60 connected thereto. This procedure permits the operator to advise the calling subscriber of the busy condition of the called line, without being inconvenienced by the busy tone being returned on the sub-tandem talking circuit.

75 The second momentary operation of the "ring

and offer" key results in the operation of relay 17510. The sub-tandem exchange talking circuit is now connected by way of 17513 and 17515, operated contacts relay 17520 and normal contacts relay 16580, to the tandem exchange talking circuit.

The second principle of operation has to do with the control of the release of the connection. As explained under item H2h, the release of the connection, prior to the answer of the control 10 operator, is under the control of the tandem exchange subscriber, as ground on hold conductor 13011 is maintained solely by relay 15430 at 16533.

15 When the control operator answers, she assumes control of the release of the tandem exchange equipment, for the reason that make contact 16533 is shunted by relay 16580 at 16583.

20 When the control operator starts to dial the number of the called sub-tandem exchange subscriber, the release of the new call is under the control of the operator, for the reason that battery to the incoming connector is maintained solely by relay 19540 at 19541.

25 The first operation of the "ring and offer" key results, in the operation of relay 17520, which locks under control of relay 16560, and shunts contact 19541 at 17527 in preparation for taking over the control of the new call.

30 The second operation of the "ring and offer" key causes the operation of relay 17510, thus insuring that the release of the new call will come under the control of the calling subscriber when the operator withdraws her answering plug from jack J—23.

35 This tentative control of the release of the new connection may, however, be withdrawn by the operator, as described below under item M1d.

40 These two general principles of operation having been discussed, we will now proceed with a somewhat detailed circuit description of the operations peculiar to a reverted call.

45 The first and second digits of the sub-tandem subscriber's number dialled by the operator will direct the call to the sub-tandem exchange switching equipment. The first digit will be "9" and will be followed by a second digit which will indicate the desired group of trunks to which the call is to be directed.

50 Relay 19540, in responding to the first series 50 of pulses from the operator's dial, operates relay 17550 and rotary magnet 18510 of the register, and repeats impulses to the associated connector over conductor 17003 at 19541. The register steps its wipers to bank contact 8. Relay 55 18550 operates relay 16570 to remove the tandem subscriber from the circuit of repeating coil R—19 so that the tandem subscriber will not hear "clicks" from the operator's dial.

55 Relay 18550 restores at the end of the first 60 series of impulses and closes relay 17560.

60 Relay 17560 operates and causes the register to release. The releasing of the register in turn permits relay 17570 to operate in series with relay 17560.

65 Relay 19540, in responding to the second series of impulses from the operator's dial, operates relay 18550 and rotary magnet 18510 of the register and repeats impulses to the associated connector 70 over conductor 17003 at 19541.

70 Relay 18550 restores at the end of the second series of impulses and closes relay 17560.

75 Relay 17560 operates; locks operated under control of relay 16580; prevents further oper-

ation of the register's wipers and closes relay 16580.

Relay 16580 disconnects the tandem subscriber from the repeating coil and connects talking conductors from the associated connector through to the repeating coil.

The two series of impulses repeated to the associated connector over conductor 17003 cause the connector to step its shaft and wipers to the first trunk of the dialled sub-tandem exchange. The connector will seize the first idle trunk encountered, and will connect battery to both sides of the trunk in order to place the equipment in the sub-tandem exchange in position to set up a call under the control of the operator's dial.

The sub-tandem switching equipment will now forward dial tone to the operator to inform the operator that the sub-tandem switching equipment is in position to set up the connection. The operator now dials the remaining digit (or digits) of the sub-tandem exchange subscriber's number.

Relay 19540 responds to the series of impulses from the operator's dial, repeats the impulses to relay 36530 of the associated connector, which in turn repeats the impulses to the sub-tandem switching equipment by removing battery from both sides of the sub-tandem trunk.

In the event that the called line is idle, the operator rings the called station on the second operation of her "ring and offer" key. The first operation of the "ring and offer" key unbalances the control center trunk, permitting relay 19560 to operate and close relay 19510.

Relay 19510 operates and closes relay 36500 by way of 35907-1, 35514, 35908, 37536, 37544, 35909, 35544, 35905, 19000 and 19515.

Relay 36500 operates and closes relay 17520 by way of 16012, 15019, 15581, 15001 and 36504.

Relay 17520 operates; locks by way of 17521, 17031, 18541, 16011, 16575 and 16561; connects holding battery to pulse conductor 17003 at 17527; extends relay 17510 by way of 17521-1 to conductor 17001; and opens relay 16580 at 17522.

Relay 16580 restores, disconnects the operator from the connection to the sub-tandem exchange and connects her to the tandem subscriber at 16585 and 16587.

The second operation of the "ring and offer" key causes relay 19560 to operate relay 19510, which in turn operates relay 36500.

Relay 36500 reoperates; closes relay 17510 by way of 17521-1, 17001, 36501 and 36517; and removes battery from one side of the sub-tandem exchange trunk.

Relay 17510 operates; locks by way of 17511, 15023 and 16531; and connects the operator and the tandem subscriber through to the tandem exchange at 17513 and 17515.

The transmission circuit between the operator and the sub-tandem exchange subscriber is completed through the repeating coils of the control relay group and associated connector. The transmission circuit between the tandem subscriber and the sub-tandem exchange subscriber is completed through the repeating coil of the associated connector. The release of the connection between the tandem subscriber and the sub-tandem exchange subscriber is now under the control of the tandem subscriber.

70 *M1a—Operator retires from the connection*

The operator now withdraws the answering plug (not shown) from jack J-23 and thereby brings about certain circuit changes as described under item L2m.

Relay 18540 restores and opens the circuit of relay 18580, the incoming connector remains operated, however, because battery is maintained on conductor 17003 by contact 17527.

Relay 18580 restores and opens relays 17580, 17570 and 18570.

Relay 18570 restores; closes release magnet 18520; and opens relays 19580 and 21520.

The control center trunk is now available for other calls, and the release of the connection between the tandem and the sub-tandem exchanges is under control of the calling subscriber.

71 *M1b—Calling subscriber releases connection*

When the calling subscriber hangs up his receiver the circuit to relay 16520 is opened at the hookswitch.

Relay 16520 restores; opens the circuit to relay 16530; and closes the circuit to relay 16560.

Relay 16530 restores; removes ground from hold conductor 13011, to permit connector C-1 to release; and opens relay 16540.

Relay 16560 operates momentarily, and opens relay 17520.

Relay 17520 restores; opens relay 36530; and releases all operated relays in RCG-1.

Relay 36530 restores and brings about the release of IC-1 and the equipment in the sub-tandem exchange.

The equipment is now ready to receive other calls.

72 *M1c—Busy condition encountered*

The operator may be unable to complete the connection because of "all sub-tandem exchange trunks busy" (see item L2f), "all sub-tandem links busy" (see item L2g) or a busy subscriber's line (see item L2i).

In any such event, the operator will momentarily operate the "ring and offer" key, thus putting herself in communication with the calling subscriber in order that she may inform him that the call cannot be completed. The operator now withdraws the answering plug from jack 23, whereupon line relay 19540 restores and closes relay 18550 by way of 17027, 17514, 17026, 18572, 18010, 19542 and 19552.

Relay 18550 operates and closes relay 16570 by way of 16016 and 18554.

Relay 17520 restores and removes battery from conductor 17003 at 17527; thus causing the release of the new call, as contact 19541 is already open.

The calling subscriber now restores his receiver and brings about the release of the local equipment as explained under item M1b.

The above explanation shows that the new call will be released when the operator withdraws the answering plug even after the first operation of the "ring and offer" key. In passing it may be pointed out that the new call will not be released when the operator withdraws the answering plug, after the second operation of the "ring and offer" key, for the reason that relay 18550 cannot operate at this time because both relay 17510 and relay 17520 are now energized.

73 *M1d—Paystation calls*

In the event that the call originates at a paystation; the connection will be set up, and the operator will ring the called party as above described. At this time relay 17510 and 17520 will be operated, relay 16570 will be restored, and the three talking circuits will be connected together.

It is desirable, however, that the operator split

- the connection (after advising the called party that a paystation is calling), in order that she may supervise the depositing of the required coins by the calling party. This splitting of the circuit is accomplished by the momentary operation of "split and incompletely call" key K-23-1.
- 5 The operation of key K-23-1 closes relay 23530, which operates to remove a shunt from around high resistance 23902. The resulting decrease in current flow over the trunk will permit relay 19530 to restore, while holding relay 19540 operated.
- 10 Relay 19530 restores and closes relay 19540 by way of 18552, 18069, 19532, 19542 and 18552.
- 15 Relay 19540 operates momentarily, unlocks relay 17520 at 18541; and closes relay 35540 by way of 17000, 17517, 17006, and 18543.
- 20 Relay 17520 restores and removes holding battery from conductor 17003, thereby placing the release of the sub-tandem exchange equipment under the control of the operator and disconnects the operator and the subscriber from the connection to the sub-tandem exchange.
- 25 Relay 35540 operates and locks by way of 35541, 35804, 16000, 16543, 16001, 36591, and 36541.
- 30 The operator will reconnect the calling paystation party to the sub-tandem exchange party after the proper coins have been deposited by operating her "ring and offer" key momentarily, thus energizing differential relay 19560.
- 35 Relay 19560 operates and closes relay 19510.
- 40 Relay 19510 operates and closes relay 17520 by way of 16012, 16541, 15019, 15001, 35544, 35006, 19000 and 19515.
- 45 Relay 17520 operates; locks under control of the control relay group; places holding battery on conductor 17003 to maintain the associated connector operated after the operator disconnects from the connection; and connects the tandem subscriber and the operator through to the sub-tandem exchange.
- This method of regaining control of the connection is also applicable in the event that the operator inadvertently actuates the "ring and offer" key twice in the face of a busy condition.
- ITEM N
- CIRCUIT DESCRIPTION—CONTROL CENTER REVERTS
CALL FROM SUB-TANDEM EXCHANGE
- 50 **N-1 Sub-tandem subscriber calls tandem subscriber**
- 55 When a subscriber in a sub-tandem exchange initiates a call, that call is automatically routed to the control center, as described under items J1a to J1i, inclusive.
- 60 Relays operated at this time: 14560, 14570, 15570, 15580, 15590, 18560, 18570, 18580, 19530, 19540, 19570, 19580, 20520, 20530, 24510, 25530, 26500, 26510, 26520, 26530, 26540, 26550, 26570, 30560 and 30570.
- 65 The operator, after ascertaining the desired party's number, operates the dial key individual to the trunk on which the call was received (assumed to be key K-23-3) and dials the wanted subscriber's number on her positional dial.
- 70 Relay 19540 responds to the first series of impulses from the operator's dial, operates relay 18560 and motor magnet 18510, and repeats impulses to conductor 17003. The register steps its wipers to the bank contact corresponding to the first digit called.
- 75 Relay 18560 operates and closes relay 15540 by way of 15584, 15027, 17542, 17554, 17023, 18551, 18581, 15023 and 19584.
- Relay 15540 operates; disconnects the sub-tandem exchange subscriber from the operator's talking circuit so that he will not receive "clicks" from the operator's dial at 15541 and 15543; and at the same contacts maintains battery by way of 18903, 18651, 17010, 18577, 17011, 17547, and 15014 on the sub-tandem exchange trunk so that the sub-tandem equipment will not release. 5
- 10 Relay 18550 restores at the end of the first series of impulses; opens relay 15540, and closes relay 17650.
- 15 Relay 15540 restores; reconnects the sub-tandem exchange trunk through to the operator's talking circuit; and closes relay 17550.
- 20 Relay 17550 operates; locks under control of relay 19580; prevents further operation of the registers wiper; and closes relay 16580.
- 25 Relay 16580 operates; connects battery to the trunk to the sub-tandem exchange by way of 16901, 16581 and 16583, 15013 and 15012 and 15583 and 15585; disconnects the sub-tandem exchange subscriber from the operator's talking circuit at 16585 and 16587; and at the same contacts connects the tandem exchange talking circuit through to the operator's talking circuit.
- 30 Relay 19540 responds to the second series of impulses from the operator's dial and repeats the impulses to the associated connector. The two series of impulses forwarded to the associated connector causes the connector to step its wipers to the bank contacts of the called line.
- 35 If the dialled line is idle, relay 37570 will operate and seize the dialled line. The operator now starts the automatic ringing of the called line by operating the "ring and offer" key twice.
- 40 Relay 19560 responds to the unbalancing of the trunk and closes relay 19510, which, in turn, closes relay 36580.
- 45 Relay 36580 closes differential relay 36590, which operates when relay 36580 restores. Relay 36580, upon the second operation, opens relay 37500.
- 50 Relay 37500 restores and connects interrupted generator to the called subscriber's line.
- 55 The first operation of relay 36580 closes relay 17520 by way of 16012, 16541, 15018, hold conductor 15001, and 36586.
- 60 Relay 17520 operates; locks under control of the control relay group; connects holding battery to pulse conductor 17003 so that the release of the connector will be under the control of the called tandem office subscriber; and opens relay 16580.
- 65 The second operation of relay 36580 closes relay 17510 by way of 17521-1, conductor 17001, 36581, 36595, 19002 and 37577.
- 70 Relay 17510 locks under control of relay 16580 and connects the sub-tandem exchange party and the operator through to the called subscriber's line.
- 75 When the called subscriber answers, relay 37500 operates; locks under control of relay 36540; and closes the called subscriber's line through to battery feed relay 35530.
- 80 Relay 35530 operates and closes relay 35520 at 35532.
- 85 Relay 35520 operates and closes relay 17530 by way of 17533, conductor 17004 and 35521.
- 90 Relay 17530 operates and closes relay 19570 by way of 15029, 15562, 15028, 17534, 16015, 16562 and 16544.
- 95 Relay 19570 operates and reverses the polarity of the control center trunk to give the operator answering supervision. 75

The transmission circuit between the operator and the tandem subscriber is connected through the repeating coils of the control relay group and the associated connector. The transmission circuit between the sub-tandem exchange subscriber and the tandem subscriber is completed through the repeating coil of the connector. The release of the connection is now under the control of the called tandem exchange subscriber.

10 *N1a—Operator retires from the connection*

The control center operator now retires from the connection by removing the answering plug (not shown) from jack J-23, thus opening the circuit of relay 19540.

Relay 19540 restores and causes the restoration of relays 18580 and 18570.

Relays 18570 restores; closes release magnet 18520; and opens the series circuit of relays 0 19580 and 21520.

Relay 21520 restores, and the trunk to the control center is now available for other calls.

11 *N1b—Called subscriber releases the connection*

25 When the called tandem subscriber hangs up his receiver, the circuit of relay 35530 is opened at the switchhook.

Relay 35530 restores and opens relay 35520 at 35532.

30 Relay 35520 restores and opens relay 17530 at 33521.

Relay 17530 restores and closes relay 18550 by way of tandem disconnect conductor 18003, 36596, 17002, 17529—2, 17005, 18579—3, 17028, 17534, 35 16015, 16562 and 16544.

Relay 18550 operates and closes relay 16570 at 18554.

Relay 16570 operates; opens relay 17520 at 16575; and opens the series circuit of relays 15570 40 and 14560 at 16573.

Relay 17520 restores and opens relay 36530 at 17527, thus causing the release of the associated connection.

Relay 15570 restores and permits the restoration of all operated relays in the control relay group. The control relay group is now available for other calls.

Relay 14560 restores and permits the release of all operated relays in the sub-tandem trunk group, thus making the sub-tandem exchange trunk available for other calls.

12 *N1c—Busy line encountered*

If the dialled line is busy, relay 37530 will operate and return busy tone to the operator.

The operator cannot offer this type of call to the busy line (compare with item L1f) because relay 37510 energized and locked when the incoming connector was seized by the control relay group.

Relay 36560, upon energizing, closed a circuit by way of the high resistance winding of relays 37510, 37512, 36002, 36566, 15001, 15581, 15019, 16012 and relay 17520. Relay 17520 will not energize at this time.

Relay 37510 operates; locks by way of 37511, 35904 and 36541; and prepares the circuit of relay 36580 at 37514.

The operator now momentarily actuates the 70 "ring and off" key, thereby unbalancing the trunk to cause the operation of relay 19560, which closes relay 19510.

Relay 19510 operates and closes relay 36580 by way of 35907, 37514, 37536, 37544, 35909, 35544, 75 35006, 19000 and 19515.

Relay 36580 operates and closes relay 17520 by way of 16012, 15019, 15581, 15001 and 36586.

Relay 17520 operates; locks under control of the control relay group; connects battery to pulse conductor 17003 to hold the associated connector; and opens relay 16580 at 17522.

Relay 16580 restores; disconnects the operator's talking circuit from the tandem exchange talking circuit; and connects the operator's talking circuit through to the sub-tandem talking circuit. 10 The operator may now inform the sub-tandem exchange party that the desired subscriber's line is busy.

The operator may now release the connection by removing the calling plug (not shown) from 15 jack J-23. The release of the connection follows, in general, the explanation given under item M1c.

16 *N2—Sub-tandem subscriber calls sub-tandem subscriber in same exchange area*

When a subscriber in a sub-tandem exchange initiates a call for a subscriber within his own exchange area, that call is automatically routed to the control center, as described under item J1. 25

The operator, after ascertaining the desired party's number, operates the dial key individual to the two-way trunk on which the call was received and dials the wanted subscriber's number on her positional dial.

Relay 19540, in responding to the first series of impulses from the operator's dial, operates relay 19550 and the rotary magnet of the register and repeats impulses to the associated conductor over pulse conductor 17003. The register steps 35 its wipers to bank contact 9. Relay 18550, upon energization, operates relay 15540 which disconnects the sub-tandem exchange trunk from the circuit of the repeating coil so that this series of impulses will not be transmitted to the sub-tandem exchange switching equipment. Relay 15540 also maintains battery on the sub-tandem exchange trunk to hold the sub-tandem switching equipment operated. Relay 18550, on restoring at the end of the first series of impulses, 40 restores relay 15540 to reconnect the sub-tandem exchange trunk through to the repeating coil, and closes the circuit of relay 17560.

Relay 17560 operates; locks operated under the control of the off-normal springs of the register; 50 prepares the circuit to relay 17570; and closes the circuit to the release magnet of the register, causing the register to release. When the register has released, the off-normal springs remove the short circuit for relay 17570, permitting relay 17570 to 55 operate in series with relay 17560. Relay 17570 opens the circuit to the release magnet of the register.

Relay 19540, in responding to the second series of impulses from the operator's dial, operates 60 relay 18550 and the rotary magnet of the register and repeats impulses to the associated connector over pulse conductor 17003 at 19541. The register steps its wipers to bank contact number one. Relay 18550, upon energization, operates relay 15540 which again disconnects the sub-tandem exchange trunk from the circuit of the repeating coil so that this series of impulses will not be transmitted to the sub-tandem exchange switching equipment.

Relay 18550, upon restoring at the end of the second series of impulses; restores relay 15540 to connect the sub-tandem exchange trunk through to the repeating coil; and closes the circuit to relay 17540 by way of 15024, 15582, wiper 15904, 75

- 15026, wiper 18902, 17022, 17574, 17021, 18551, 18581, 15023 and 19584.
- Relay 17540 operates; prevents the operation of relay 17550 at 17541; prevents further operation of motor magnet 18510 at 17544; prevents further operation of relay 15540 at 17542; locks under control of relay 16530; removes battery from pulse conductor 17003 at 17547, to allow the associated connector to release, inserts impulsive contacts 19541 of line relay 19540 into the battery feed circuit to the sub-tandem exchange trunk at 17547; maintains ground on relay 28530 at 17548, and places dial tone on the control center trunk at 17549, to inform the operator that she can proceed with the dialling.

N2a—Dialling connector in the sub-tandem exchange

The operator now dials the remaining digits of the sub-tandem exchange subscriber's number. Relay 19540, in responding to each series of impulses from the operator's dial, repeats the impulses to the sub-tandem switching equipment by removing battery from both sides of the sub-tandem exchange trunk.

Relay 26570 follows the dial impulses, closing ground to motor magnet 29540 in multiple with relay 29520. Relays 26550 and 29520, due to their slow action remain operated during impulsive. The connector switch now comes to rest upon the back contact dialled. Relay 29520 closes relay 29510. Relay 29510 removes ground from wiper 29904 during dialling, connects relay 29500 to wiper 29902 to test for busy, and closes relay 28540. Relay 28540 locks; opens the calling line at 28545 and 28547; and opens dial tone at 28546.

Presuming that the called line has no other connection established to it; battery through a cut-off relay will be encountered by wiper 29902 and, when relays 29510 and 29520 have restored, the circuit of relay 28570 will be closed.

Relay 28570 energizes and locks; closes relay 29530; and connects the called line through to repeating coil R—27.

N2b—Called line busy

In case ground had been encountered by wiper 29902, due to a connection already having been established from or to the called line, relay 29500 would have operated and returned busy tone to the operator.

A transmission circuit is completed between the called line and the operator, and the operator may challenge on the line to make sure that no one is talking before she proceeds to ring the called line.

N2c—Operator rings called line

If the dialled line is idle the operator will cause the sub-tandem exchange equipment to ring the called party by twice operating her "ring and offer" key. At each operation of the "ring and offer" key the control trunk is unbalanced to effect the operation of differential relay 19550. Relay 18510 is actuated thereby and functions to unbalance the trunk to the sub-tandem exchange at 19513.

Relay 27500 operates at the first unbalancing of the trunk; closes relay 27560; and opens relay 17550. Relay 27560 closes relay 28510. Relay 28510 shunts relay 28500; locks to ground through relay 28500; and disconnects the called line from repeating coil R—27. When relay 27500 restores, it opens relay 27560, the latter relay then restores and removes the shunt from relay 28500, allowing it to energize in series with relay 28510.

Relay 27500 operates at the second unbalancing of the trunk; closes relay 27560; and opens relay 28510.

Relay 27560 shunts relay 28550, which restores and closes relay 28530. Relay 28530 operates; closes relay 28520 and connects direct generator to the called line. The calling line will get ring-back tone through condensers 28800 and 28801. Relay 28520 operates and locks; and connects the calling line to the called line. When the operator releases the key, relay 27500 will restore and open relay 27560. Relay 27560 will remove the shunt from relay 28550, causing it to operate. Relay 28550 will open relay 28530, which will restore and remove generator from the calling line. The calling party, the called party, and the operator are now connected together.

N2d—Operator retires from the connection

When the operator retires from the trunk, relay 19540 restores; removes battery from the sub-tandem exchange trunk; opens relay 28580 and closes relay 18550. Relay 18580 restores and opens relay 18570. Relay 18570 restores, closes release magnet 18520; and opens the circuit of relays 15570 and 14560, the series circuit of relays 19580 and 21520, and other operated relays.

Relay 21520 restores, and the trunk to the control center is made available for other calls.

Relay 14560 restores and opens the holding circuit of other sub-tandem trunk relays. The trunk to the sub-tandem exchange is now available for other calls.

Relay 26570 restores when battery is removed from both sides of the sub-tandem exchange trunk, and closes relay 27540; and opens relay 28550.

Relay 27540 operates and locks to ground on conductor 31002; closes a multiple ground to relays 26530 and 28550 to hold them operated when slow-to-release relay 28550 removes ground therefrom; and opens the series circuit of relays 28500 and 30570.

Relay 26550 restores and closes relay 25540 to start the timing equipment, as explained below.

Relay 30570 restores; opens relay 30560; opens the trunk to the tandem exchange; and closes the charging lead. The two subscribers are using only equipment contained in the sub-tandem exchange.

N2e—Ringing off connection

When the conversation has been completed, either the calling or called party can ring off by actuating his hand magneto to operate relay 27550. Relays 27550, 27530 and 27520 operate in order and, when the ring-off is completed, relays 27550, 27530 and 27520 restore in order. Relay 27520 is slow to release, and holds the circuit to relay 27540 open long enough for the latter relay to restore, and opens relays 26530 and 28550.

Relay 26530 restores and opens relays 26520, 26540 and 25530.

Relay 26530 restores and opens relays 26510 and 25510.

Relay 26520 restores and opens relays 28420, 28540, 28570, 28510 and 28520.

Relay 28570 restores and opens relay 29530.

Relay 26520 closes ground to the multiplied contacts of the bank available to wiper 29903, thus causing the connector to advance to its normal position.

The sub-tandem equipment is now free for other calls.

N2f—Connection released by timing equipment

When the operator retired from the connection, as explained above, the deenergization of relay 26550 closed relay 25540 by way of 25021, 26551, 26511, 25006, 25541, and ground on "time in" conductor 31000.

Relay 25540 operates; locks at 25541, grounds time start conductor 31003 at 25542, closes "ground off" conductor 31001 through to relay 27510; and replaces ground at 25545 by that on "ground on" conductor 31002, thus placing the release of the connection under the control of the timing equipment.

15 The connection may now be released either by the timer, or by either subscriber ringing off. In case the subscribers fail to ring off, the connection will be released after an interval of time by the timer.

20 After the timer has completed its cycle of operations, see item J2c, ground is removed from "ground on" conductor 31002, causing the restoration of relays 27540, 28510, 28500, 28520, 28540 and 28570.

25 Relay 27540 restores and opens relays 26530 and 26550.

Relay 26530 restores and opens relays 26520, 26540 and 25530.

30 Relay 25530 restores and opens relays 26510 and 24510.

Relay 26510 restores and opens relay 25540.

Relay 25540 restores and removes ground from time start conductor 31003, to stop the timer equipment.

N3—Sub-tandem subscriber calls sub-tandem subscriber in another exchange area

When a subscriber in a sub-tandem exchange initiates a call, that call is automatically routed 40 to the control center as described under item J—1. The control center operator then completes the call to the desired tandem exchange, (an exchange other than the originating exchange) in the same manner as she would revert 45 a call from the tandem office to a sub-tandem exchange. This procedure was explained under item M1.

If the called line is idle, the operator will 50 twice operate the "ring and offer" key to cause the sub-tandem exchange equipment to ring the called subscriber's station.

Relay 19560 responds to the unbalancing of the control center trunk and closes relay 19510.

Relay 19510 in turn operates relays 36500 and 55 36510 of the associated connector to remove battery from one side of the sub-tandem exchange trunk.

The first operation of relay 26500 closes relay 17520, and the second operation closes relay 60 17510, thereby causing the calling sub-tandem exchange party and the operator to be connected through to the connection at the called sub-tandem exchange.

65 The transmission circuit between the operator and the called sub-tandem exchange party is completed through the repeating coils of the control relay group and the associated connector. The transmission circuit between the calling sub-tandem exchange subscriber and the called sub-tandem exchange subscriber is completed through the repeating coil of the associated connector. The release of the connection is now under the control of either sub-tandem exchange 70 party.

N3a—Operator retires from the connection

The operator now retires from the connection by removing the answering plug (not shown) from jack J—23, thereby opening the circuit of 5 relay 19540.

Relay 19540 restores and causes the restoration of relays 18580 and 18570.

Relay 18570 restores; closes release magnet 10 18520, thus causing the release of the register; and opens the series circuit of relays 19580 and 21520. The trunk to the control center is now available for other calls.

N3b—Ringing off connection

15

When the sub-tandem exchange parties finish their conversation, either party may operate his hand generator to release the connection.

If the called sub-tandem exchange subscriber 20 operates his hand generator first, the called sub-tandem exchange equipment will remove battery from one side of the sub-tandem exchange trunk, thereby causing the energization of differential relay 26520.

Relay 36520 operates and opens relay 17530 25 at 36522.

Relay 17530 restores and closes relay 18530 by way of 18002, 36596, 17002, 17529—2, 17005, 18579—3, 17028, 17534, 16015, 16562 and 16544.

Relay 18530 operates and closes relays 18550 30 at 18532.

If the calling sub-tandem exchange subscriber 35 operates his hand generator first, the calling sub-tandem exchange equipment will function to remove battery from one side of the sub-tandem exchange trunk, thereby causing the energization of differential relay 15560.

Relay 15560 operates and closes relay 18530 by way of 18002, 36596, 17002, 17529—2, 17005, 18579—3, 18004, 35522, 15000, 15562, and 15586. 40

In either event, relay 18530 closes relay 18550 at 18532.

Relay 18550 operates and closes relay 16570 at 45 18554.

Relay 16570 operates; opens relay 17520 at 45 16575; and opens the series circuit of relays 15570 and 14560 at 16573.

Relay 17520 will restore and remove holding battery from pulse conductor 17003 at 17521, thereby causing the release of the associated 50 connector.

Relay 14560 will restore and cause the release of all sub-tandem trunk relays, thus making the calling sub-tandem exchange trunk available for other calls. 55

The release of the associated connector will make the called sub-tandem exchange trunk available for other calls.

N3c—Connection released by timing equipment

60

Should both the calling and called sub-tandem exchange parties fail to operate their hand generators, the timing equipment will function to release the connection after a predetermined 65 interval.

When the operator retires from the connection, as explained above, the restoration of relay 18570 closes a circuit from ground at wiper 6902 by way of bank contact 6905 (assuming that TTE is at normal), 6002, high resistance winding of relay 70 35500, 35502, 35512, 15002, 15589—3, 15003, 18579—2, 18579—3, 17005, 17529—2, 17002, 36596, 18002 to relay 18530. Relay 18530 will not operate at this time.

Relay 35500 operates to "time in" the con- 75

- nection; locks by way of 35501, 35904 and 36541; and closes timer start relay 6500 by way of 6003 and 35503.
- Relay 6500 operates; closes relay 6510 by way of 6531 and 6502; and opens the homing circuit of motor magnet 6540 at 6502.
- Relay 6510 operates and closes relay 6520 by way of 6501 and 6502.
- Relay 6520 operates; locks to vibrating contact 6501 at 6521; and closes slow-to-operate relay 6530 by way of 6523 and 6502.
- Relay 6530 operates and opens relay 6510 at 6531.
- Relay 6510 restores and, when contact 6501 ceases to vibrate, opens slow-to-release relay 6520.
- Relay 6520 restores; opens relay 6530 (which is also slow to release) at 6523; and closes motor magnet 6540 by way of 6522, 6531 and 6502.
- Relay 6530 restores; opens motor magnet 6540 at 6531; and at the same contact again closes relay 6510.
- The cycle of operations just described will be repeated, and motor magnet 6540 will operate to advance wipers 6900 to 6903, inclusive, over their respective bank contacts. Ground is removed from "time in" conductor 6002 when wiper 6902 leaves bank contact 6905, it follows then that subsequent connections cannot "time in" until switch TTE again reaches its normal position.
- Wiper 6903, after a predetermined length of time, will engage bank contact 6904 and place ground from 6502 on time cut-off conductor 6001. In the case under consideration this circuit proceeds by way of 35502, 35512, 15002, 15589-3, 3515003, 18679-2, 18579-3, 17005, 17529-2, 17002, 36596, and 18002 to relay 18530.
- Relay 18530 operates and brings about the release of the connection as described above.
- The release of the associated connector causes the restoration of relay 35500 and, assuming that there are no other like relays energized, the restoration of start relay 6500 will next occur. The slow stepping of TTE then ceases, with the wipers in their normal position, and the telephone conversation timing equipment awaits the next call from a sub-tandem exchange to a sub-tandem exchange.
- In the event that only one such connection is established, and that the connection is released by one of the subscribers, it follows that start relay 6500 will restore at a time when the wipers of TTE are in some off-normal position.
- Relay 6500 restores and closes motor magnet 6540 by way of 6541, 6900 (or 6901), multiplied bank contact and 6502.
- Motor magnet 6540 will operate; open its own circuit at 6541; and act as a buzzer to advance the associated wiper step by step until wiper 6900 engages its normal bank contact.
- TTE is now in position to allow subsequent calls to "time in". If several sub-tandem to sub-tandem calls are established at about the same time, the operation of TTE will be continuous, and attention is called to the fact that a given connection can only "time in" while wiper 6902 is in engagement with bank contact 6905.
- To summarize, it may be said that a call from a sub-tandem subscriber to a sub-tandem subscriber in another exchange area will attempt to "time in" when the operator retires from the connection. The actual "timing in" will occur when the wiper 6902 next engages bank contact 6905; and the connection will be released when TTE next completes its full cycle.

ITEM O

CIRCUIT DESCRIPTION—CONTROL CENTER REVERTS CALL FROM SATELLITE EXCHANGE

When a subscriber in the satellite exchange initiates a call, that call is automatically routed to the control center as described under items K1a to K1g, inclusive. The call can then be reverted by the control center operator in various ways as explained under item N1, N2, or N3. 10 The only peculiarity of a reverted call from the satellite exchange is that arising when a satellite subscriber calls a satellite subscriber in the same area.

O1—Satellite subscriber calls satellite subscriber 15 in same area

When the call is extended to the sub-tandem exchange, ground is placed on test conductor 24007 by relay 24520 (and retained thereon by 20 relay 24530) in order that the calling line may appear busy in the banks of the associated connection, as was previously described under item K1c.

If the control center operator should originate 25 a call to the satellite exchange at this time, the presence of ground on test conductor 24007 would cause the busy signal to be returned to the operator as explained in item L3h.

The reverted call to the satellite progresses as 30 explained in item N2, up to the point where the wipers of connector C—2 are advanced into engagement with the bank contacts associated with conductors 24007 to 24011, inclusive. Relays operated at this time 14560, 14570, 15570, 15580, 35 15590, 18560, 18570, 18580, 19530, 19540, 19570, 19580, 20520, 20530, 20580, 21520, 24530, 24540, 25530, 26500, 26510, 26520, 26530, 26540, 26550, 26570, 29540, 29510, 29520, 30560, 30570, 32510, 33500, 33520, 33560, 33580, 34500, 34510, and 34570. 40

Relay 29500 operates by way of 29511 and 29902, and prepares the circuit of relay 28560 at 29504.

Relay 29520 restores shortly after the dialling ceases and opens relay 29510 at 20522.

Relay 29510 restores and closes relay 28560 by 45 way of 28007, 28004, 28008, 26010, 26516, 25009, 25903, 25013, 29532, bank contact and wiper 29904, 29538 and 29514.

Relay 38560 operates; locks its upper winding by way of 28561, 26002, 26521, 25004 and 25545, 50 closes relay 28570 by extending its locking circuit at 28563; removes busy tone 28562; and disconnects conductor 26016 from conductors 26014 and 26015 at 28564 and 28566.

Relay 28570 operates; locks to its operating circuit at 28571; closes relay 29530 by way of 28003 and 28573; and opens the circuit to rotary magnet 29540 at 28572.

Relay 29530 operates and places battery by way of 28900, 26574, 26017, 27654, 26017 and 27008, 60 29538 and 29538-1, 29804 and 29905, 29542, 24009, and 24008, windings 3 and 1 of repeating coil R—24, conductors 24006 and 24005, thereby closing the circuit of relay 34510 as explained under item L3a. 65

Thus it will be seen that connector C—2 is enabled to cut in on a busy sub-tandem exchange line when finder F—2 is already positioned upon that line.

In this connection it may be mentioned that 70 relay 29530 must be provided with a break-make spring combination, such as 29532, for each sub-tandem exchange line circuit available thereto.

Further dialling by the control operator will have no effect upon connector C—2, but will ac- 75

tuate the equipment in the satellite exchange as described under item L3b.

The completion and release of the connection follows as described under items N2d, N2e, and 5 N2f.

While there has been described what is at present considered to be the preferred embodiment of the invention, it will be understood that various modifications may be made therein, and it is 10 aimed in the appended claims to cover all such modifications as fall within the true spirit and scope of the invention.

What is claimed is:

1. In a telephone system, a local exchange, 15 local subscribers' lines terminating in said exchange, automatic switches in said exchange for completing connections to said local subscribers' lines, a plurality of pairs of conductors extending from said local exchange to a remote operator, means responsive to a local subscriber calling for automatically selecting an idle pair of conductors from among said plurality of conductors for automatically signalling the remote operator over said idle pair of conductors and for selecting one of said switches, means at the local exchange controlled by the operator over a circuit including both said conductors in series for operating said one switch into connection with the called line, and means at the local exchange 20 controlled by the operator over a circuit including both said conductors in parallel for ringing the called subscriber by way of said switch.

2. In a telephone system, a local exchange, 25 local subscribers' line terminating in said exchange, automatic switches in said exchange for completing connections between said local subscribers' lines, a plurality of pairs of conductors extending from said local exchange to a remote operator, means responsive to a local subscriber calling for automatically selecting an idle pair of conductors from among said plurality of conductors for automatically signalling the remote operator over said idle pair of conductors and for selecting one of said switches, means at the local exchange controlled by the operator over a 30 circuit including both said conductors in series for operating said one switch into connection with the called line, a differential relay in the local exchange connected to both said conductors, means controlled by the operator for operating said differential relay over a circuit including both said conductors in parallel, and ringing means at the local exchange for connecting ringing current to the called line by way of said operated switch in response to said operations.

3. In a telephone system, a local exchange, 35 local subscribers' lines terminating in said exchange, automatic switches in said exchange for completing connections between said local subscribers' lines, a plurality of pairs of conductors extending from said local exchange to a remote operator, means responsive to a local subscriber calling for automatically selecting an idle pair of conductors from among said plurality of conductors for automatically signalling the remote operator over said idle pair of conductors and for selecting one of said switches, and for operatively connecting the calling line in a talking circuit over said conductors, means at the local exchange controlled by the operator dialling the 40 digits of the called line over a circuit including both said conductors in series for operating said switch into connection with the called line, means at the local exchange automatically operated after the dialling period for automatically discon-

necting the calling line from said conductors and for connecting the called line to said conductors to complete a talking circuit between the called line and the operator excluding the calling line, means at the local exchange controlled by the operator over a circuit including both said conductors in parallel and means at the local exchange for reconnecting the calling line to said conductors in response to the first actuation of said last means and for connecting ringing current to the called line in response to subsequent actuation of said last means.

4. In a telephone system wherein an operator at a control center remote from a local exchange controls automatic switches in the local exchange 15 over one of a plurality of common control trunks to complete direct connections between local subscribers' lines, a second local exchange having automatic switches controlled over said control trunk to complete direct connections between 20 local subscribers' lines therein, two branches of said control circuit at said first local exchange, the first of said branches terminating in the first local exchange and the second branch terminating in the second local exchange, means in each 25 branch at the first local exchange operated responsive to a subscriber in either local exchange initiating a call for seizing an idle one of said trunks by way of its corresponding branch, and means responsive to said seizure for preventing 30 the seizure of said trunk over the other branch and for automatically signalling the remote operator over said trunk.

5. In a telephone system, a local exchange, 35 local subscribers' lines terminating in said exchange, a plurality of finder-connector links for completing connections between said lines, a plurality of remote control relay groups common to said links, a plurality of control trunks common to said remote control relay groups extending 40 from said local exchange to an operator's position in a remote operating center, means responsive to a local subscriber calling for operating a finder of an idle finder-connector link to find the calling line, to select an idle one of said remote 45 control relay groups, to select an idle one of said control trunks, for signalling the operator over said control trunk, and for connecting the calling line to said control trunk, means responsive to the remote control operator answering and 50 dialling the number of the called line for operating the associated connector switch of said link to extend a connection to the called line, means controlled by the operator over said control trunk for ringing the called subscriber, a talking circuit including a portion of said control trunk connected in series between the finder connector of 55 the link for connecting the calling and called subscribers and the operator, operator controlled means for disconnecting said control trunk from said finder-connector link, means operated responsive to said disconnecting means for excluding said portion of the control trunk from 60 said talking circuit to complete a direct talking circuit between said lines including only the 65 finder and connector of said link, and means responsive to said finder finding the calling line for preselecting an idle one of said finder connector links.

6. In a telephone system wherein an operator 70 remote from a local exchange controls automatic switches in the local exchange over a control trunk to complete desired connections between local subscribers' lines in response to the initiation of a call by any local subscriber, local pay-

- station lines also terminating in the local exchange, paystation tone generating means in the local exchange, means operated responsive to a paystation initiating a call for connecting the calling line to said control trunk and for signalling the operator, means for momentarily connecting said tone generating means to said control trunk when the operator answers to indicate that the call is from a paystation line, and means 5 in said local exchange controllable over said control trunk for momentarily reconnecting said tone generating means to said control trunk during the time the connection between the calling paystation line and the remote operator is maintained.
- 10 7. In a semi-automatic telephone system, a first and a second exchange, switches at said exchanges, an operator's position at a third exchange, trunk lines interconnecting said first exchange with said second exchange and said second exchange with said operator's position, a subscriber's line terminating in said first exchange, means operated responsive to the initiation of a call by said subscriber for automatically 15 extending a talking connection via said first and second exchange automatic switches and interconnecting exchange trunk lines to said operator's position, and means operated responsive to the extension of said talking connection to said 20 operator's position for transmitting a tone signal to notify said calling subscriber that the connection has been established.
- 25 8. In a telephone system wherein an operator remote from a local exchange controls automatic switches in the local exchange over any one of a plurality of control trunks to complete connections between local subscribers' lines in response to the initiation of a call by any local subscriber, means responsive to the initiation of a call by 30 any one of said subscribers for automatically extending a talking connection via certain of said switches and an idle one of said control trunks to said remote operator, and means for transmitting a tone signal to the calling subscriber to indicate that the connection is established over 35 one of the control trunks.
- 35 9. In a semi-automatic telephone system, a first and a second exchange, switches at said exchanges, an operator's position at a third exchange, a trunk line interconnecting said first and second exchanges, a trunk line interconnecting said second and third exchanges, a subscriber's line terminating in said first exchange, means operated responsive to the initiation of a call by said subscriber for automatically extending 40 a talking connection via said switches and trunk lines to said operator's position, means operated responsive to the extension of said connection to said position for transmitting a tone signal to notify the calling subscriber that the connection is established, and means for storing an initiated call when the trunk lines interconnecting any of said exchanges are busy and for extending said stored call to the operator's position at said third exchange when the busy condition is removed.
- 45 10. In a semi-automatic telephone system, a first and a second exchange, switches at said exchanges, an operator's position at a third exchange, a trunk line interconnecting said first and second exchanges, a trunk line interconnecting said second and third exchanges, a subscriber's line terminating in said first exchange, means operated responsive to the initiation of a call by said subscriber for automatically ex-

tending a talking connection via said switches and trunk lines to said operator's position, means operated responsive to the extension of said connection to said position for transmitting a tone signal to notify the calling subscriber that the connection is established, and means effective responsive to a busy trunk line being encountered for preventing transmission of said tone signal and for storing an initiated call to permit the calling subscriber to hang up his receiver.

10 11. In a semi-automatic telephone system, a first and a second exchange, switches at said exchanges, an operator's position at a third exchange, a trunk line interconnecting said first and second exchange, a trunk line interconnecting 15 said second and third exchanges, a subscriber's line terminating in said first exchange, means operated responsive to the initiation of a call by said subscriber for automatically extending a connection via said switches and trunk lines to said operator's position, means operated responsive to the extension of said connection to said position for transmitting a tone signal to notify the calling subscriber that the connection is established, means effective responsive to a busy 20 trunk line being encountered for storing an initiated call to permit the calling subscriber to hang up his receiver, and means responsive when said busy trunk line becomes idle for extending said stored call to said operator's position.

25 12. In a telephone system, a satellite exchange, subscribers' lines terminating in said exchange, a link at said exchange for completing connections between said lines, a sub-tandem exchange, 30 a tandem exchange, a control center, a trunk line interconnecting said satellite and sub-tandem exchanges, a trunk line interconnecting said sub-tandem and said tandem exchanges, a trunk line interconnecting said tandem exchange and said control center, means responsive to a subscriber calling for automatically connecting the 35 said calling subscriber with said link and for automatically completing a connection via said exchanges and interconnecting trunk lines to signal the operator at said control center, means at said control center for controlling the link over the 40 trunk lines of the established connection to connect said calling subscriber's line with a desired call subscriber's line and for releasing the trunk line interconnecting the sub-tandem and tandem exchange and the tandem exchange and control center, subscriber controlled means for releasing and restoring said link, and timing means at said 45 sub-tandem exchange effective to release and restore said link after the elapse of a predetermined time interval in the event that the connected subscribers fail to operate said subscriber controlled means.

50 13. In a telephone system, a first exchange, a remote operator's position, a second exchange, 55 automatic switches in said first exchange operable to enable any local subscribers thereto to extend connection to any other local subscriber and to said remote operator's position, control relay groups at said first exchange, trunk lines 60 interconnecting said first exchange and said operator's position, means controllable by a calling local subscriber when a connection to said second exchange is desired for operating said automatic switches to find and seize an idle one 65 of said relay groups, means operated responsive to the seizure of a relay group for automatically connecting an idle one of said interconnecting trunk lines to said seized control group and for signalling said operator, an incoming connector 70

in said first exchange individually associated with the seized control relay group, trunk lines to said second exchange accessible to said incoming connector, and means controllable from said operator's position over the connected remote operator's trunk line and control relay group for disconnecting and holding said calling local subscriber's line disconnected from said remote operator's trunk line and for operating said incoming connector to find and seize an idle trunk line extending to said second exchange.

14. In a telephone system, a first exchange, a remote operator's position, a second exchange, automatic switches in said first exchange operable to enable local subscriber thereat to extend connections to any other local subscriber and to said remote operator's position, control relay groups at said first exchange, trunk lines interconnecting said first exchange and said operator's position, means controllable by a calling local subscriber when a connection with a subscriber in said second exchange is desired for operating said automatic switches to find and seize an idle one of said relay groups, means operated responsive to the seizure of a relay group for automatically connecting an idle one of said interconnecting trunk lines to said seized control group and for signalling said operator, an incoming connector in said first exchange individually associated with the seized control relay group, trunk lines to said second exchange accessible to said incoming connector, automatic switches in said second exchange having access to subscribers' lines local to the said second exchange, and means controllable from said remote operator's position over said connected remote operator's trunk line and control relay group for disconnecting and holding said calling subscriber's line disconnected from said remote operator's trunk line, for operating said incoming connector to find and seize an idle trunk line extending to said second exchange, and for controlling the said second exchange switches to extend a connection to a desired one of said second exchange local subscriber's lines.

15. In a telephone system, a first exchange, a remote operator's position, a second exchange, automatic switches in said first exchange operable to enable local subscribers thereat to extend connections to any other local subscriber and to said remote operator's position, control relay groups at said first exchange, trunk lines interconnecting said first exchange and said operator's position, means controllable by a calling local subscriber when a connection with a subscriber in said second exchange is desired for operating said automatic switches to find and seize an idle one of said relay groups, means operated responsive to the seizure of a relay group for automatically connecting an idle one of said interconnecting trunk lines to said control group and for signalling said operator, an incoming connector in said first exchange individually associated with the seized control relay group, trunk lines to said second exchange accessible to said incoming connector, automatic switches in said second exchange having access to subscribers' lines local to the said second exchange; means controllable from said remote operator's position over said connected operator's trunk line and control relay group for disconnecting and holding said calling subscriber's line disconnected from said remote operator's trunk line, for operating said incoming connector to find and seize an idle trunk line extending to said second exchange, and for controlling the said second exchange switches to extend a connection to a desired one of said second exchange local subscriber's lines; a source of ringing current at said second exchange, and a control key at said operator's position operated twice to connect said ringing current to the called subscriber's line, only the second and subsequent operations of said control key by said remote operator ringing the called subscriber's bell.

second exchange switches to extend a connection to a desired one of said second exchange local subscriber's lines; a busy tone source at said second exchange, means responsive when the desired subscriber's line is engaged when a connection is made therewith for connecting said busy tone source to said connection to indicate to the remote operator that the desired subscriber's line is busy, and a control key at said operator's position momentarily operated for releasing said incoming connector and second exchange automatic switches to disconnect from the connected second exchange subscriber's line and for reconnecting the local first exchange subscriber to the remote operator's trunk line.

16. In a telephone system, a first exchange, a remote operator's position, a second exchange, automatic switches in said first exchange operable to enable local subscribers thereat to extend connections to any other local subscriber and to said remote operator's position, control relay groups at said first exchange, trunk lines interconnecting said first exchange and said operator's position, means controllable by a calling local subscriber when a connection with a subscriber in said second exchange is desired for operating said automatic switches to find and seize an idle one of said relay groups, means operated responsive to the seizure of a relay group for automatically connecting an idle one of said interconnecting trunk lines to said control group and for signalling said operator, an incoming connector in said first exchange individually associated with the seized control relay group, trunk lines to said second exchange accessible to said incoming connector, automatic switches in said second exchange having access to subscribers' lines local to the said second exchange; means controllable from said remote operator's position over said connected operator's trunk line and control relay group for disconnecting and holding said calling subscriber's line disconnected from said remote operator's trunk line, for operating said incoming connector to find and seize an idle trunk line extending to said second exchange, and for controlling the said second exchange switches to extend a connection to a desired one of said second exchange local subscriber's lines; a source of ringing current at said second exchange, and a control key at said operator's position operated twice to connect said ringing current to the called subscriber's line, only the second and subsequent operations of said control key by said remote operator ringing the called subscriber's bell.

17. In a telephone system, a first exchange, a remote operator's position, a second exchange, automatic switches in said first exchange operable to enable local subscribers thereat to extend connections to any other local subscriber and to said remote operator's position, control relay groups at said first exchange, trunk lines interconnecting said first exchange and said operator's position, means controllable by a calling local subscriber when a connection with a subscriber in said second exchange is desired for operating said automatic switches to find and seize an idle one of said relay groups, means operated responsive to the seizure of a relay group for automatically connecting an idle one of said interconnecting trunk lines to said control group and for signalling said operator, an incoming connector in said first exchange individually associated with the seized control relay group, trunk lines to said second exchange accessible to said incoming connector, automatic switches in said second exchange

- change having access to subscribers' lines local to the said second exchange; means controllable from said remote operator's position over said connected operator's trunk line and control relay group for disconnecting and holding said calling subscriber's line disconnected from said remote operator's trunk line, for operating said incoming connector to find and seize an idle trunk line extending to said second exchange, and for controlling the said second exchange switches to extend a connection to a desired one of said second exchange local subscriber's lines; a source of ringing current at said second exchange, a control key at said operator's position operated twice to connect said ringing current to the called subscriber's line, only the second and subsequent operations of said control key by said remote operator ringing the called subscriber's bell, and means at said operator's position for releasing the trunk line interconnecting said first exchange and said remote operator's position to connect the calling first exchange subscriber to the called second exchange subscriber after the called subscriber has answered.
18. In a telephone system, a calling subscriber's line, a remote operator's position, a plurality of switching relay groups, trunk lines extending to said remote operator's position, means for connecting said calling subscriber's line with one of said switching relay groups, means for automatically finding the said relay group to connect an idle one of said trunk lines thereto and for signalling said operator, an incoming switch individually associated with each of said switching relay groups, a plurality of groups of trunk lines extending to distant exchanges accessible to each of said incoming switches, means at said operator's position for holding the calling subscriber's line and for directly controlling the incoming switch associated with the said one switching relay group over the connected operator's trunk line to select a particular group of said distant exchange trunk lines, and means in said incoming switch for automatically selecting an idle one of the trunk lines in the selected group.
19. In a telephone system, a first exchange, a second exchange, subscriber's lines at said exchanges, a remote operator's position, a switching point, a plurality of control trunk lines extending to said operator's position, an incoming connector at said switching point, a plurality of trunk lines interconnecting said first exchange and said switch point, a plurality of trunk lines interconnecting said second exchange and said switch point, means operated responsive to the initiation of a call by a subscriber at said first exchange for causing an idle interconnecting trunk line from said switch point to find and

connect with the calling line, means at said switching point operated responsive to the connection of a trunk line to said calling line for automatically connecting an idle one of said control trunks to said switching point and to signal the remote operator, and means controlled by the remote operator over the said connected control trunk and connected switching point for operating said incoming connector to find and connect with an idle trunk line interconnecting said switch point and said second exchange to connect with a called subscriber in said second exchange.

20. In a telephone system, a remote operator's position, a first exchange, a plurality of control relay groups in said first exchange, a plurality of hunting switches in said first exchange, a like plurality of trunk lines extending from said remote exchange, each of said trunk lines terminating in a different one of said hunting switches and each of said plurality of control relay groups accessible to all of said plurality of hunting switches, means in said first exchange for seizing an idle one of said control relay groups to extend a connection to the remote operator, means operated responsive to the seizure of an idle one of said control relay group for controlling a predetermined one of said hunting switches to search for the seized control relay group, and means operated responsive to said hunting switch finding said control relay group for signalling the remote operator over the trunk line terminating in said predetermined hunting switch.

21. In a telephone system a remote operator's position, a first exchange, a plurality of relay groups in said first exchange, a plurality of hunting switches, a plurality of trunk lines extending from said remote operator's position, each one of said trunk lines terminating in a corresponding one of said hunting switches and all of said hunting switches having access to all of said relay groups, means operated responsive to a call from said first exchange to said remote operator's position for seizing one of said relay groups, means operated responsive to the seizure of one of said relay groups for controlling one of said hunting switches to find the seized relay group to complete the connection between the calling subscriber in the first exchange and the remote operator, and means operated responsive to a call from said remote operator's position for controlling the hunting switch individually associated with the trunk line seized by the operator to find and connect with an idle one of said relay groups in said first exchange.

JOHN H. VOSS.
